UNITED STATES PATENT OFFICE.

WILLIAM L. DODGE, OF MAPLEWOOD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 2, 1921. Serial No. 482,189.

To all whom it may concern:

Be it known that I, WILLIAM L. DODGE, a citizen of the United States of America, residing at Maplewood, in the county of 5 Essex, State of New Jersey, have invented certain new and useful Improvements in Telephone-Exchange Systems, of which the following is a full, clear, concise, and exact description.

- 10 This invention relates to a telephone exchange system and more particularly to a system equipped with machine switching mechanism for extending connections from subscribers' lines: In its more specific 15 aspect this invention relates to means for transferring the control of switching mechanism from one switching center or control position to a second switching center or control position.
- 20 In telephone exchange systems in which connections between subscribers' lines are established by machine switching means, it is the usual practice to provide a special operator's position, sometimes known as the 25 "zero operator's position," for handling special service calls, such as calls to the information and complaint desks of the office and calls to outside exchanges or toll points. Such an operator's position is located on 30 the "A" board of the office and is reached by the calling subscriber through the dialing of a single digit zero, or by a special routing determined by the line designation which the calling subscriber dials and the 35 restricted service conditions which have been imposed upon the calling subscriber under the terms of his contract with the telephone company.

The zero operator in response to calls 40 coming to her position determines the nature of the service desired from the calling subscriber, and then takes steps to extend the calling subscriber's line to such special operators' positions of the exchange as to 45 enable the desired service to be effectively rendered. To enable the zero operator to more rapidly and economically perform her duties, she is provided with semimechanical equipment comprising link circuits, each 50 terminating at one end in an answering plug and at the other end in a selector switch, keyboards upon which she may record line designations transmitted to her by calling

subscribers, and office senders of the register type, the registers of which are set by the 55 depressed keys of the keyboard in accordance with desired line designations for controlling the selector switches to extend connections from her position.

Ordinarily, the zero operator is required 60 to render only a limited character of service, as hereinbefore outlined, and, therefore, a small number of groups of trunks outgoing from her selector switches is adequate for 65 routing calls from her position to the different service desks or toll positions of the office. Consequently, the office senders which are assigned for her use, which hereinafter will be termed suburban senders, 70 may be comparatively simple in construction inasmuch as they are not required to control the many and more complex routings of calls to the several offices of the exchange area.

It is, however, advisable to provide means 75 for enabling subscribers to receive aid in securing connections to any subscribers' lines of the exchange area. This is especially true during the period immediately following the cut-over of the exchange from 80 manual operation when the subscribers are unfamiliar with the use of their calling dials and the necessary procedure for obtaining desired connections, or for other 85 reasons desire the operator to control the establishment of connections. Since it is not advisable on account of the expense entailed to provide all of the senders of the operator's position with facilities for controlling all connections which subscribers 90 may request, a small number of complete 95 office senders capable of controlling the establishment of connections to all offices of the exchange area are provided at the "A board" accessible to the zero operators' positions over one of the groups of trunks outgoing from the operators' selector switches. These senders, which will hereinafter be termed local senders, are associated with district and office selector switches 100 which provide a large number of outgoing trunking paths to the several offices and districts of the exchange.

If upon communicating with the calling subscriber the operator ascertains that the 105 subscriber desires a connection with a line

in an office of the exchange which is not directly accessible over the trunk circuits outgoing from her position, she then records the full designation of the desired line, including both the office and numerical designation, upon one of her keyboards, whereupon an idle suburban sender at her position functions to select an idle trunk having access to an idle local sender and to then transfer the line designation to the registers of the local sender. The local sender then functions in the usual manner to control the establishment of the desired connection.

It is, therefore, the principal object of this invention to provide means for transferring the registration of line designations from one office sender to a second office sender for the purpose of enabling the establishment of connections under the control of the second sender.

A further object of the invention is the provision of means for transferring the registration of line designations from one office sender to a second office sender either adjacent to or remote from the first sender by means of code impulses.

A still further object of the invention is the provision of means for variously setting the translator switch of an office sending mechanism by means of code impulses.

These and other objects of the invention will be apparent from the following description taken in connection with the accompanying drawings. While the invention has been illustrated in connection with the transfer of line designations from suburban senders to local senders at the "A board" of the office, it is obvious that the second sender may be more remotely removed from the zero position and, therefore, operate as a tandem switching sender.

Indeed, the principles involved in the setting of the registers of the local sender by means of code impulses, and the operation of the sender in response to the setting of its registers may be broadly applied to the control of connections through tandem offices of the exchange area.

The accompanying drawings disclose one embodiment of the invention as applied to the zero operator's position of a telephone exchange system.

Fig. 1 shows one of a plurality of subscribers' lines terminating in a full mechanical office of the exchange, a diagrammatical representation of the line switch, a district selector and office sending-mechanism of the originating office, one of a group of trunk circuits extending from the district selector bank to a zero operator's position, and the answering plug of a plug ended district link at the operator's position.

Fig. 2 shows one of the zero operator's link circuits, the district selector switch in which the link circuit terminates, and the

supervisory and controlling circuits associated with the link circuit.

Figs. 3 to 5 inclusive, taken together, show the operator's keyboard and one of the associated sender selector link selector circuits of a group individual to the operator's position. Of these figures Fig. 3 shows the sender selector and allotter circuit comprising a district link selector, a sender selector, and an allotter for allotting idle sender selector circuits; Fig. 4 shows the key control circuit for determining the sequential functioning of the several banks of the associated operator's keyboard and the transmission of code signals to the register relays of the selected sender in accordance with the digital designation of the various keys in each bank of the keyboard and Fig. 5 shows the operator's keyboard comprising four rows of routing keys, three rows of tandem keys, four rows of numerical keys, and one row of stations keys and circuits for associating the keyboard with the key control circuit of Fig. 4.

Figs. 6 to 12 inclusive show the circuits of one of the suburban register senders common to the zero operator's position at the special "A" board of the office and adapted to be connected to the operators' keyboards and key control circuits through the sender selector shown in Fig. 3, and to the operators' link circuits through the link selector of Fig. 3. Of these figures, Fig. 6 shows eight groups of register relays for registering the codes corresponding to keys depressed in the tandem, numerical and stations rows of the operator's keyboard; Fig. 7 shows the register control circuit of the sender for sequentially associating the several groups of register relays with the key control circuit for registering in proper sequence the tandem and numerical digits of a line designation recorded upon the keyboard; Fig. 8 shows the circuits of a translator or route switch which determines the selective movements of the operator's district selector, the setting of the class switch of the sender, the compensation of the resistance in the fundamental switch control circuit in accordance with the character of various connections, and the control of office selectors through which connections may be routed from the operators' district links, and register relays and controlling circuits for enabling the translator switch to assume a setting in accordance with the code determined by the depressed route keys of the operator's keyboard; Fig. 9 shows the relay call indicator impulser which is controlled in accordance with the setting of the sender register relays of Fig. 6 to transmit tandem and numerical code impulses for setting the registers of a local sender; Fig. 10 shows the circuits of the class switch for changing the operating circuits of the sender in accord-

100
105
110
115
120
125
130

ance with the character of desired connections; Fig. 11 shows the sender circuit comprising a group of impulse counting relays, a fundamental circuit controlling relay, a 5 sender stepping relay, and an auxiliary switch for controlling the various sender circuits and Fig. 12 shows the sender control circuit which operates in conjunction with the sender circuit of Fig. 11 and the sender 10 selector circuit of Fig. 3.

Fig. 13 shows one of a plurality of local 15 sender district link circuits accessible from the zero operator's district of Fig. 2, the district selector in which this link circuit terminates, a sender finder switch individual to the link circuit for associating the link with an idle local sending mechanism, and the 20 controlling mechanism associated with the link. Fig. 14 shows an interoffice trunk circuit terminating at a manual office in a call-extending terminal plug, the associated manual operator's supervising equipment and an 25 interoffice trunk terminating in a terminating manual operator's position.

Figs. 15 and 16, taken together, show the 30 registers and indicating lamps of a call indicator associated with the incoming trunks of the manual office, Fig. 15 showing the control relays of the indicator and the register 35 relays and indicator lamps for indicating the stations and tandem hundreds digits of line designations, and Fig. 16 showing the register relays and indicator lamps for indicating the tens and units tandem digits and the thousands, hundreds, tens and units numerical 40 designations of line designations.

Figs. 17 to 24 inclusive show the circuits 45 of one of the local register-senders common to the special "A" board of the office and adapted to be taken for use by a zero operator. Of these figures Fig. 17 shows the sender control circuit which operates in conjunction with the sender circuit of Fig. 22 and with the local register circuit of Fig. 18; Fig. 18 shows a portion of the relay register control circuit for receiving code impulses incoming to the local sender and directing them sequentially to the relay registers shown in Fig. 19; Fig. 19 shows the remainder of the register control circuit and a plurality of groups of register relays for registering the tandem, numerical and stations 55 codes of line designations transmitted to the sender; Fig. 20 shows the "A" and "B" code registers for registering the proper codes for routing calls to the several offices of the exchange area, which registers assume a setting from the tandem register relays of Fig. 19, the translator switch which is variously set in accordance with the combined 60 settings of the "A" and "B" code registers, and a pulse machine for variously energizing the translator register relays of the 65 sender shown on Fig. 21, in accordance with

the office code settings assumed by the translator switch; Fig. 21 shows the translator register relays of the sender which register the office codes for controlling the selective 70 positioning of district and office selectors for extending connections to desired offices of the exchange and the setting of the class switch and of the compensating resistance switch of the sender; Fig. 22 shows the sender circuit comprising a group of impulse counting relays, a relay for controlling the fundamental circuit, the sender stepping relay and a sequence switch for sequentially controlling the various functions of the sender; Fig. 23 shows a switch for controlling the class setting of the sender circuits and a switch for controlling the adjustment of the resistance of the fundamental circuit in accordance with the office designation of calls; and Fig. 24 shows the circuit of an impulser for transmitting codes of impulses to manual offices having relay call indicators for indicating the designations of desired lines terminating in such offices, or for transmitting codes of impulses to mechanical tandem 80 offices having senders similar to the local sender disclosed in Figs. 17 to 24, inclusive.

Fig. 25 is a diagram illustrating the manner in which the several figures of the drawing should be arranged to show the organization of circuits necessary for establishing a connection from a calling line, Fig. 1, through a zero operator's position in the originating office and a manual tandem office to a subscriber's line terminating in a distant manual office, Fig. 16.

Figs. 26 and 27 taken together with Fig. 27 beneath Fig. 26 disclose a table of sequence switch movements showing the positions of the various sequence switches at different times during the establishment of a connection.

Fig. 28 is a circuit diagram showing the manner in which connections may be established from a subscriber's line terminating in a full mechanical office to another subscriber's line local to the same office or to subscribers' lines in other offices through one or more mechanical tandem offices or through a manual tandem and manual terminating office. The figure also shows the manner in which such connections may be established with the aid of the zero operator.

Fig. 29 is a diagram illustrating the manner in which the several figures of the drawing should be arranged to show how connections may be established as outlined in Fig. 28 from a calling subscriber's line, Fig. 1, through the zero operator's position in the originating office, through two tandem switching offices and a manual tandem office to a subscriber's line terminating in a distant manual office, Fig. 16.

The subscriber's line switch 100, the dis-

trict selector 101 and the office sender 125, diagrammatically represented in Fig. 1, may be of the type fully disclosed in the patent to F. A. Stearn, No. 1,505,171, issued August 5 19, 1924, and since they enter only incidentally into the disclosure of this invention and form no essential part thereof, a further disclosure and description of them is deemed unnecessary herein.

10 The selector switch 250, Fig. 2, and the district selector 1350, Fig. 13, are of the well-known power driven panel type of the general construction disclosed in the patent to E. B. Craft and J. N. Reynolds 1,123,696, 15 issued January 5, 1915.

The translator switch 2000, Fig. 20, is also of the power driven panel type similar in construction to the switch shown in the above noted patent but provided with ten sets of brushes arranged in five pairs, the two brush sets of each pair being adapted to be tripped together. Ten banks of terminals of forty terminals each are provided to which the ten brush sets have access 20 respectively, the terminals of the banks being cross-connected as desired with the brushes of the pulse machine. The switch is also provided with an additional bank of test terminals which are connected to the 25 bank terminals of the "A" and "B" code registers, Fig. 20, and to contacts of the tandem units register relays of Fig. 19.

The district link selector DS, the sender selector SS, Fig. 3, the sender finder SF, 30 Fig. 13, and the "A" and "B" code registers, Fig. 20, are of the well-known step-by-step type. These switches have no normal position, the wipers thereof remaining in contact with the bank terminals last employed.

40 The pulse machine PM, shown diagrammatically in Fig. 20, comprises a constantly rotating drum of insulating material in which a plurality of groups of conducting terminals are embedded. These conducting 45 terminals are all connected to a common segment 2037 which is connected to battery through a brush 2036. In order to clarify the disclosure the pulse machine has been represented in Fig. 20 as a development of 50 the drum. Only a sufficient number of brushes of the pulse machine have been shown cross-connected to the bank terminals of the translator switch 2000 to illustrate the manner in which a single office code may be 55 registered upon the register relays of the sender, shown in Fig. 21.

Throughout the several figures of the drawing auxiliary switches have been illustrated for exercising local control over the 60 several portions of the circuit. These auxiliary switches may be of the type known as sequence switches described in the patent to J. N. Reynolds and C. F. Baldwin 1,127,808, issued February 9, 1915.

65 The translator switch shown in Fig. 8 is

of the power driven type divided into two units of twelve banks each. The two units of the switch are arranged to be driven in parallel by means of magnetically operated clutches.

The different pieces of apparatus constituting the essential parts of the disclosure having now been briefly described, it is thought that a clearer understanding of the invention may be had from a brief description 70 of the operation of the system and a detailed description of the circuits involved. The invention will first be considered in connection with the establishment of a connection to a manual office through a single intervening manual tandem office, the drawings being arranged in accordance with the diagram of Fig. 25. In general the system functions in the following manner: The subscriber 150 desiring a connection with a 75 special desk of the office, or desiring a toll connection, removes his receiver from its switch hook and through the operation of the line switch 100 becomes connected to a trunk line terminating in a district selector 80 101. The subscriber then proceeds to dial the digit 0 and through the operation of the full mechanical sender 125 obtains a connection with a trunk circuit 102 extending to the zero operator's position, Fig. 2. The 85 zero operator upon answering the call ascertains the connection which the calling subscriber desires, and proceeds to set up upon a keyboard associated with her position such a routing as will set the district 90 selector 250 upon the terminals of an idle trunk line extending to the special service desk or to the toll operator's position, as requested by the calling subscriber. In 95 response to the operation of a routing key of the keyboard, Fig. 5, the translator switch shown in Fig. 8 assumes a setting for routing the connection, and in accordance with the setting of this translator switch the 100 sender shown in Fig. 11 functions to selectively operate the district selector 250.

If upon the establishment of a connection between the operator's link circuit of Fig. 2 and the calling subscriber's line 150, the operator ascertains from the calling subscriber that a connection is desired to a subscriber's line in an office of the exchange area to which office the operator has no facilities for establishing direct connections, she will, therefore, record the complete designation 115 of the desired line upon her keyboard and depress a routing key for routing a connection from her district link circuit to a second district link circuit having access to all offices of the exchange. Following the depression of keys in her keyboard, the translator switch of her sender assumes a setting 120 for controlling the selective movements of the district selector 250 for routing the call to an idle local sender district link, and the 130

complete line designation recorded upon the keyboard is registered upon a plurality of groups of register relays.

Upon the seizure of the local sender 5 distinct link by the selector switch 250, a local office sender is associated with the seized link through the operation of the sender finder SF. The zero operator's suburban sender now functions through the relay call indicator impulser, Fig. 9, associated therewith, to 10 transmit codes of impulses as determined by the registration set up upon the groups of register relays, over the link circuit to the local sender where they are recorded upon 15 groups of register relays disclosed in Fig. 19. The code registers "A" and "B", Fig. 20, now assume settings in accordance with the office designation registered upon the tandem register relays of Fig. 19 for controlling the 20 setting of the translator switch 2000 and the registration of the office code upon the register relays of Fig. 21 to control the selective setting of the district selector 1350, and if 25 an office selector is also employed, the setting of such office selector to select an idle trunk extending to an office of the exchange in which the desired line terminates. In the case assumed the desired line is considered as 30 terminating in a distant manual office which is reached through a manual tandem office shown in Fig. 14, the manual tandem office being selected directly from the terminal banks of the selector switch 1350 without the employment of an office selector.

35 Following the setting of the district selector 1350 through the operation of the sender, in accordance with the registration on the register control relays, Fig. 21, the office code of the desired terminating office and the 40 numerical designation of the desired line in such office is registered upon the relay call indicator associated with the manual tandem office, Fig. 14, through the operation of the relay call indicator impulser, 45 Fig. 24. The codes of impulses transmitted by the impulser are determined by the registration set up upon the register relays, Fig. 19, of the local sender. Upon the establishment of a connection from the line of 50 the calling subscriber through the link circuits of Figs. 2 and 13, the manual tandem cord circuit of Fig. 14 and over the inter-office trunk to the terminating office, the zero operator's suburban sender and the local 55 sender which were employed in establishing connection are disconnected and revert to common use.

In order that the positions of the various 60 sequence switches associated with the circuits of this invention may be more readily ascertained at the various stages in the progress of a connection, a table disclosed in Figs. 26 and 27 has been prepared. The various sequence switches employed have 65 been designated at the top and bottom of

the vertical columns in Figs. 26 and 27 and the principal steps in the establishment of a connection have been indicated in the columns at the extreme right-hand and left-hand of these figures. Inasmuch as two 70 complete senders are involved, the sequence switches associated with one of these senders, that is, the A operator's suburban sender have been disclosed at the left-hand of the heavy vertical lines and the sequence 75 switches associated with the other or local sender are indicated at the right-hand of the heavy vertical lines, and the various steps indicated by the data set forth in the extreme right-hand column of the figures applies particularly to the sequence switches 80 at the right-hand of the heavy line and the data in the extreme left-hand column applies in a similar manner particularly to the sequence switches on the left-hand of the 85 heavy line.

The movements of the various sequence switches from one position to another where dependent upon the advance of another sequence switch have been indicated by two 90 numerals connected by a plus sign. Thus, for example, the movement of switch 220 from position 2 to 3 which is dependent upon switch 320 reaching position 4 is indicated 95 2+3. In connection with relay call indicator impulser switches 920 and 2420, the numeral 8 followed by a plus sign indicates that these switches advance out of position 8 and continue advancing until they reach their normal positions as indicated by the 100 numeral 1 preceded by a plus sign, and the various positions 12½, 16½, etc., intermediate these two positions indicate the termination of definite periods in the transmission of code impulses. 105

Initiation of a call.

Having now given a general description of the manner in which the apparatus is to be employed, a detailed description of the 110 method of extending a connection from the line of subscriber 150 to the line of the subscriber 1450 in a manual terminating office of the exchange will now be given. The calling subscriber upon removing his receiver from the switch hook closes a circuit for starting the line switch 100 in search of an idle trunk circuit extending to a district selector 101. As soon as an idle district 115 selector 101 has been seized the central office 120 sender 125 is associated with the trunk circuit in the manner fully set forth in the patent to F. A. Stearn, No. 1,505,171, issued Aug. 19, 1924, hereinbefore mentioned. The subscriber then proceeds to dial the digit 0 125 for adjusting the central office sender to set the district selector 101 upon an idle trunk circuit 102 extending to the zero operator's position of the originating office.

As soon as the trunk circuit 102 is seized 130

a circuit is established for the line relay 103 extending from battery through the right-hand winding of this relay, conductors 104 and 105, the tip conductor of trunk circuit 102, the winding of the supervisory relay (not shown) associated with district selector 101, and back through the ring conductor of trunk circuit 102, conductors 106 and 107, and to ground at the left-hand winding 16 of relay 103. Relay 103 energizes in this circuit and at its left-hand armature closes a circuit for the trunk signal lamp 108. At its right-hand armature relay 103 closes a circuit extending from battery through the 15 winding of slow to release relay 109, which relay upon energizing connects a busy ground potential to the multiples of test terminal 110 appearing in the banks of all selector switches having access to the trunk 20 circuit 102. This circuit may be traced from ground through the resistance element 111, the armature and contact of relay 109, and thence to the terminal 110. This circuit is effective for holding switches 100 and 101 25 in their operated positions until the zero operator takes down the connection.

The operator upon noting the illumination of the trunk lamp 108 inserts the plug 112 of an idle link circuit of her position in 30 the jack 113 of the trunk circuit 102 with which the trunk lamp 108 is associated. A circuit is now established from battery through the winding of sleeve relay 200, conductor 201, sleeve contact 114 of the plug 35 112, sleeve contact 115 of the jack 113, and thence to ground through the winding of cut-off relay 116. Both relays 200 and 116 energize in this circuit, relay 116 opening the circuit previously traced extending 40 through the windings of trunk relay 103 and at its right-hand armature closing a new circuit for maintaining relay 109 energized. Relay 109 being slow to release does not deenergize during the interval in which 45 relay 103 is deenergized before relay 116 has fully attracted its armatures. Relay 200 of the operator's link circuit upon energizing closes a circuit for the listening-in relay 203 which may be traced from battery through 50 the normally closed left-hand contacts of key 202, the winding of relay 203, the lower armature and contact of relay 200, and to ground through the lower right-hand contact of cam 204 (1 to 1 1/4). Relay 203 upon 55 energizing closes a locking circuit for itself independent of the contact of cam 204 extending from battery through the left-hand contact of key 202, the winding and inner armature of relay 203, and thence to ground 60 through the winding of relay 215. Relay 215 does not, however, energize in this circuit at this time since its winding is shunted by a direct connection to ground through the lower armature and contact of relay 200 65 and the lower right-hand contact of cam

204, but will energize, however, as soon as sequence switch 220 leaves position 1 1/4, as hereinafter described.

Upon the energization of relay 203 circuits for relays 205, 206, and 207 are established extending from ground through the outer armature of relay 203, thence in parallel through the windings of relays 205 and 206 to battery and through the right-hand winding of relay 207 to battery. Relay 206 70 upon energizing closes a circuit extending from battery through the supervisory lamp 208, the lower contact of cam 209 (1 to 2 1/2), and thence to ground through the armature contact of relay 206. Relay 205 at its inner 75 armature and contact establishes a circuit for the supervisory lamp 210 which may be traced from battery through the lamp, the left-hand contact of cam 211 (1 to 2 1/4), and thence to ground at the inner 80 armature and contact of relay 205. Both supervisory lamps 209 and 210 being now illuminated, the operator is apprised of the fact that the connection has been properly 85 extended from the calling subscriber's line 90 to her link circuit and that the circuits of the link are proceeding to function in the proper manner. Relay 205 at the contact of its outer armature prepares a circuit for the flashing relay 226, which circuit becomes 95 effective later in the progress of the connection.

Relay 207 upon energizing closes a locking circuit for itself extending from battery through the answering supervisory lamp 212, the armature and front contact of answering supervisory relay 213, which relay became energized over the trunk circuit extending through the calling subscriber's line as soon as the connection was 100 established with the operator's link circuit, thence to ground through the left-hand armature and left-hand winding of relay 207. At its right-hand armature and front contact relay 207 closes a circuit for driving 105 sequence switch 220 of the district link out of its normal position 1 into position 2, this circuit extending from battery through the driving magnet of switch 220, the lower left-hand contact of cam 219 (1), conductor 218, and thence to ground at the right-hand armature and front contact of relay 207. After leaving position 1 a circuit for the magnet of switch 220 is closed over the contact of the master cam 221 to insure the 110 movement of the switch into position 2 in the manner well-known in the art. As soon as the sequence switch leaves position 1 1/4 cam 204 opens its lower right-hand contact, thereby removing the shunt from around 115 the relay 215, and this relay then energizes in series with relay 203 and connects the tip and ring conductors 217 and 216 to the operator's set which is indicated at O. T. The operator is now able to converse with 120 125 130

the calling subscriber and receives from him instructions as to the further extension of the connection.

5 Association of a keyboard with the operator's link circuit.

As soon as sequence switch 220 reaches position 2 a starting circuit is established for starting an allotted district link selector DS in search of the operator's link circuit which has been taken for use. This starting circuit may be traced from battery through the windings of relays 301 and 302 in parallel, the left-hand and lower right-hand contacts of cam 300, conductor 224, the lower right-hand contact of cam 223 (2), and to ground at the back contact and inner left-hand armature of relay 222. Relay 301 upon energizing establishes a locking circuit for itself and for the relay 302 extending through its right-hand armature and front contact to cam 300 for maintaining relays 301 and 302 energized after sequence switch 320 leaves position 1 and opens the left-hand contact of cam 300. At its inner left-hand armature and front contact relay 301 establishes a circuit for relay 303 which may be traced from the armature contact of relay 301 through the upper left-hand contact of cam 304 (1 to 1 1/4), and to battery through the left-hand winding of relay 303. Relay 303 upon energizing establishes a circuit for relay 305 which may be traced through the right-hand winding of relay 305, the right-hand contact of cam 306 (1 to 1 1/4), conductor 307, the right-hand armature and front contact of relay 303, and thence to ground through the upper right-hand contact of cam 308 (16 to 5). Relay 305 upon energizing now establishes a circuit to advance sequence switch 320 into position 2 for controlling the operation of the district link selector DS and the sender selector SS. The circuit of sequence switch 320 may be traced from battery through the magnet winding of switch 320, the upper left-hand contact of cam 310 (1), right-hand armature and front contact of relay 305, and thence to ground through the lower left-hand contact of cam 311 (15 to 1).

With sequence switch 320 in position 2 a circuit is established for the stepping magnet 313 of the district link selector DS from battery through the winding and armature contacts of magnet 313, the upper contact of cam 314 (2), conductor 307, the right-hand armature and front contact of relay 303, and thence to ground at the upper right-hand contact of cam 308 (16 to 5). After sequence switch 320 leaves position 1 1/4 the initial energizing circuit of relay 303 is opened at the contact of cam 304, but so long as the test wiper 317 of switch DS engages test terminals connected to opera-

tors' link circuits which have not been placed in use, or are not in a calling condition, relay 303 remains locked over its right-hand winding, the upper contact of cam 315 (1 to 3), the left-hand armature and contact of relay 303, the right-hand contacts of cam 316, wiper 317, conductor 318, and the lower contacts of cam 267. The sequence switches of all operators' link circuits which are in a non-calling condition will be standing in position 1 and if link circuits have already been taken for use and are not, therefore, in a calling condition, the sequence switches will have advanced beyond position 2 3/4. When the calling district link circuit is found whose sequence switch 220 is in position 2, no circuit exists over conductor 318 and the lower contacts of cam 267 and the locking circuit of relay 303 is no longer maintained and relay 303 thereupon de-energizes opening the circuit of stepping magnet 313. The wipers of switch DS are now arrested in such a position as to connect the calling district link with the key control circuit, Fig. 4, and the operator's keyboard, Fig. 5.

Selection of an idle suburban sender.

At the time sequence switch 320 advanced into position 2 a circuit was also closed for stepping magnet 319 of the sender selector SS for advancing the wipers of this switch in search of an idle sender. The circuit for magnet 319 may be traced from battery through the winding and armature contacts of the magnet, the lower contact of cam 309 (2), the outer left-hand armature and contact of relay 305, and to ground through the upper left-hand contact of cam 311 (2). At the time sequence switch 320 moved out of position 1 1/4, the initial energizing circuit of relay 305 was opened at the right-hand contact of cam 306, but so long as the test wiper 324 of the switch SS engages terminals associated with busy senders, relay 305 is maintained locked to maintain the stepping circuit of magnet 319. The locking circuit of relay 305 may be traced from battery through the left-hand winding of relay 305, right-hand contacts of cam 321, the inner left-hand armature and front contact of relay 305, the right-hand contact of cam 322 (1 1/2 to 3), conductor 323, test wiper 324, conductor 325, the right-hand winding of relay 700, and thence to ground at the left-hand contact of cam 701 (2 to 18).

As soon as an idle sender is found the locking circuit of relay 305 is no longer maintained since this locking circuit will be opened at the lower contact of cam 701 of the idle sender, the sequence switch 720 of the register control circuit of such idle sender being in position 1. Upon the deenergization of relay 305 the circuit of magnet 319

is opened to arrest the hunting movement of switch SS and a circuit is established from wiper 324 over conductor 323, the right-hand contact of cam 322, the inner left-hand 5 armature and back contact of relay 305 to ground at the upper right-hand contact of cam 311 (1 to 3) for maintaining the seized sender busy until the sequence switch 320 reaches position 2 $\frac{3}{4}$ when busy potential is 10 applied to wiper 324 over conductor 326 and the lower right-hand contact of cam 308 (2 $\frac{3}{4}$ to 8 $\frac{1}{4}$).

Upon the deenergization of relay 305 a circuit is closed for advancing sequence 15 switch 320 into position 3, this circuit extending from battery through the magnet winding of switch 320, the lower left-hand contact of cam 310 (2), the right-hand armature and back contact of relay 305, conductor 20 327, the lower contacts of cam 328, the right-hand armature and back contact of relay 303, and thence to ground at the upper right-hand contact of cam 308 (16 to 5). To insure the movement of sequence switch 25 320 from position to position its driving circuit is maintained between positions over the master cam contact 312. Sequence switch 320 upon leaving position 2 $\frac{1}{2}$ opens the locking circuits of relays 301 and 302 at 30 the lower contact of cam 300, but these relays are held energized over a new holding circuit extending through the upper right-hand contact of cam 300 (2 $\frac{3}{4}$ to 8), wiper 329, conductor 330, the upper contacts of 35 cam 267, the right-hand armature and back contact of relay 222, and thence to ground through the lower left-hand contact of cam 257 until the district sequence switch 220 leaves position 2 $\frac{1}{4}$ when the holding conductor 40 330 is connected to ground through the lower left-hand contact of cam 267.

With sequence switch 320 in position 3 relay 305 is again energized over a circuit extending through its right-hand winding, the 45 upper contact of cam 306 (3 to 4), the outer left-hand armature of relay 302, wiper 332, conductor 333, the outer left-hand armature and back contact of relay 274, and thence to ground through the lower contacts of cam 225, and at its right-hand armature and front contact establishes a circuit for advancing sequence switch 320 into position 4. The driving circuit for sequence switch 320 50 may be traced from battery through the magnet winding of switch 320, the upper left-hand contact of cam 310 (3), the right-hand armature and front contact of relay 305, and thence to ground through the lower left-hand contact of cam 311 (3 to 4).

60 *Recording desired line designation on keyboard.*

As soon as sequence switch 320 of the allotted sender selector circuit reaches position

2, the lamp 344 is lighted over the lower left-hand contact of cam 308 to indicate to the operator that a keyboard has been associated and that she may proceed to record the line designation given her by the calling subscriber. It will be assumed that the designation is such that it is necessary for the operator to route the connection to a local sender at the special "A" board and that it is necessary for the operator to press No. 38 route key 500 to accomplish this. At the same time the operator depresses the tandem and numerical keys to designate the office and line designation of the desired line. Assuming that the desired line is in the Chelsea office and that the number is 3916-R, 80 the operator depresses tandem hundreds key 502, tandem tens key 503, tandem units key 504, thousands key 505, hundreds key 506, tens key 507, units key 508, and stations key 509. All of the depressed keys in the key-board are mechanically locked in the well-known manner under the control of the locking magnets shown in the uppermost portion of Fig. 5.

When the sender selector sequence switch 90 320 reaches position 3 a circuit is closed for energizing control relay 700 of the register control circuit which may be traced from battery through the left-hand winding of relay 700, the lower right-hand contact of cam 703 (1), conductor 702, conductor 344, wiper 343 of the sender selector SS, the right-hand contact of cam 304 (3 to 4), and thence to ground at the front contact of the inner left-hand armature of relay 301. Relay 700 upon energizing locks through its left-hand winding and left-hand armature contact to conductor 325, and to ground at the lower right-hand contact of cam 308, and at its inner right-hand armature and front 100 contact establishes a circuit over the upper right-hand contact of cam 704 (1) for driving register control sequence switch 720 into position 2 to prepare the register control circuits for controlling the route registration 110 upon the route register relays of Fig. 8.

Upon the depression of the route key 500, a circuit is established for relay 400 which may be traced from battery through the winding of relay 400, the upper right-hand and lower left-hand contacts of cam 401 (1), the lower left-hand contact of cam 402 (17 $\frac{3}{4}$ to 1), the upper left-hand contact of cam 403 (17 to 2), conductor 404, the right-hand contact of key 500, conductor 501, and thence to ground at the lower left-hand contact of cam 405. Relay 400 upon energizing locks through its inner right-hand armature over conductor 406, and thence over the circuit previously traced, and at its outer left-hand armature and front contact establishes a circuit for advancing the district sequence switch 220 out 120 125

of position 2 and into position 3. This circuit may be traced from battery through the magnet winding of sequence switch 220, conductor 227, the lower right-hand contact of cam 219 (2), conductor 334, wiper 335 of switch DS, the inner left-hand armature and contact of relay 302, the left-hand contacts of cam 336 (4), conductor 337, the lower contact of cam 338 (1) of allotter switch 339, conductor 340, the upper contacts of cam 407 (1), the inner left-hand armature and back contact of relay 408, and thence to ground at the outer left-hand armature and front contact of relay 400.

15 The advance of the district sequence switch 220 out of position 2 and into position 3 opens the circuit of relay 305, as previously traced, at the lower right-hand contact of cam 225 (2), and relay 305 upon deenergizing closes a circuit for advancing sequence switch 320 out of position 4 and into position 5. This circuit may be traced from battery through the magnet winding of switch 320, the lower left-hand contact 20 of cam 310 (4), the right-hand armature and back contact of relay 305, and thence to ground through the lower left-hand contact of cam 311 (3 to 4). A circuit is now closed for energizing relay 408 of the key control 25 circuit and relay 342 of the sender selector circuit which may be traced from battery through the right-hand winding of relay 408, the left-hand contact of cam 409 (1), conductor 410, the upper left-hand contact 30 of cam 341 (5), the winding of relay 342, the lower contact of cam 304 (5 to 7), and to ground at the inner left-hand armature and front contact of relay 301. Relay 408 upon energizing closes a locking circuit to 35 conductor 410 independently of the left-hand contact of cam 409 through its right-hand armature and contact and the right-hand contact of cam 409 (1 to 8), and closes a circuit for advancing sequence switch 420 of the key control circuit into position 2 for preparing the key control circuit for 40 controlling the transmission of code impulses for setting the route registers of Fig. 8. This latter circuit may be traced from 45 battery through the magnet winding of switch 420, the lower right-hand contact of cam 411 (1), conductor 412, the inner left-hand armature and front contact of relay 408, and thence to ground at the contact of 50 the outer left-hand armature of relay 400.

55 Relay 342 upon energizing in the circuit previously traced closes a circuit for relay 305 which may be traced from battery through the right-hand winding of relay 305, the lower left-hand contact of cam 306 (5 to 7), and thence to ground at the right-hand armature and contact of relay 342. A circuit is also established at this time 60 through the left-hand winding of relay 303, and to ground at the armature contact of 65 relay 342. With relays 303, 305 and 342 energized, conductors 352, 353, 354, 355 and 356 are extended from the key control circuit, Fig. 4, through the wipers of sender selector SS to a cable of conductors extending to the register control circuit, Fig. 7, preparatory to enabling the setting of the route registers of the sender. Upon the energization of relays 303 and 305, a circuit is also established for advancing sequence switch 320 out of position 5 and into position 6 which may be traced from battery through the magnet winding of switch 320, the upper left-hand contact of cam 310 (5), the right-hand armature and front contact 70 of relay 305, the lower right-hand contact of cam 314 (5), conductor 307, right-hand armature and front contact of relay 303, and thence to ground at the upper right-hand contact of cam 308 (16 to 5). After sequence switch 320 leaves position 5 the circuit for maintaining relay 342 energized 75 may be traced from conductor 410 through the upper contact of cam 309 (5 to 7), the outer left-hand armature and contact of 80 relay 305, and thence to the winding of relay 342 through the right-hand contact of cam 341 (5 to 7) in shunt of the left-hand contact of cam 341 which opens when the sequence switch leaves position 5.

85 As soon as sequence switch 320 reaches position 5 1/4, a circuit is closed for advancing the allotter switch 339 to allot a sender selector circuit to take care of the next call incoming to the operator's position. This circuit may be traced from battery through the magnet winding of allotter switch 339, the right-hand contact of cam 347 (1), conductor 346, and thence to ground at the left-hand contact of cam 345 (5 1/4 to 8). The 90 allotter switch 339 continues to rotate so long as ground potential is applied to its magnet winding over conductors similar to 346 of busy sender selector circuits, which conductors are connected to the contacts of 95 cams 347, 348 and 349. It will be assumed that when allotter switch 339 reaches position 7 the sender selector circuit corresponding to this position is idle, that is, its sequence switch is standing in either of positions 9 or 18, and, therefore, no ground potential is applied to the upper contact of cam 348 (7 or 16), over a conductor similar to conductor 346. When the allotter switch 100 105 110 115 120 125 339 stops in position 7 a circuit is closed from ground over the lower contact of cam 350, thence over a conductor corresponding to conductor 351 through the lower right-hand contact of a cam corresponding to cam 310 (9 or 18), and through the magnet winding of the sequence switch of the idle sender selector circuit. The sequence switch of such idle sender selector circuit is

thereupon advanced out of either sub-normal position 9 or 18 in which it is then standing into allotted position 10 or 1.

Setting route register relays.

When the operator completes the recording of the desired number upon her keyboard by depressing stations key 509, a circuit is established for relay 429 which may 10 be traced from battery through the winding of relay 429, conductor 518, contact 517, which is operated whenever any key in the stations row of the key bank is operated, conductor 428, and thence to ground at the 15 upper left-hand contact of cam 427 (2 to 9). Since the operator depressed a key in the fourth row of routing keys a circuit is also established for relay 415 which may be traced from battery through the winding 20 of this relay, conductor 416, row contact 510, which is closed whenever any key in the fourth row is depressed, and thence to ground on conductor 511.

Upon the energization of relay 415 ground 25 potential is applied to conductors 355 and 356 of the keyboard cable for operating route register relays 800 and 802, Fig. 8. The circuit for relay 800 may be traced over conductor 801, the upper contact of cam 30 705 (1 $\frac{3}{4}$ to 2), conductor 706, wiper 357 of sender selector SS, conductor 358, conductor 356, the lower contacts of cam 413, conductors 414 and 417, and thence to ground at the left-hand armature contact of relay 415. 35 The circuit of relay 802 may be traced over conductor 803, the lower left-hand and upper right-hand contacts of cam 707, conductor 708, wiper 359 of switch SS, conductor 360, the lower contacts of cam 316, the left- 40 hand armature and contact of relay 303, the lower contact of cam 315 (5 to 7), conductor 355, the upper contact of cam 418 (13 to 2), the lower right-hand contact of cam 419 (1 $\frac{3}{4}$ to 2), conductors 421 and 422, and thence to ground at the right-hand armature 45 contact of relay 415. Relays 800 and 802 upon energizing both lock through their right-hand armature contacts to conductor 804, and to ground at the upper left-hand 50 contact of cam 709 (1 $\frac{3}{4}$ to 9).

If the operator depressed a route key in the first row instead of the fourth row, then relay 415 would not have energized and neither relays 800 nor 802 would have become energized. If the depressed key had been in the second row, then conductor 414 would have been grounded through the row contact 521 and relay 800 would have energized, relay 802 remaining unenergized. If 55 a key in the third row had been depressed, row contact 522 of the third row of route keys would have connected ground potential to conductor 421 and relay 802 would have energized, relay 800 remaining deenergized. 60 In this manner the energized or deenergized 65

condition of register relays 800 and 802 determines the particular row in which the depressed route key is located.

Since the operator has depressed the No. 38 key in the fourth row of route keys a circuit is established at this time for energizing both register relays 805 and 806 which may be traced from ground through the windings of these relays, conductor 807, the lower left-hand and upper right-hand contacts of cam 710, conductor 344, wiper 343 of switch SS, conductor 353, the upper right-hand and lower left-hand contacts of cam 423, conductor 512, the left-hand contact of route key 500, conductors 513 and 514, the low resistance right-hand winding of relay 424 and resistance element 425 in parallel, the left-hand contact of cam 426 (1 $\frac{3}{4}$ to 2), and thence to battery. Since the low resistance winding of relay 424 is included in this 75 circuit both the sensitive relay 805 and marginal relay 806 energize and lock through their left-hand windings and left-hand armature contacts to ground on conductor 804. Relay 809 is energized at this time over a 80 circuit which may be traced from battery through the right-hand winding of marginal relay 809, conductor 810, the upper contacts of cam 714, conductor 715, wiper 361 of switch SS, conductor 362, conductor 352, the 85 upper right-hand contact of cam 402, the upper left-hand contact of cam 403, conductor 404, the right-hand contact of key 500, conductor 501, the right-hand contact of cam 430 (2), conductor 440, and thence through 90 the right-hand low resistance winding of relay 431 to ground at the left-hand armature and back contact of relay 432. Relays 431 and 809 energize in this circuit, relay 809 closing a locking circuit for itself 95 through its left-hand winding and left-hand armature contact to ground on conductor 804, and relay 431 locking through its right-hand armature and front contact at the normally closed contact of its right-hand armature removing the shunt from around the winding of relay 432, whereupon relay 432 100 energizes over a circuit traced through its winding and left-hand contact of cam 439 (2).

With relays 431 and 424 energized, a low resistance circuit is established for energizing relays 808 and 711 in series, which circuit may be traced from ground through relay 711, the upper contact of cam 712, conductor 713, the right-hand winding of marginal relay 808, conductors 811 and 716, wiper 363 of switch SS, the left-hand contact of cam 322, the inner left-hand armature and front contact of relay 305, the 105 lower right-hand and upper left-hand contacts of cam 364 (5 to 7), conductor 354, the upper contacts of cam 433, conductor 434, the left-hand armature and front contact of relay 424, conductor 435, and thence 110 115 120 125 130

to battery and ground through the left-hand armature and front contact of relay 431 and the low resistance 436. Since relay 424 is energized at this time the high resistance element 438 is shunted from the circuit previously traced over the lower contact of cam 433 and conductor 437. Thus, to register upon the route register relays the depression of route key No. 38 or the eighth key in the 5 fourth row of route keys, all of the route register relays 800, 802, 805, 806, 808 and 809 are energized, relays 800 and 802, as previously stated, determining the particular row in which the key is located, relay 808 10 determining whether the key is in the first five or last five of any row, and relays 805, 806 and 809 determining the particular key in either the first or last five of any row.

The following table shows the condition 20 of the various register relays as determined by the depression of any route key in any row and the current characteristics which exist on the several conductors of the keyboard cable for governing the operation of 25 the register relays:

Key No. 1	Conductor 353 connected to battery through high resistance 529	Relay 806 deenerg.
	Conductor 352 connected to ground through low resistance winding of relay 431	Relay 805 energ.
30	Conductor 354 connected to battery through high resistance elements 436 and 438	Relay 808 deenerg.
	Conductor 353 open	Relay 806 deenerg.

Relay 711 upon energizing in series with register relay 808 closes a circuit for advancing the register control sequence switch 720 out of position 2 and into position 3

over a circuit which may be traced from battery through the magnet winding of switch 720, the armature and front contact of relay 711, the lower left-hand and upper right-hand contacts of cam 717 (2), the armature and back contact of relay 718, the lower contacts of cam 719, conductor 721, the lower contacts of cam 1200 of the sender control sequence switch 1220, conductor 1201, the lower contacts of cam 1100 of sequence switch 1120 of the sender circuit conductor 1101, the upper contacts of cam 1000, conductor 1001, and thence to ground at the lower left-hand contact of cam 812 (1). In moving from position 2 to position 3 conductors 352 to 356 inclusive of the keyboard cable are disconnected from the route register relays preparatory to controlling the tandem hundreds registration. Upon the disconnection of conductor 352 the circuit previously traced through the winding of relay 431 is opened and this relay deenergizes, whereupon a circuit is established for advancing sequence switch 420 out of position 2 and into position 3, which circuit may be traced from battery through the magnet winding of switch 420, the upper right-hand contact of cam 411 (2), the right-hand armature and front contact of relay 432, thence to ground at the normal contacts of the right-hand armature of relay 431. As soon as sequence switch 420 leaves position 2 the circuit of relay 432 is opened at the contact of cam 439 and all conductors 352 to 356 inclusive of the keyboard cable are opened at the cams of the key control circuit unless the operator has at this time depressed the start key 515 to energize relay 429.

As soon as sequence switch 420 reaches position 3 a circuit is established for advancing sequence switch 320 into position 7 which may be traced from battery through the magnet winding of switch 320, the left-hand contact of cam 314 (6), conductor 307, the right-hand armature and front contact of relay 303, the right-hand contacts of cam 336 (6), conductor 365, and thence to ground at the upper right-hand contact of cam 427 (3 to 9). With sequence switch 320 in position 7 the tip conductor 333 of the fundamental circuit is connected through to the wiper 357 of the sender selector SS preparatory to controlling district brush selection at district selector 250.

Setting the translator switch, Fig. 8.

Since as hereinbefore stated a route key in the last five of the fourth row in the operator's key bank has been depressed, relays 800, 802 and 808 have been energized and locked, whereupon with sequence switch 720 in position 3 a circuit is established for advancing route sequence switch 820 out of its normal position and into position 9. Switch 130

820 is advanced from position 1 into position 8 over a circuit which may be traced from ground at the lower left-hand contact of cam 709 (3 to 9), conductor 722, the left-hand armature and front contact of relay 800, the outer left-hand armature and front contact of relay 802, the upper left-hand contact of cam 813, and thence to battery through the driving magnet of switch 820. 5
 10 and the winding of relay 814 in parallel. As soon as sequence switch 820 reaches position 8 it is further advanced into position 9 over a circuit extending from ground through the right-hand armature contact of relay 808. 15
 15 and the lower contact of cam 815 (8). Had the depressed key been in the first row and, therefore, relays 800 and 802 been both deenergized, switch 820 would have been driven into position 2, and if the key 20 had been in the second half of the row it would have been further advanced into position 3 through the energization of relay 808. In a similar manner, if the depressed key had been in the first half of the second 25 row with relay 800 energized and relay 802 deenergized, the sequence switch would have been driven into position 4 and further into position 5 by the energization of relay 808 if the key had been in the last five of the 30 second row. If the depressed key had been in the first half of the third row with relay 800 deenergized and relay 802 energized, then switch 820 would have been driven into position 6. For a depressed key in the last 35 half of the third row switch 820 would further advance into position 7 through the energization of relay 808.

With sequence switch 820 in position 9, as determined by the energization of relays 40 800, 802 and 808, ground potential is connected to the No. 38 terminal 816 of the translator switch TS from ground at the right-hand contact of cam 812 (2 to 9), the left-hand armature and back contact of relay 814, the right-hand armature and front contact of relay 805, the inner right-hand armature and front contact of relay 809, the inner right-hand armature and front contact of relay 806, conductor 819; the lower right-hand contact of cam 817 (9), and thence to bank terminal 816. 45

Upon the deenergization of relay 814 following the setting of the route sequence switch 820, a circuit is closed for the clutch 55 magnets 821 and 822 for advancing the two sections of the translator switch TS until the test wipers 828 and 827 engage a terminal in the banks T^2 and T^1 upon which ground potential has been placed through 60 the operation of the route register relays. The translator switch TS is divided into two sections each section comprising two hunting banks of terminals T^2 , T^3 and T^1 , T^4 of twenty-two terminals each, and each section

further comprising ten other banks of terminals arranged in five pairs. These pairs of banks are disclosed at the bottom of Fig. 8, the wipers serving the banks of each pair being arranged 180 degrees apart so that during the first half of the rotary movement of the translator switch the uppermost wipers cooperate with their respective banks for establishing connections with terminals 0 to 21 inclusive, and the lower wipers cooperating with their respective banks during the second half of the rotary movement of the switch for establishing connections over the bank terminals 22 to 43 inclusive. The pairs of banks T^8 and T^9 are employed for controlling the compensating resistance in the fundamental circuit; the pair of banks T^5 control the setting of class switch 1020; the pair of banks T^6 control district brush selection; the pair of banks T^7 control district group selection; the pair of banks T^{10} control office brush selection; the pair of banks T^{11} control office group selection; the pair of banks T^{12} control compensating resistance; the pair of banks T^{13} control second office brush selection; and the pair of banks T^{14} control second office group selection. The switch is divided into two sections in order to divide the driving load upon the driving clutch magnets. The circuit for clutch magnet 821 may be traced from battery through the winding of magnet 821, the outer right-hand armature and back contact of stop relay 823, conductor 824, and thence to ground through the outer right-hand armature and back contact of relay 814 and the right-hand contact of cam 812 (2 to 9). Similarly, the circuit of magnet 822 extends through the outer-left hand armature and back contact of relay 825, conductor 826, and thence to ground through the inner right-hand armature and back contact of relay 814 and the right-hand contact of cam 812. 100

When wipers 827 and 828 of the switch TS engage the grounded terminal 816 and the multiple thereof in bank T^2 , a circuit is closed from these terminals through wipers 827 and 828, and thence to battery through the windings of stop relays 825 and 823. Stop magnets 829 and 830 are also energized at this time in parallel with the windings of relays 825 and 823, respectively. Relay 825 upon energizing opens the driving circuit of magnet 822 and relay 823 opens the driving circuit of magnet 821. 110 The wipers of switch TS are now in position in engagement with the No. 38 terminals of their respective banks. From an inspection of the connection between the test terminals of banks T^1 to T^4 inclusive through the sequence switch cams shown at the right of Fig. 8, it will be obvious 120 how the translator switch may be set into

any one of forty selective positions through the selective operation of the route register relays.

Setting the class switch 1020.

- 5 Upon the energization of relays 823 and 825, a circuit is closed through bank T⁶ of the translator switch for setting the class switch 1020 into a position for controlling 10 the establishment of a connection to a sender having control of the establishment of connections in the local area. It will be assumed that for this purpose the class switch is set into position 12 over a circuit 15 which may be traced from battery through the magnet winding of switch 1020, the upper right-hand contact of cam 1002 (1 to 11), conductor 1003, terminal 831 in bank T⁶, wiper 832, conductor 833, the left-hand 20 armature and front contact of relay 823, and thence to ground at the inner left-hand armature and contact of relay 825. A circuit is also closed at this time to advance the sender sequence switch 1120 out of position 25 1 into position 2 for completing the establishment of the fundamental circuit between the office sender and the operator's district selector 250. This circuit may be traced from battery through the magnet 30 winding of sequence switch 1120, conductor 1102, the upper left-hand contact of cam 1103 (1), conductor 1104, the inner right-hand armature and contact of relay 823, and thence to ground at the intermediate 35 armature and contact of relay 825.

District brush selection.

- With sender sequence switch 1120 in position 2 and the district sequence switch 220 40 in position 3, a fundamental circuit is established which may be traced from battery through the right-hand winding of relay 222, the lower left-hand contact of cam 228 (3), the left-hand contact of cam 225 (2 to 6), the outer left-hand armature and back contact of relay 274, conductor 333, wiper 332, the outer left-hand armature and contact of relay 302, the left-hand contacts of cam 321 (7 to 8), conductor 358, wiper 357, 45 conductor 706, the lower contact of cam 705, conductor 723, the armature and back contact of relay 1105, conductor 1106, the upper contact of cam 1202 (16 to 14), conductor 1203, the winding of overflow relay 50 1107, the winding of sender stepping relay 1108, conductor 1109, the right-hand contact of cam 1110 (2), resistance element 1111, and thence to ground at the lower contact of cam 1112 (1 to 6). Relays 222 and 55 1108 energize in this circuit.

Upon the energization of relay 222 a circuit is closed for driving sequence switch 220 out of position 3 and into position 4 which may be traced from battery through 60 the left-hand contacts of cam 229, and to

ground at the inner left-hand armature and front contact of relay 222. As soon as the sequence switch leaves position 3 the initial energizing circuit of relay 222 is opened at the lower left-hand contact of cam 228 but 70 relay 222 remains locked to the fundamental circuit through its right-hand winding, right-hand armature and front contact and the lower right-hand contact of cam 228 (3 to 6).

When switch 220 reaches position 4 a circuit is established for the updrive magnet 230 of the district selector 250, which circuit may be traced from battery through the winding of magnet 230, the lower right-hand and upper left-hand contacts of cam 229, and thence to ground at the inner left-hand armature and front contact of relay 222. Magnet 230 upon energizing presses 80 the depending portion of switch shaft 231 against the constantly rotating updrive roller 232 whereby the switch shaft is driven upwardly in its brush selection movement. When the switch shaft approaches its first brush selection position the shaft wiper 235 85 engages the conducting portion of commutator segment 234, whereupon a circuit is established in shunt of the windings of the sender stepping relay 1108 which may be traced from battery through the right-hand winding and the right-hand armature and front contact of relay 222, the lower right-hand and upper left-hand contacts of cam 228, conductor 233, segment 234, wiper 235, and thence to ground at the upper contact 90 of cam 204 (9 to 7). Relay 222 is maintained energized over this shunt circuit but sender stepping relay 1108 becomes deenergized. As the switch shaft continues in 95 its upward movement the wiper 235 engages an insulating portion of segment 234, whereupon the shunt circuit is opened and relay 1108 again energizes. In this manner during the continued upward movement of the switch shaft relay 1108 is intermittently 100 energized and deenergized.

As soon as sequence switch 220 reached position 2 3/4 a circuit was established for lamp 208 extending from battery through the lamp, the left-hand contact of cam 209 (2 3/4 to 15), and to ground at the outer left-hand armature and back contact of relay 236, and a circuit was established for lamp 210 extending from battery through the lamp and to ground at the right-hand contact of cam 211 (2 3/4 to 10 1/4) for giving the operator a signal that selection is in progress.

At the office sender upon the initial energization of relay 1108, it being assumed that the translator switch has connected the No. 2 counting relay lead over its bank T⁶ for controlling district brush selection, a circuit is now effective for the No. 2 counting relay which may be traced from battery 125

- through the winding of the No. 2 counting relay 1113, the armature and back contact of the No. 2' counting relay 1114, the lower contact of cam 1115 (8 to 5), counting relay lead 1116, lead 1116, Fig. 8, bank terminal 834 of bank T^o, wiper 835, conductor 836, the upper right-hand contact of cam 1117 (2), conductor 1118, the left-hand contact of cam 1119 (1 to 2), the armature and contact of relay 1108, conductor 1122, and thence to ground at the upper left-hand contact of cam 1125 (2). Upon the energization of counting relay 1113 a locking circuit is closed through its winding, the winding of the No. 2' counting relay 1114, the armature and contact of relay 1113, and thence to ground at the right-hand contact of cam 1112 (2). Relay 1114 does not energize in this locking circuit until stepping relay 1108 deenergizes upon the engagement of shaft wiper 235 of the selector switch 250 with the first conducting segment of commutator 234. When relay 1114 energizes counting relay lead 1116 is extended through the armature and front contact of relay 1114 through the armature and back contact of the No. 1' counting relay 1124, thence to battery through the winding of the No. 1 counting relay 1123. Relay 1123 upon energizing locks through the winding of relay 1124 and its own armature contact to ground at the upper left-hand contact of cam 1112 (2), and upon the next deenergization of relay 1108 relay 1124 energizes in this locking circuit to extend counting relay lead 1116 through its armature and front contact over conductor 1131, the left-hand armature and back contact of transfer relay 1132, and thence to battery through the winding of the No. 0 counting relay 1127. In response to the next deenergization of relay 1108, the No. 0' counting relay 1128 energizes in parallel with relay 1105 in the locking circuit of relay 1127, relay 1105 opening the previously traced fundamental circuit at its armature and back contact, and relay 1128 closing a circuit for advancing sender sequence switch 1120 out of position 2 into position 4. This latter circuit may be traced from battery through the magnet winding of switch 1120, conductor 1130, the lower left-hand contact of cam 1129, and thence to ground at the armature contact of relay 1128. When switch 1120 leaves position 2 the locking circuits of the counting relays which have been energized are opened at the upper contacts of cam 1112.
- As soon following the opening of the fundamental circuit as the shaft wiper 235 engages the next insulating segment of commutator 234, the circuit of relay 222 is opened and relay 222 deenergizes to open the circuit of the updrive magnet 230 to arrest the upward movement of the switch shaft, with the third set of brushes carried thereby so positioned with respect to a finger on the tripping spindle 256 as to cause such set of brushes to be tripped upon the energization of trip magnet 237 and the subsequent upward movement of the switch shaft. At its inner left-hand armature and back contact relay 222 closes a circuit for advancing sequence switch 220 out of position 4 and into position 5, this circuit extending from battery through the winding of the magnet of switch 220, the left-hand contact of cam 223 (4), and to ground at the inner left-hand armature and back contact of relay 222. A circuit is now established for the trip magnet 237 extending from battery through the winding of magnet 237, and thence to ground at the right-hand contact of cam 257 (5 to 7).
- District group selection.*
- With switch 1120 of the sender in position 4 and switch 220 in position 5, the previously traced fundamental circuit is again established and relays 222 and 1108 again energize as previously described. Relay 222 upon energizing closes a circuit extending from battery through the magnet winding of switch 220, the left-hand contacts of cam 229, the inner left-hand armature and front contact of relay 222 for driving switch 220 out of position 5 and into position 6. Upon leaving position 5 the initial energizing circuit of relay 222 is opened at the lower left-hand contact of cam 228, but this relay is maintained energized over its right-hand winding, right-hand armature and front contact and the lower right-hand contact of cam 228 and thence over the fundamental circuit. With switch 220 in position 6 the circuit of the updrive magnet 230 is again established as previously traced and switch shaft 231 is now driven upwardly in its group selection movement by the updrive roller 232.
- During the initial portion of this upward movement the selected set of brushes is tripped and during the remaining portion of this movement the tripped set of brushes is moved upwardly to a desired group of terminals in the bank to which it has access. As the brush set approaches its first group selection position the shaft wiper 240 engages a conducting portion of the group selection commutator segment 239, whereupon a circuit is closed in shunt of the sender stepping relay 1108 which may be traced from battery through the right-hand winding and right-hand armature contact of relay 222, the right-hand contacts of cam 228, conductor 238, segment 239, wiper 240, and thence to ground at the upper contact of cam 204 (9 to 7). As the switch shaft continues in its upward movement the wiper 130

240 engages an insulating portion of segment 239 and the shunt circuit is again opened. Thus, during the continued upward movement of the switch shaft the shunt circuit is closed and opened, thereby causing the intermittent energization and deenergization of relay 1108.

Upon the initial energization of relay 1108, it having been assumed that wiper 838 of the translator switch TS has been so positioned as to establish a connection to the No. 1 counting relay lead, a circuit is established for the No. 1 counting relay which may be traced from battery through the winding of the No. 1 relay 1123, the armature and back contact of relay 1124, the lower contact of cam 1133 (8 to 5), counting relay lead 1134, lead 1134 Fig. 8, bank terminal 837 of bank T', wiper 838, conductor 839, the upper left-hand contact of cam 1117, conductor 1118, the right-hand contact of cam 1119 (3 to 4), conductor 1122, the armature and contact of relay 1108, conductor 1121, and thence to ground at the upper right-hand contact of cam 1125 (3 to 4). In the manner previously described, relay 1123 establishes a locking circuit for itself in series with relay 1124, and upon the first deenergization of relay 1108 relay 1124 energizes and extends the circuit from counting relay lead 1134 to the No. 0 counting relay 1127. Upon the next energization of relay 1108 relay 1127 becomes energized and locks through the windings of the No. 0' counting relay 1128 and relay 1105 in parallel. Upon the next deenergization of relay 1108 relays 1105 and 1128 energize, relay 1105 opening the fundamental circuit and relay 1128 closing a circuit as previously traced for advancing sequence switch 1120 out of position 4 and into position 5. As soon as switch 1120 leaves position 4 the locking circuits of the energized counting relays are opened at the upper contacts of cam 1112 (4). As soon following the opening of the fundamental circuit as the shaft-wiper 240 engages the next insulating portion of commutator 239, relay 222 deenergizes opening the circuit of the updrive magnet 230 to arrest the further upward movement of the switch shaft and closing at the back contact of its inner left-hand armature the circuit previously traced for advancing sequence switch 220 out of position 6 and into position 7. The tripped set of brushes 244, 252 and 253 are now positioned on the lowermost set of terminals of the selected group.

Trunk hunting.

60

As soon as sequence switch 220 reaches position 7 a circuit is again established for relay 222 which may be traced from battery through the left-hand winding of this relay 65 and to ground through the lower contacts of

cam 241. Relay 222 upon energizing closes the previously traced circuit for driving sequence switch 220 out of position 7 into position 8. As soon as the sequence switch leaves position 7 1/4 the energizing circuit 70 of relay 222 is opened at the lower left-hand contact of cam 241, but relay 222 is maintained energized over a locking circuit extending through its right-hand winding, its right-hand armature and front contact, the 75 right-hand contacts of cam 242, the outer left-hand armature and contact of relay 222, the right-hand contact of cam 243, test brush 244, and thence to the lowermost test terminal 245 of the group of trunk lines to 80 which the selected brush set has been moved if the first trunk line of the group is busy. If this first trunk line, however, is at the time idle, the locking circuit of relay 222 is not established and relay 222 immediately 85 deenergizes, thereby preventing the establishment of a circuit for the updrive magnet 230 and the operation of the switch in its trunk hunting movement when sequence switch 220 reaches position 8. 90

Assuming, however, that the first trunk line of the group is busy, relay 222 remains locked after sequence switch 220 leaves position 7 and a circuit is thereupon established for the updrive magnet 230 which may be traced from battery through the winding of magnet 230, the lower right-hand and upper left-hand contacts of cam 229, and thence to ground at the inner left-hand armature and front contact of relay 222. When test brush 244 engages the test terminal of the first idle trunk in the group, which in the case assumed is terminal 246, the locking circuit of relay 222 is opened and relay 222 deenergizes, thereby opening the circuit of magnet 230. Relay 222, however, does not deenergize until the brush set has become properly centered upon the terminals of the selected idle trunk, since relay 222 is held energized over a circuit extending from battery through its left-hand winding, the right-hand contacts of cam 241, the centering segment 247, shaft wiper 248, the upper contacts of cam 229, and thence to ground at the inner left-hand armature and front contact of relay 222. This centering locking circuit is opened as soon as wiper 248 engages an insulating portion of segment 247 corresponding to the position of switch shaft 231 in which the brushes of the selected 115 brush set are properly centered on the selected set of trunk terminals. 120

Relay 222 upon deenergizing, in addition to opening the circuit of updrive magnet 230, closes a circuit extending from battery 125 through the winding of the magnet of switch 220, the lower left-hand contact of cam 223 (8), and thence to ground through the inner left-hand armature and back contact of relay 222 for driving switch 220 from posi- 130

tion 8 into position 9. Ground potential is now connected to test brush 244 to mark the selected trunk as busy to other selector switches which have access thereto, over a circuit extending from ground through the lower left-hand contact of cam 257 (7 to 9), the right-hand armature and back contact of relay 222, the lower right-hand and upper left-hand contacts of cam 242, overflow 5 commutator segment 254, shaft wiper 255, and thence to test brush 244. The selected trunk circuit is also held busy by ground potential connected to the test brush at the right-hand armature and back contact of relay 274, the right-hand contacts of cam 242, and thence over the circuit previously traced, this ground potential being maintained on test brush 244 through position 11 of sequence switch 220. Sequence switch 10 220 remains in position 9 until the number which the operator has recorded upon the keyboard has been completely registered upon the register relays of Fig. 6.

Skip office.

It will be assumed that trunk lines extending directly to local sender district selectors, such as disclosed in Fig. 13, may be reached directly from the terminal bank of district selector 250 without the employment of an office selector. Therefore, with the translator switch TS in position 38 the wiper 841 in the office brush bank T^{10} of the translator switch will not establish a connection to a counting relay lead and battery but a connection directly to ground. When, therefore, sender sequence switch 1120 passes from position $4\frac{3}{4}$ into position 5, following district group selection, the skip office relay 30 1205 becomes energized over a circuit which may be traced from battery through the winding of relay 1205, conductor 1206, the left-hand contacts of cam 1207, conductor 1208, the lower left-hand and upper right-hand contacts of cam 1135, conductor 840, wiper 841, terminal 842 in the lower bank T^{10} to ground. Relay 1205 upon energizing closes a locking circuit through its inner left-hand armature and front contact over the upper 35 left-hand contacts of cam 1209 (2 to 5), to ground, and at its outer left-hand armature and front contact establishes a circuit over the upper left-hand contact of cam 1210 to advance sequence switch 1220 out of position 1. When switch 1220 leaves position 2 the initial energizing circuit of relay 1205 is opened, but when the switch reaches position $5\frac{3}{4}$ a new energizing circuit for relay 1205 is established over the upper contact of cam 1207 ($5\frac{3}{4}$ to 7), the lower right-hand contact of cam 1213 ($5\frac{3}{4}$ to 8), conductor 1214, wiper 843, terminal 844 of the lower bank of the pair of banks T^{13} to ground. Relay 1205 again locks over the upper left-hand contact of cam 1209 until

sequence switch 1220 leaves position 10 when this locking circuit is opened and switch 1220 is arrested in position 11.

The circuits of the sender are now prepared for controlling the transfer of registration from the operator's suburban sender to a local sender at the special "A" board as soon as registration is completed at the suburban sender.

Setting the tandem and numerical register 75 relays.

Returning to the point in the discussion where the keyboard cable conductors 352 to 354 were disconnected from the route 80 register relays by the movement of the register control switch 720 into position 3, and the movement of the key control switch 420 into position 3, conductor 352 was connected to the tandem hundreds register relays 603 85 and 604, conductor 353 to the tandem hundreds register relay 600, conductor 354 to the incoming brush relay 605, and conductor 355 to the tandem hundreds register relay 607. Under the assumption that the operator has depressed No. 2 tandem hundreds key 502, a circuit is now closed for relay 600 which may be traced from battery through the left-hand winding of relay 600, conductor 601, the upper contacts of cam 724, 95 thence to conductor 353 as previously traced, conductor 441, conductor 442, the lower left-hand contact of cam 443 (3), conductor 404, the right-hand contact of key 502, conductor 523, the lower contact of cam 445 (3), conductor 446, and thence through the low resistance right-hand winding of relay 447 to ground at the left-hand armature and contact of relay 448. Relays 600 and 447 energize in this circuit, relay 600 100 locking through its right-hand winding and inner right-hand armature and contact over conductor 602 to ground at the upper left-hand contact of cam 725 ($1\frac{3}{4}$ to 9), and relay 447 opening the shunt around relay 448, 105 which latter relay thereupon energizes over the right-hand contact of cam 439 (3).

The circuit of relays 603 and 604 may be traced through the windings of these relays in series over the right-hand contacts of cam 115 726, and thence as previously traced to conductor 352, conductors 449 and 450, the upper left-hand contact of cam 402 (2 to 8), the lower left-hand contact of cam 403 ($2\frac{3}{4}$ to 3), and to conductor 451. Since conductor 451 has no connection to the left-hand contact of key 502, this circuit is ineffective and relays 603 and 604 do not energize. The circuit for relay 605 may be traced from battery through the winding of relay 125 605, conductor 606, the upper contacts of cam 727, thence over conductor 354 as previously traced, conductor 452, the right-hand contacts of cam 454, conductor 455, the right-hand contact of No. 3 thousands 130

key 505, conductor 428, and thence to ground at the upper left-hand contact of cam 427 (2 to 9). The circuit of relay 607 may be traced in series with the winding of relay 718 from ground through the winding of relay 718, the upper contact of cam 728 (3), conductor 729, the right-hand winding of marginal relay 607, conductor 608, thence as previously traced to conductor 355, conductor 453, the upper right-hand contact of cam 419 (3), resistance element 438, the left-hand armature and front contact of relay 447, and thence to battery through resistance element 436. Since both resistance elements 436 and 438 are included in this circuit, marginal relay 607 does not energize. Relay 718, however, energizes establishing a circuit for advancing register control switch 720 out of position 3 and into position 4. This circuit may be traced from battery through the magnet winding of switch 720, the armature and back contact of relay 711, the upper left-hand and lower right-hand contacts of cam 717 (3), armature and front contact of relay 718, the left-hand contact of cam 730 (3), conductor 731, and thence to ground at the outer right-hand armature and contact of relay 600.

The movement of sequence switch 720 into position 4 opens the connections previously traced from the windings of relays 600, 603, 604, 605 and 607 to conductors 352 to 355 and connects these conductors to the windings of relays 608, 609, 611, 612, 613 and 614. Conductor 352 is now connected to the winding of tandem tens relay 611; conductor 653 to the windings of tandem tens relays 608 and 609; conductor 654 to the tandem tens relay 612; and conductor 355 to the incoming brush relays 613 and 614.

Assuming that the operator has depressed the No. 4 tandem tens key 503, a circuit is now established through the windings of tandem tens relays 608 and 609 which may be traced from ground through the windings of these relays, conductor 610, the upper contacts of cam 710, thence over the circuit previously traced to conductor 353, conductors 441 and 442, the lower right-hand contact of cam 443 (3 $\frac{3}{4}$ to 4), conductor 456, the left-hand contact of key 503, conductor 524, and thence to battery through the low resistance element 519. Due to the low resistance of this circuit both relays 608 and 609 energize and lock through their left-hand windings and left-hand armature contacts to ground on conductor 602. A circuit is also established for relay 611 which may be traced from battery through the winding of this relay, conductor 615, the lower left-hand and upper right-hand contacts of cam 714, thence over the circuit previously traced to conductor 352, conductors 449 and 450, the upper left-hand contact of cam 402 (2 to 8), the lower right-hand contact of cam 403 (4), conductor 457, through both windings of relay 431, to ground at the left-hand armature and contact of relay 432. Due to the inclusion of both windings of relay 431 in this circuit, marginal relay 611 does not energize. Relay 431, however, energizes opening the shunt around relay 432 for permitting the energization of relay 432. A circuit is also closed from ground through the windings of incoming brush relays 613 and 614 over conductor 616, the upper contacts of cam 707, and thence over the circuit previously traced to conductor 355, conductor 453, the lower contact of cam 418 (3 $\frac{3}{4}$ to 4), conductor 458, the left-hand contact of key 505, conductor 525, the lower contact of cam 466 to ground through resistance element 459. The resistance of element 459 is such that marginal relay 613 does not energize in this circuit. Relay 614, however, energizes and locks through its left-hand winding to ground on conductor 624. A circuit is also established through the winding of tandem tens relay 612 and relay 711 which may be traced from ground at relay 711, the right-hand contact of cam 712 (4), conductor 751, the right-hand winding of relay 612, conductor 617, and thence as previously traced through conductor 354, conductor 452, the lower contact of cam 433 (4), conductor 437, high resistance element 438, and thence to battery through the left-hand armature and front contact of relay 431 and resistance element 436. Due to the inclusion of high resistance element 438 in this circuit, relay 612 does not energize. Relay 711, however, energizes.

Tandem tens relays 608 and 609 have now been energized and locked and incoming brush relay 614 has been energized to complete the incoming brush registration. Upon the energization of relay 711 a circuit is established for advancing sequence switch 720 into position 5 which may be traced from battery through the magnet winding of switch 720, the armature and front contact of relay 711, the lower left-hand and upper right-hand contacts of cam 717 (4), the armature and back contact of relay 718, the upper right-hand contact of cam 730 (4), conductor 732, and thence to ground at the outer left-hand armature and front contact of relay 608. Upon the advance of switch 720 into position 5, conductors 352 to 355 inclusive are disconnected from the tandem tens relays 608, 609, 611 and 612 and the incoming brush relays 613 and 614, whereupon relay 431 deenergizes closing a circuit to advance sequence switch 420 into position 5 as previously traced. Conductor 352 is now connected to the tandem units relays 618 and 619; conductor 353 to the

- tandem units relay 620; conductor 354 to the incoming group relay 625; and conductor 355 to the tandem units relay 621.
- Assuming that the No. 3 tandem units key 504 has been depressed by the operator, a circuit is now established for relay 620 which may be traced from battery through the winding of this relay, conductor 622, the lower right-hand and upper left-hand contacts of cam 724, and thence as previously traced to conductor 353, conductors 441 and 442, the lower left-hand contact of cam 443 (5), conductor 404, the right-hand contact of key 504, conductor 526, the left-hand contact of cam 445 (5), conductor 446, thence through the low resistance right-hand winding of relay 447 to ground at the left-hand armature and back contact of relay 448. Marginal relay 620 energizes in this circuit and locks through its right-hand winding to ground on conductor 602, and relay 447 energizes removing the shunt from around the winding of relay 448, whereupon relay 448 energizes over the right-hand contact of cam 439 (5). A circuit is also established for tandem units relays 618 and 619 which may be traced from ground through the windings of these relays, conductor 623, upper left-hand and lower right-hand contacts of cam 726, thence over the circuit previously traced to conductor 352, conductors 449 and 450, the upper left-hand contact of cam 402 (2 to 8), the lower right-hand contact of cam 402 (4 $\frac{3}{4}$ to 5), conductor 460, the left-hand contact of key 504, conductor 524, and thence to battery through the low resistance element 519. Due to the inclusion of low resistance element 519, both marginal relay 618 and relay 619 energize and lock through their left-hand windings to ground on conductor 602. A circuit is also established for incoming group relay 625 which may be traced from battery through the winding of this relay, conductor 626, the left-hand contacts of cam 727, and thence as previously traced to conductor 354, conductor 452, the upper right-hand contact of cam 454 (2 to 7), the lower right-hand contact of cam 407 (4 $\frac{3}{4}$ to 5), conductor 458, the left-hand contact of key 505, conductor 525, and thence to ground through the upper contact of cam 461 (4 $\frac{3}{4}$ to 5). Relay 625 energizes in this circuit and locks through its inner right-hand armature and front contact over conductor 627 to ground at the lower right-hand contact of cam 709. A circuit is also established for tandem units relay 621 which may be traced from ground at relay 718 through the lower right-hand contact of cam 728 (5), conductor 734, the right-hand winding of relay 621, conductor 608, and thence as previously traced to conductor 355, conductor 453, the upper right-hand contact of cam 419 (5), resistance element 438, the left-hand armature and front

contact of relay 447, and thence to battery through resistance element 436. Due to the inclusion of resistance element 438, marginal relay 621 does not energize in this circuit. Relay 718, however, energizes.

Tandem units relays 618, 619 and 620 have been energized and incoming group relay 625 has been energized to partly establish incoming group registration. Upon the energization of relay 718 a circuit is established through the winding of sequence switch magnet 720, the armature and back contact of relay 711, the upper left-hand and lower right-hand contacts of cam 717, the armature and front contact of relay 718, the lower contact of cam 730 (5), conductor 735, and thence to ground at the outer right-hand armature of relay 620 for advancing switch 720 into position 6. Following the advance of switch 720 into position 6, conductors 352 to 355 inclusive are disconnected from the circuits previously traced through the tandem units relays 618 to 621 inclusive and the incoming group relay 625, whereupon relay 447 becomes deenergized to advance sequence switch 420 into position 6. Conductor 352 is now connected to the final brush relay 630; conductor 353 to the final brush relays 628 and 629; conductor 354 to the incoming group relay 631; and conductor 355 to the station's relays 632 and 633.

Assuming that the operator has depressed the No. 3 thousands key 505, the No. 9 hundreds key 506, and the R stations key 509, a circuit is now established for relay 630 which may be traced from battery through the winding of this relay, conductor 634, the right-hand contacts of cam 714, and thence as previously traced to conductor 352, conductors 449 and 450, the upper left-hand contact of cam 402 (2 to 8), the lower right-hand contact of cam 403 (6), both windings of relay 431, and thence to ground at the left-hand armature and contact of relay 432. Since both windings of relay 431 are included in this circuit, marginal relay 630 does not energize. Relay 431, however, energizes and in the manner previously described permits the energization of relay 432. A circuit is also established at this time for relays 628 and 629 which may be traced from ground through the windings of these relays, conductor 635, the right-hand contacts of cam 710, and thence as previously traced to conductor 353, conductors 441 and 442, the lower right-hand contact of cam 423 (5 $\frac{3}{4}$ to 6), conductor 462, the left-hand contact of key 506, conductor 514, the low resistance winding of relay 424, the left-hand contact of cam 426 (5 $\frac{3}{4}$ to 6), and thence to battery. Relays 628 and 629 both energize in this circuit and lock to ground on conductor 636 and relay 424 also energizes. A circuit is also established through the windings of relays 632 and 633 which may be traced from

battery through the windings of these relays, conductor 637, the right-hand contacts of cam 707, and thence as previously traced to conductor 355, conductor 453, the lower left-hand contact of cam 419 (5 $\frac{3}{4}$ to 6), conductor 463, the left-hand contact of stations key 509, conductor 428, and thence to ground at the upper left-hand contact of cam 427 (2 to 9). Relays 632 and 633 both energize in this circuit and lock through their left-hand windings to ground on conductor 624. A circuit may also be traced through the winding of relay 631 from ground at the winding of relay 711, the right-hand contacts of cam 736, conductor 737, the right-hand winding of relay 631, conductor 617, and thence as previously traced over conductor 354, conductor 452, the upper left-hand contact of cam 433 (6), conductor 434, conductor 435, thence to battery through the left-hand armature and front contact of relay 431 and resistance element 436. Since relay 424 is energized at this time the high resistance element 438 is shunted from the circuit previously traced and sufficient current, therefore, flows to cause the energization of marginal relay 631 in series with relay 711. Relay 631 upon energizing locks through its left-hand winding to ground on conductor 627.

The final brush register relays 628 and 629 have now been energized, incoming group register relay 631 has been energized to complete incoming group registration, and stations register relays 632 and 633 have been energized to establish a portion of the stations registration. Upon the energization of relay 711 in the circuit previously traced, a circuit is established for advancing sequence switch 720 from position 6 to position 7 which may be traced from battery through the magnet winding of switch 720, the armature and front contact of relay 711, the lower left-hand and upper right-hand contacts of cam 717, the armature and back contact of relay 718, and thence to ground at the lower left-hand contact of cam 725 (6 to 8). Upon the advance of switch 720 into position 7, conductors 352 to 355 are disconnected from the circuits previously traced through the windings of relays 629 to 633 inclusive, whereupon relay 431 deenergizes to establish the circuit previously traced for advancing sequence switch 420 into position 7. Conductor 352 is now connected to the windings of final tens relays 638 and 639; conductor 353 is connected to final tens relay 640; conductor 654 is connected to stations relay 641; and conductor 355 to final tens relay 642.

Assuming that the operator has depressed the No. 1 tens key 507 and the R stations key 509, a circuit is now established through the windings of final tens register relays 638 and 639 which may be traced from ground

through the right-hand windings of these relays, conductor 643, the lower contacts of cam 726; thence over the circuit previously traced to conductor 352, conductors 449 and 450, the upper left-hand contact of cam 402 (2 to 8), the upper right-hand contact of cam 403 (6 $\frac{3}{4}$ to 7), conductor 464, the left-hand contact of key 507, conductor 528, and thence to battery through the high resistance element 520. The resistance of element 520 is such that the marginal relay 638 does not energize. Relay 639, however, energizes and locks through its left-hand winding and left-hand armature contact to ground on conductor 636 through the lower right-hand contact of cam 733 (1 $\frac{3}{4}$ to 9). A circuit is also established for final tens relay 640 which may be traced from battery through the left-hand winding of this relay, conductor 644, the left-hand contacts of cam 724, thence over the circuit previously traced to conductor 353, conductors 441 and 442, the lower left-hand contact of cam 443 (7), conductor 404, the right-hand contact of key 507, the upper right-hand contact of cam 445 (7), conductor 446, thence through the low resistance right-hand winding of relay 447 to ground at the left-hand armature and back contact of relay 448. Relays 447 and 640 energize in this circuit, relay 447 removing the shunt from around the winding of relay 448 for permitting the energization of relay 448, and relay 640 closing a locking circuit for itself through its right-hand winding and inner right-hand armature contact to ground on conductor 636. A circuit is established for stations relay 641 which may be traced from battery through the winding of relay 641, conductor 645, the lower right-hand and upper left-hand contacts of cam 727, thence over the circuit previously traced to conductor 354, conductor 452, the upper contacts of cam 454, conductor 465, the right-hand contact of stations key 509, conductor 428, and thence to ground at the upper left-hand contact of cam 427 (2 to 9). Relay 641 energizes in this circuit and locks through its inner right-hand armature and front contact to ground on conductor 624. A circuit is also established for final tens relay 642 which may be traced from ground through the winding of relay 718, the left-hand contact of cam 728 (7), conductor 738, the right-hand winding of relay 642, conductor 608, thence over the circuit previously traced to conductor 355, conductor 453, the upper right-hand contact of cam 419 (7), resistance element 438, the left-hand armature and front contact of relay 447, and thence to battery through resistance element 436.

Due to the inclusion of high resistance element 438, the current flowing in this circuit is not sufficient to cause the energization of marginal relay 642. Relay 718, however, is

energized. Final tens relays 639 and 640 and stations relay 641 have now been energized completing the final tens registration and stations registration.

- 5 Upon the energization of relay 718 a circuit is established for advancing sequence switch 720 into position 8 which may be traced from battery through the magnet winding of switch 720, the armature and 10 back contact of relay 711, the upper left-hand and lower right-hand contacts of cam 717, the armature and front contact of relay 718, and thence to ground at the lower left-hand contact of cam 725. Following the 15 advancement of switch 720 into position 8, the circuits previously traced through relays 638 to 642 inclusive and over conductors 353 to 355 inclusive are now opened. The circuit of relay 447 being now opened 20 a circuit is established as previously traced for advancing sequence switch 420 out of position 7 and into position 8. Conductor 352 is now connected to the winding of final units register relay 648; conductor 353 to 25 the windings of final units register relays 646 and 647; conductor 354 to final units relay 649; and conductor 355 is maintained open.
- Assuming that the operator has depressed 30 the No. 6 units key 508, a circuit is now established for final units relay 648 which may be traced from battery through the left-hand winding of relay 648, conductor 650, the lower contact of cam 739, and thence as 35 previously traced to conductor 352, conductors 449 and 450, the upper left-hand contact of cam 402, the upper left-hand contact of cam 403 (8 to 11), conductor 404, the right-hand contact of key 508, the upper 40 contacts of cam 413, conductor 440, and thence through the low resistance right-hand winding of relay 431 to ground at the left-hand armature and back contact of relay 432. Relays 431 and 648 energize in this 45 circuit, relay 431 permitting the energization of relay 432 as previously described, and relay 648 closing a locking circuit for itself through its right-hand winding and inner right-hand armature contact to ground 50 on conductor 636. A circuit is also closed extending from ground through the right-hand windings of relays 646 and 647 over conductor 651, the upper contact of cam 703, and thence as previously traced to conductor 55 353, conductors 441 and 442, the upper left-hand contact of cam 443 (7 $\frac{3}{4}$ to 8), the left-hand contact of units key 508, conductor 527, both windings of relay 424, thence to battery through the lower left-hand contact 60 of cam 426 (7 $\frac{3}{4}$ to 8). Since both windings of relay 424 are included in this circuit, the marginal register relay 646 does not receive sufficient current to energize, but relay 424 energizes. Relay 647, however, energizes 65 and locks through its left-hand winding and
- left-hand armature contact to ground on conductor 636. A circuit may also be traced through the right-hand winding of relay 649 from ground through the winding of relay 711, the lower left-hand contact of cam 712 (8), conductor 740, the right-hand winding of relay 649, conductor 617, thence as previously traced to conductor 354, the upper contacts of cam 433, conductor 434, the armature and contact of relay 424, conductor 435, the left-hand armature and front contact of relay 431, and to battery through resistance element 436. Since relay 424 was previously energized and closed a shunt around the high resistance element 438, the current flowing in the circuit traced through the winding of register relay 649 is sufficient to cause the energization of both relays 711 and 649. Relay 649 upon energizing closes a locking circuit for itself through its left-hand winding and left-hand armature contact to ground on conductor 627. Relay 711 upon energizing establishes a circuit for advancing sequence switch 720 into position 9 which may be traced from battery through the magnet winding of switch 720, the armature and front contact of relay 711, the lower left-hand and upper right-hand contacts of cam 717, the armature and back contact of relay 718, and thence to ground at the lower left-hand contact of cam 725 (6 to 8). Upon the advancement of switch 720 out of position 8, circuits previously traced over conductors 352 to 354 inclusive are opened and 100 relay 431 thereupon deenergizes establishing the previously traced circuit for advancing sequence switch 420 out of position 8 into position 9. The final units relays 647, 648 and 649 are now energized and the registration of the complete line designation which the operator recorded upon the keyboard has now been transferred to the register relays of Fig. 6, preparatory to controlling the transmission of code impulses to a local 105 sender for completing the establishment of the desired connection.

Release of keyboard keys.

As soon as key control sequence switch 115 420 reaches position 9, a circuit is closed for key release magnets 530 to 535 inclusive which may be traced from ground through the windings of these magnets in parallel, conductor 529, the upper contact of cam 120 426 (9) and to battery; for key release magnets 535 to 541 inclusive, from ground through the windings of these magnets in parallel, conductor 542, and thence to battery through the upper left-hand and 125 right-hand contacts of cam 401 (9) for release magnet 543 from ground to the winding of magnet 543, conductor 546, normally closed contacts of key 54, conductor 546, conductor 542, and t

battery through the upper left-hand and lower right-hand contacts of cam 401.

- During the process of registration, relay 400 was operated over a circuit extending 5 through the winding of relay 400 and the upper right-hand contact of cam 405 (5 to 8½), and upon completion of registration and following the movement of sequence switch 420 out of position 8, relay 400 is 10 maintained energized until all depressed keys of the keyboard have been released. The locking circuit of relay 400 is maintained so long as any No. 0, 4, 5 or 9 key of any of the four rows of route keys is 15 depressed over a circuit extending from ground through the right-hand contacts of any one of these keys, conductor 516, conductor 406, and thence through the inner right-hand armature and front contact and 20 winding of relay 400, and so long as a Nos. 1, 2, 3, 6, 7 or 8 key is depressed in any of the rows of route keys from ground at the lower left-hand contact of cam 405 (8½ to 10), conductor 501, right-hand contacts of 25 any one of these keys, conductor 404, the upper left-hand contact of cam 403 (8 to 11), the lower left-hand contact of cam 402 (8½ to 10), conductor 406, and thence to 30 battery through the inner right-hand armature and winding of relay 400.

Relay 400 is locked so long as any tandem keys or hundreds, tens or units keys Nos. 1, 4, 5 or 9 are depressed from ground at the upper left-hand contact of cam 427 (2 to 9), 35 conductor 428, the right-hand contacts of one of these keys, conductor 516, and thence as previously traced through the winding of relay 400, or over the Nos. 2, 3, 6, 7 or 8 tandem hundreds keys from ground at the 40 lower right-hand contact of cam 461 (8½ to 9), conductor 523, the right-hand contacts of one of these keys, conductor 404, and thence as previously traced through contacts of cams 403 and 402 to the winding of relay 45 400, or over the Nos. 1, 2, 3, 6, 7 or 8 tandem tens keys from ground through the lower left-hand contact of cam 427 (8½ to 9), conductor 468, the right-hand contacts of one of these keys, conductor 404, the contacts of cams 403 and 402, and to the winding 50 of relay 400 as previously traced, or through the Nos. 1, 2, 3, 6, 7 or 8 tandem units keys from ground at the lower left-hand contact of cam 469 (8½ to 9), conductor 526, the right-hand contacts of one of these keys, conductor 404, and thence to the winding of relay 400 over the circuit previously traced.

So long as either the Nos. 0, 1, 8 or 9 60 thousands key is depressed, relay 400 is locked over the same circuit as previously traced for the Nos. 0, 4, 5 or 9 route keys and is maintained locked if a Nos. 2, 3, 4, 5 or 6 thousands key is depressed from ground 65 at the upper left-hand contact of cam 427,

conductor 428, the right-hand contact of one of these keys, conductor 455, the lower contacts of cam 454, conductors 516 and 406, and thence through the winding of relay 400. Relay 400 is maintained locked 70 as long as a Nos. 1, 2, 3, 6, 7 or 8 hundreds key is depressed over the upper right-hand contact of cam 469 (8½ to 9), conductor 470, the right-hand contacts of one of these keys, conductor 404, and thence to the winding of relay 400 over the circuit previously traced, and so long as a tens key Nos. 1, 2, 3, 6, 7, or 8 is depressed over the upper contact of cam 461 (8½ to 9), the upper right-hand contact of cam 466 (8 to 9), the right-hand contact of one of these keys to conductor 404, and thence as previously traced. Until all of the units keys Nos. 1, 2, 3, 6, 7 and 8 are restored, relay 400 is locked over 80 a circuit extending from ground through the lower right-hand contact of cam 427 (8½ to 9), conductor 471, the contact of one of these keys, and thence over conductor 404 to the winding of relay 400. Until either start key 515 or stations key 547 is 85 restored, relay 400 is locked in a circuit extending from ground through the upper left-hand contact of cam 427, conductor 428, the right-hand contacts of these keys, conductor 516, and thence through the winding 90 of relay 400 as previously traced and until the remaining stations keys have been released over a circuit from ground on conductor 428, through the right-hand contacts of these keys, and thence as previously 100 traced over conductor 516 through the winding of relay 400.

With all keys restored no locking circuit for relay 400 exists and relay 400 thereupon deenergizes closing a circuit extending from battery through the magnet winding of switch 420, the outer right-hand armature and back contact of relay 400, and to ground at the upper left-hand contact of cam 405 (9) for advancing sequence switch 420 into 110 position 10. Since switch 420 is arranged to complete two cycles of operation during a single revolution, position 10 is, therefore, a normal position of the switch.

If at the time the key release magnets 115 operate to release the depressed keys of the keyboard there is no idle sender selector available for the next call, relay 467 operates in parallel with the windings of release magnets 530 to 536 inclusive and maintains 120 battery potential over its armature contacts on conductors 529 and 542 to maintain the key release magnets energized so that the operator cannot record a line designation. If there is an idle sender selector available 125 at this time the right-hand operating winding of relay 467 will be shunted by connection from ground on conductor 472 which may be traced over conductor 472 through the upper left-hand contact of cam 308 (9 130

to 13) or (18 to 4) of all idle sender selectors.

If the operator wipes out the connection by pulling down her cord circuit during the registration of the desired line number, the circuit of holding relays 301 and 302 is opened, thereby opening the locking circuit of relay 408 which upon deenergizing immediately drives sequence switch 420 into position 9 over a circuit which may be traced from battery through the magnet winding of switch 420, the lower left-hand contact of cam 411 (2 to 8), the inner left-hand armature and back contact of relay 408, and thence to ground at the left-hand contacts of cam 473 (2 to 8). Sequence switch 420 upon reaching position 9 initiates the release of the keys of the keyboard following which sequence switch 420 is driven into normal position 10 as previously described.

Following registration when key control switch 420 leaves position 8, the circuit previously traced through the windings of relays 408 and 342 is opened at the right-hand contact of cam 409 (1 to 8), and these relays thereupon deenergize, relay 342 opening the previously traced circuits of relays 303 and 305. Relay 305 upon deenergizing closes a circuit extending through the magnet winding of sequence switch 320, the lower left-hand contact of cam 310 (6 to 7), the right-hand armature and back contact of relay 305, and thence to ground at the lower left-hand contact of cam 311 (6 to 11) for advancing switch 320 into position 8. With sequence switch 320 in position 8 a circuit is closed to advance sequence switch 220 of the district selector into its selection beyond position over a circuit which may be traced from battery through the magnet winding of switch 220, the left-hand contacts of cam 258, conductor 259, wiper 366, the upper contacts of cam 328 (8), wiper 343, conductor 344, the left-hand contact of cam 703 (9), conductor 741, and thence to ground at the lower contact of cam 1112 (1 to 6).

Trunk testing.

Since the class switch 1020 was set into position 12 for controlling a connection in the local area when sender control sequence switch 1220 reaches position 11, a circuit is established for advancing it into position 13. This circuit may be traced from battery through the magnet winding of switch 1220, the left-hand contacts of cam 1234 (11), conductor 1215, the contact of class switch cam 1006 (10 to 13), the inner left-hand armature and back contact of relay 1007, and thence to ground at the upper left-hand contact of cam 1008 (2 to 18). In passing through positions 12 $\frac{3}{4}$ to 13 sequence switch 1220 closes a circuit to advance the sender

sequence switch 1120 into position 6 for closing a fundamental circuit which may be traced from battery through the magnet winding of switch 1120, the upper right-hand contact of cam 1103 (5), conductor 1138, the outer armature and back contact of relay 1007, the right-hand contact of cam 1009 (12 to 13), conductor 1010, and thence to ground at the lower right-hand contact of cam 1223 (12 $\frac{3}{4}$ to 13). 75

With district selector sequence switch 220 in position 10, sequence switch 320 in position 8, and sender sequence switch 1120 in position 6, a fundamental circuit is established from the office sender to the selected trunk which may be traced from battery through the winding of relay 1300, the lower right-hand and upper left-hand contacts of cam 1301 (1 to 3), the outer left-hand armature and back contact of relay 1306, the right-hand contacts of cam 1322 (1 to 3) trunk conductor 1302, bank terminal 249 and brush 252 of district selector 250, the upper right-hand and lower left-hand contacts of cam 225, the outer left-hand armature and back contact of relay 274, conductor 333, wiper 332, the outer left-hand armature and front contact of relay 302, the left-hand contacts of cam 321, conductor 358, wiper 357, conductor 706, lower contact of cam 705 (3 to 9), conductor 723, the armature and back contact of relay 1105, conductor 1106, the upper contact of cam 1202 (16 to 14), conductor 1203, the winding of overflow relay 1107, conductor 1137, the winding of trunk test relay 1037, the lower contact of class switch cam 1004 (12 to 15), conductor 1005, the lower right-hand contact of cam 1139 (6), conductor 1140, wiper 845 of translator switch TS, bank terminal 846, conductor 847, the upper portion of compensating resistance coil 848, conductor 742, the left-hand contacts of cam 736, conductor 708, wiper 359, conductor 360, the left-hand contacts of cam 316, the intermediate left-hand armature and contact of relay 302, wiper 367, conductor 261, the lower contact of cam 260 (10), brush 252 and bank terminal 251 of selector switch 250, trunk conductor 1303, conductor 1304, the upper right-hand and lower left-hand contacts of cam 1305, and thence to ground through the outer right-hand armature and back contact of relay 1306. 110

Relays 1300 and 1037 energize in this circuit, relay 1037 closing an obvious circuit for relay 1011 which locks over its inner left-hand armature and contact, conductor 1012, and to ground through the lower-left-hand contact of cam 1141 (6). As the sender sequence switch passed through positions 2 to 6, a circuit was closed for advancing the relay call indicator impulser 920 from position 1 into position 8, which circuit may be traced from battery through the magnet 130

- winding of switch 920, the upper left-hand contact of cam 900 (1 to 2), conductor 901, the left-hand contact of cam 1013 (12 to 17), conductor 1014, and thence to ground
- 5 through the upper left-hand contact of cam 1141 (2 to 6). After switch 920 leaves position 2 the initial driving circuit is opened at cam 900 but the switch is driven into position 8 over the contact of its master cam 902.
- 10 When sequence switch 1120 passes through positions $5\frac{3}{4}$ to 6 a circuit is closed for the tandem relay 903 which may be traced from battery through the winding of relay 903, conductor 904, the right-hand contact of
- 15 cam 1015, conductor 1016, and thence to ground through the upper right-hand contact of cam 1141 ($5\frac{3}{4}$ to 6), and relay 903 upon energizing closes a locking circuit for itself extending through its inner left-hand
- 20 armature and front contact, the lower contact of cam 905 (8 to 2), conductor 906, and thence to ground through the upper right-hand contact of cam 733 (1 $\frac{3}{4}$ to 9) to insure that the tandem relay shall be maintained energized until after the impulser 920 has started upon its second revolution.
- 25 Upon the energization of relay 903 a circuit is also established for relay 908 which may be traced from battery through the winding of this relay, conductor 909, the inner right-hand armature and front contact of relay 903, conductor 906, and thence to ground at the upper right-hand contact of cam 733 (1 $\frac{3}{4}$ to 9). Relay 908 closes a locking circuit for itself extending through its inner right-hand armature and contact, conductor 910, the upper contact of cam 905 (1 to 9), and thence to ground on conductor 906. Through the joint operation of relay 903
- 30 and sequence switch 920, relay 908 is thus maintained energized until switch 920 starts upon the second half of its second revolution and thus maintains impulse conductors 1022 and 1146 connected to impulse conductors 913 and 911 at the impulser circuit, Fig. 9.

Relay 1011 upon energizing also establishes a circuit for advancing the sender sequence switch 1120 out of position 6 into position 7, which circuit may be traced from battery through the magnet winding of switch 1120, the lower contacts of cam 1126 (6), conductor 1142, the outer left-hand armature and front contact of relay 1011, conductor 1017, the right-hand contact of cam 1018 (12 to 18), conductor 1019, the upper contacts of cam 907 (8 to 9), conductor 901, the left-hand contact of cam 1013 (12 to 17), conductor 1014, and thence to ground at the upper left-hand contact of cam 1141 (2 to 6). The circuits of the office sender are now in condition for the transmission of relay call indicator code impulses as soon as a local sender has been

65 associated with the trunk 1302 and 1303.

At the district selector 1350 upon the energization of relay 1300, a circuit is established from the armature and contact of relay 1300 over the left-hand contact of cam 1307 (1), through the right-hand winding 70 of relay 1308 for energizing relay 1308 which thereupon establishes a circuit for advancing sequence switch 1320 out of position 1 and into position 2. This circuit may be traced from battery through the magnet 75 winding of switch 1320, the lower right-hand contact of cam 1310 (1), conductor 1309, and thence to ground at the right-hand armature and front contact of relay 1308. With sequence switch 1320 in position 2, busy ground potential is connected to the multiples of test terminal 246 in the terminal banks of all district selectors having access thereto over conductor 1311 and the upper right-hand contact of cam 1312 80 (2 to 15 $\frac{1}{2}$).

Hunting for a local sender.

With sequence switch 1320 in position 2 a circuit is established through the stepping 90 magnet 1313 of the sender finder SF for advancing the wipers of the sender finder in search of an idle local sender. This circuit may be traced from battery through the armature and contact and winding of magnet 1313, conductor 1315, the lower contact of cam 1345, conductor 1309, and thence to ground at the right-hand armature and front contact of relay 1308. A circuit is also closed through the magnet winding 1313 95 over conductor 1314 through the winding of relay 1306, and to ground at the upper contacts of cam 1312, but since relay 1306 is shunted by direct ground at the armature contact of relay 1308, it does not energize at 105 this time. Upon the movement of sequence switch 1320 out of position 1 the initial energizing circuit of relay 1308 is opened at cam 1307, but if the wipers of sender finder SF were at the time resting upon the terminals 110 of a busy sender, relay 1308 was maintained energized for establishing the circuit of stepping magnet 1313 as previously described, over a circuit which may be traced from battery through the left-hand winding of relay 1308, the inner left-hand armature and front contact of the relay, conductor 1319, the upper left-hand and lower right-hand contacts of cam 1318, wiper 1317, and to ground on the test terminal of such 115 busy sender. Had the sender been idle it is obvious that relay 1308 would have no locking circuit following the movement of sequence switch 1320 out of position 1, and further no circuit through stepping magnet 120 1313 would have been established to advance the wipers of the sender finder. Assuming that the wipers of the switch rest upon the terminals of a busy sender, magnet 1313 is 125 energized in the circuit previously traced 130

- for advancing the wipers of the switch one step to the terminals of the next sender in the group. If this sender is also busy, magnet 1313 continues to advance the wipers of the switch SF until an idle sender is found when the locking circuit of relay 1308 is opened and relay 1308 upon deenergizing opens the circuit of stepping magnet 1313 to arrest the movement of switch SF.
- 10 Upon the deenergization of relay 1308 busy ground potential is connected to the test terminal of the seized sender over test wiper 1317, the lower right-hand and upper left-hand contacts of cam 1318, conductor 1319, the inner left-hand armature and back contact of relay 1308, to ground through the left-hand contact of cam 1334 (1½ to 2¼), for the purpose of maintaining the seized sender busy to other sender finders until sequence switch 1320 reaches position 2½ to apply a more permanent busy potential over the lower contacts of cam 1318. Relay 1308 upon deenergizing also closes a circuit for advancing sequence switch 1320 out of position 2 into position 3, which circuit may be traced from battery through the magnet winding of switch 1320, the left-hand contact of cam 1310 (2), conductor 1321, and to ground through the right-hand armature and back contact of relay 1308. At the front contact and right-hand armature of relay 1308 the shunt circuit around the winding of relay 1306 is opened upon the deenergization of relay 1308, and relay 1306 energizes in series with the winding of stepping magnet 1313 for connecting trunk conductors 1302 and 1303 over impulse leads 1324 and 1328 and wipers 1325 and 1327 of the sender finder SF to the register control circuit of the sender. The resistance of relay 1306 is of such value that stepping relay 1313 does not energize in series therewith.
- 45 Relay 1306 upon energizing also establishes a circuit for relay 1700 of the office sender which may be traced from battery through the right-hand winding of relay 1700, the contact of cam 1701 (1), conductor 1702, conductor 1703, wiper 1330 of switch SF, conductor 1331, the lower right-hand and upper left-hand contacts of cam 1332 (2 to 3), conductor 1333, and to ground at the inner left-hand armature and front contact of relay 1306. Relay 1700 upon energizing closes a locking circuit through its right-hand winding and inner right-hand armature to conductor 1704, thence over wiper 1317, to ground at the lower contacts of cam 1318, which circuit is maintained until the office sender has completed its controlling functions. At its left-hand armature and front contact relay 1700 establishes a circuit from battery through the lamp 1748, resistance element 1749, and to ground through the upper left-hand contact of cam 1747 (1

65 to 8) for lighting the lamp 1748 dimly to indicate the progress of selection through the district selector 1350. Relay 1306 also upon energizing opens the fundamental circuit previously traced through the windings of relays 1300 and 1037, whereupon relay 1037 deenergizes opening the circuit of relay 1011.

An impulsing circuit is now established from the register control circuit, Fig. 18, of the local sender to the impulsing circuit, Fig. 9, of the operator's suburban sender which 75 may be traced over the tip fundamental from conductor 1326, wiper 1325 of switch SF, conductor 1324, the right-hand contact of cam 1323, the outer left-hand armature and front contact of relay 1306, the right-hand 80 contacts of cam 1322 (1 to 3), trunk conductor 1302, thence as previously traced to conductor 723, Fig. 7, the armature and back contact of relay 1105, the upper left-hand and lower right-hand contacts of cam 1135, conductor 1143, the intermediate left-hand armature and back contact of relay 1011, the contact of cam 1021 (8 to 17), conductor 1022, the inner left-hand armature and front contact of relay 908, and thence to the tip 90 impulsing conductor 913 of the relay call indicator impulser circuit, Fig. 9. The ring fundamental of the impulsing circuit may be traced through the windings of polarized relays 1800 and 1801, the winding of marginal relay 1802, conductor 1803, the contacts of cam 2200 (1), conductor 2201, wiper 1327 of switch SF, conductor 1328, the lower contact of cam 1329 (1 to 3), the outer right-hand armature and front contact of relay 1306, the lower left-hand and upper right-hand contacts of cam 1305 (1 to 3), conductor 1304, trunk conductor 1303, thence as previously traced to conductor 1140, Fig. 11, the upper contact of cam 1139 (6 to 7), conductor 1144, the left-hand contacts of cam 1023 (8 to 17), the right-hand armature and back contact of relay 1011, conductor 1024, the right-hand contacts of cam 1145, conductor 1146, the outer left-hand armature and front contact of relay 908, and thence to the ring conductor 911 of the impulsing circuit, Fig. 9. It is to be noted that relays 1800 and 1801 are both sensitive, relay 1800 responding to impulses of positive 115 polarity only and relay 1801 to impulses of negative polarity, and that relay 1802 is marginal and responds to only strong impulses of either polarity.

Registration of tandem hundreds digit on 120 register relays of local sender.

It has been assumed that the office designation of the desired line is Chelsea and that the code C H E has been registered on 125 the tandem register relays of the suburban sender. With the previously traced fundamental circuit established between the relay

call indicator impulser 920 and the register control circuit of the local sender, tandem code impulses are transmitted during the rotation of impulser switch 920 from position 8 into position 1 during the second half of its first revolution.

Upon the deenergization of relay 1011 with sequence switch 1120 in position 7, a circuit is closed for advancing switch 920 out of position 8, which circuit may be traced from battery through the magnet winding of switch 920, right contact of cam 900 (8 to 9), outer right armature and front contact of relay 908, conductor 912, lower right and upper left contacts of cam 1025, conductor 1026, right contacts of cam 1147, conductor 1148, outer left armature and back contact of relay 1011, conductor 1149 to ground at the lower right contact of cam 1141.

As switch 920 rotates from position 8½ to position 12½, a code of impulses comprising a strong negative and a weak negative impulse is transmitted to represent the letter C or its numerical equivalent numeral 2. For the purpose of this description the code impulses will be described by reference to the pole of the battery which is connected to the tip and ring conductors 913 and 911 of the fundamental circuit at the impulser shown in Fig. 9. The tandem hundreds code is transmitted under the control of the tandem hundreds register relays 600, 603, 604, and 607, relay 600 of this group being energized at this time as previously described.

As switch 920 rotates from position 8¾ to position 9¼, positive battery potential is connected to ring conductor 911 over the lower contact of cam 914, but as the tip conductor 913 is open at this time no impulse over the fundamental circuit results. As switch 920 rotates from position 9¾ to position 10¼, the ring conductor 911 is connected to the negative pole of battery over the lower contact of cam 918 (9¾ to 10¼) through the high resistance element 925 and the low resistance element 923 to the negative pole of battery, and the tip conductor 913 is connected to the positive pole of battery through the upper contact of cam 914. Since tandem hundreds register relay 600 is energized at this time a shunt is established around the high resistance winding 925 which may be traced from one terminal of resistance element 925 over conductor 924, cam 1115 (6 to 7), No. 2 lead 1116, lead 653, Fig. 6, the intermediate right-hand armature and front contact of relay 600, the right-hand armature and back contact of relay 604, conductor 652, the lower contact of cam 919 (8½ to 11½), the lower contact of cam 921 (9¾ to 10¼), the outer right-hand armature and front contact of relay 903, and thence to the other terminal of resistance element 925. The resulting impulse of negative current transmitted over the fundamen-

tal circuit is, therefore, a strong impulse. During the rotation of switch 920 from position 10¾ to position 11¼, the ring conductor 911 of the fundamental circuit is connected to the positive pole of battery through the lower contact of cam 914, but as the tip conductor 913 is open at this time no impulse is transmitted. As switch 920 rotates from position 11¾ to position 12¼, the ring conductor 911 is connected over the lower contact of cam 918 and through resistance elements 925 and 923 to the negative pole of battery, and the tip conductor 913 is connected to the positive pole of battery through the upper contact of cam 914. As no shunt exists around the high resistance element 925 this high resistance is included in the fundamental circuit and the resulting impulse of negative current is, therefore, weak.

Had the code digit been 7 requiring the transmission of a final strong negative impulse, tandem hundreds relay 607 would have been energized and high resistance element 925 would have been shunted by a shunt circuit which may be traced from resistance element 925 over conductor 927, the right-hand armature and front contact of register relay 607, conductor 654, the left-hand contacts of cam 926, conductor 928, and thence to the other terminal of resistance element 925 through the outer right-hand armature and front contact of relay 903.

At the local sender, Fig. 18, in response to the first impulse of current over the fundamental circuit which, as previously described, is a strong negative impulse, the negatively polarized relay 1801 and the marginal relay 1802 respond. Relay 1801 upon energizing closes a circuit from ground on conductor 1702 through the upper left-hand contact of cam 1705 (1), conductor 1706, conductor 1804, the armature and contact of relay 1801, conductor 1805, the left-hand armature and back contact of relay 1806, the winding of relay 1807, and thence to battery through the low resistance left-hand winding of relay 1806. Relay 1807 energizes in this circuit but owing to the high resistance winding of relay 1807, relay 1806 does not receive sufficient current to become energized. Upon the energization of relay 1807 a circuit is established for transfer relay 1812 which may be traced from battery through the winding of relay 1812, the right-hand armature and back contact of relay 1809, the intermediate armature and contact of relay 1807, and thence to ground on conductor 1804. Relay 1812 energizes in this circuit and locks through its winding, the winding of relay 1809, the right-hand armature and front contact of relay 1812, and to ground on conductor 1804, but relay 1809 does not energize in this locking circuit since at this time its winding is shunted

by ground connected through the armature contact of relay 1807.

Marginal relay 1802 upon energizing closes a circuit extending from ground over conductor 1808, the outer right-hand armature and back contact of relay 1806, the outer left-hand armature and back contact of relay 1809, conductor 1810, and thence to battery through the right-hand winding 5 of register relay 1900. Relay 1900 upon energizing locks in a circuit from battery through both of its windings and its left-hand armature contact, conductor 1811, and the upper contacts of cam 1705 to ground on 10 conductor 1702.

Relay 1807 upon energizing also establishes a circuit which may be traced from ground on conductor 1804 through the innermost armature and contact of relay 1807, the 20 right-hand high resistance winding of relay 1806, the winding of relay 1807, and thence to battery through the left-hand winding of relay 1806, but this circuit is ineffective to energize relay 1806 since the 25 right-hand winding of relay 1806 is shunted by a connection to ground through the armature contact of relay 1801. Upon the de-energization of relay 1801 following the completion of the first negative impulse, the 30 shunt around the winding of relay 1806 is removed at the contact of relay 1801 and relay 1806 thereupon energizes. Upon the energization of relay 1806 another shunt is established around the winding of relay 1809 35 which may be traced from conductor 1804, the right-hand armature and contact of relay 1812, the winding of relay 1809, the right-hand armature and back contact of this relay, to conductor 1804 through the 40 inner right-hand armature and contact of relay 1806.

The next impulse which is transmitted being a weak negative impulse, only the 45 negatively polarized relay 1801 responds closing a circuit from ground on conductor 1804 over conductor 1805, the left-hand armature and front contact of relay 1806 to one terminal of the winding of relay 1807, and since the other terminal of this winding 50 is at the time connected to ground at the right-hand winding of relay 1806 and the innermost armature and contact of relay 1807, relay 1807 is shunted down and de-energizes. Relay 1806 is now maintained 55 energized through its left-hand winding and its left-hand armature and front contact over conductor 1805 and the armature contact of relay 1801, and deenergizes upon the cessation of the second negative impulse and 60 the consequent deenergization of relay 1801. Relays 1806 and 1807 both being now de-energized, relay 1809 energizes in the locking circuit of relay 1812. The tandem hundreds code has now been transmitted and in response thereto the tandem hundreds register 65

relay 1900 has been energized and locked.

Registration of tandem tens code on register relays of local sender.

During the rotation of impulser switch 70 920 from position $12\frac{1}{2}$ to position $16\frac{1}{2}$, a code of impulses is transmitted in accordance with the setting of the tandem tens register relays 608, 609, 611 and 612 of the suburban sender. It having been assumed 75 that the second office code letter is H having a numerical equivalent of 4 and that register relays 608 and 609 have been locked energized, a code comprising three impulses, a weak negative, a weak positive, and a 80 weak negative is now transmitted. As the impulser switch rotates from position $12\frac{3}{4}$ to position $13\frac{1}{4}$, ring conductor 911 of the fundamental circuit is connected to positive pole of battery over the lower contact of 85 cam 914, but since the tip conductor 913 is open at this time no impulse results. In rotating from position $13\frac{3}{4}$ to position $14\frac{1}{4}$, the ring conductor 911 is connected through the lower contact of cam 918 through resistance elements 925 and 923 to the negative 90 pole of battery, and the tip conductor 913 is connected through the upper contact of cam 914 to the positive pole of battery. Since both resistance elements 923 and 925 are included in the fundamental circuit, a weak negative impulse results. During the rotation of switch 920 from position $14\frac{3}{4}$ to position $15\frac{1}{4}$, the ring conductor 911 is connected to the positive pole of battery over 95 the lower contact of cam 914, and the tip conductor 913 is connected over the contacts of cam 915, conductor 929, the upper contact of cam 1149, the No. 4 lead 1150, lead 655, Fig. 6, the outer right-hand armature and contact of relay 609, the left-hand armature and back contact of relay 611, the right-hand armature and front contact of relay 608, conductor 656, the upper contact 100 of cam 919 ($12\frac{1}{2}$ to $15\frac{1}{2}$), the upper contact of cam 921 ($14\frac{3}{4}$ to $15\frac{1}{4}$), the outer left-hand armature and front contact of relay 903, and thence to the negative pole of battery through the high resistance element 922. A weak positive impulse is thus 105 transmitted over the fundamental circuit. As switch 920 rotates from position $15\frac{3}{4}$ to position $16\frac{1}{4}$, the ring conductor 911 is connected to the negative pole of battery through the lower contact of cam 918 and resistance elements 923 and 925, and the tip conductor 913 is connected to the positive pole of battery through the upper contact 110 of cam 914 and a second weak negative impulse is consequently transmitted.

At the local sender, Fig. 18, in response to the first weak negative impulse of current, the negatively polarized relay 1801 responds establishing a circuit for relay 1807 as previously traced, which in turn closes a 115 120 125 130

circuit for relay 1813 which may be traced from battery through the winding of relay 1813, the right-hand armature and back contact of relay 1814, the right-hand armature and front contact of relay 1809, the intermediate armature and contact of relay 1807, and thence to ground on conductor 1804. Relay 1813 upon energizing closes a locking circuit for itself extending through its winding, the winding of relay 1814, the inner right-hand armature and front contact of relay 1813, and thence to ground on conductor 1804. Relay 1814 does not energize in this circuit since at this time its winding is shunted by ground connected through the armature and contact of relay 1807. Upon the cessation of the first negative impulse and the deenergization of relay 1801, relay 1806 becomes energized. In response to the next impulse which is of positive polarity, the positively polarized relay 1800 energizes establishing a circuit which may be traced from ground on conductor 1804 through the armature and contact of relay 1800, conductor 1815, the outer armature and front contact of relay 1807, the inner left-hand armature and front contact of relay 1813, the inner left-hand armature and back contact of relay 1816, conductor 1817, the right-hand winding of relay 1901, and thence to battery. Relay 1901 upon energizing locks up to ground on conductor 1811 through both of its windings and left-hand armature contacts. In response to the last weak negative impulse, relay 1801 again energizes and through its armature contact closes a shunt around the winding of relay 1807 as previously traced. Relay 1807 thereupon deenergizes opening the shunt around the winding of relay 1814. Relay 1814, however, is prevented from energizing by another shunt established through the inner right-hand armature and front contact of relay 1806 until relay 1801 deenergizes following the cessation of the last negative impulse. The tandem tens code impulses have now resulted in the energization of the tandem tens register relay 1901.

50 *Registration of tandem units code on register relays of local sender.*

During the rotation of impulser switch 920 from position $16\frac{1}{2}$ to $20\frac{1}{2}$, a code of impulses is transmitted in accordance with the setting of tandem units register relays 618, 619, 620 and 621. It having been assumed that the third office code letter was E having a numerical equivalent of 3 and that register relays 618, 619 and 620 are energized, a code comprising three impulses is transmitted for registering this code designation upon the tandem units register relays of the local sender. The impulses of this code in the order of their transmission are a positive, a strong negative, and a weak negative impulse. As switch 920 rotates from position $16\frac{3}{4}$ to position $17\frac{1}{4}$, the ring conductor 911 of the fundamental circuit is connected to the positive pole of battery through the lower contact of cam 914, and the tip conductor 913 is connected over the upper contact of cam 915 ($16\frac{3}{4}$ to $17\frac{1}{4}$), the lower contact of cam 933 ($16\frac{3}{4}$ to $17\frac{1}{4}$), conductor 930, the upper contact of cam 1151, the No. 3 lead 1152, lead 657, Fig. 6, the inner right-hand armature and front contact of relay 618, the left-hand armature and front contact of relay 620, the right-hand armature and front contact of relay 619, conductor 658, the lower contact of cam 932 ($16\frac{1}{2}$ to $19\frac{1}{2}$), the upper contact of cam 921 ($16\frac{3}{4}$ to $17\frac{1}{4}$), the upper left-hand armature and front contact of relay 903, and thence to the negative pole of battery through the high resistance element 922. The resulting impulse transmitted over the fundamental circuit is, therefore, a weak positive impulse. As switch 920 rotates from position $17\frac{3}{4}$ to $18\frac{1}{4}$, the ring conductor 911 is connected to the negative pole of battery over the lower contact of cam 918 and through the high resistance 925 and the low resistance element 923, and the tip conductor 913 is connected to the positive pole of battery through the upper contact of cam 914. Since at this time register relays 618, 619 and 620 are energized, a shunt exists around the high resistance element 925 which may be traced from one terminal of resistance element 925 through the upper contact of cam 918 ($17\frac{3}{4}$ to $18\frac{1}{4}$), conductor 930, sequence switch cam 1151 (6 to 7), lead 1152, thence as previously traced over conductor 658 through the contact of cam 932, the lower contact of cam 921, the outer right-hand armature and front contact of relay 903 to the other terminal of resistance element 925. The resulting negative impulse transmitted over the fundamental circuit is, therefore, strong. During the rotation of switch 920 from position $18\frac{3}{4}$ to position $19\frac{1}{4}$, the ring conductor 911 of the fundamental circuit is connected to the positive terminal of battery over the lower contact of cam 914, and the tip conductor 913 being open at this time no impulse is transmitted over the fundamental circuit. During the rotation of switch 920 from position $19\frac{3}{4}$ to position $20\frac{1}{4}$, the ring conductor 911 of the fundamental circuit is connected to the negative pole of battery over the lower contact of cam 918 and through resistance elements 923 and 925, and conductor 913 is connected to the positive pole of battery through the upper contact of cam 914. Since no shunt exists at this time around the high resistance element 925, a weak negative impulse is transmitted over the fundamental circuit.

- At the local sender in response to the first positive impulse, the positively polarized relay 1800 energizes and establishes a circuit from ground on conductor 1804 through its armature and front contact, conductor 1815, the outer armature and back contact of relay 1807, the left-hand armature and front contact of relay 1812, the outer left-hand armature and front contact of relay 1813, the outer left-hand armature and back contact of relay 1816, conductor 1818, winding of relay 1902, and thence to battery. Relay 1902 upon energizing closes a locking circuit for itself through the winding of relay 1903 and through its own right-hand armature and front contact to ground on conductor 1811. In response to the second strong negative impulse, the negatively polarized relay 1801 and marginal relay 1802 energize. Relay 1801 upon energizing closes the previously traced circuit for relay 1807 which upon energizing establishes a circuit for transfer relay 1816 which may be traced from battery through the winding of relay 1816, the right-hand armature and back contact of relay 1819, the right-hand armatures and front contacts of relays 1814 and 1809, the intermediate armature and contact of relay 1807, and thence to ground on conductor 1804. Relay 1816 upon energizing opens the previously traced circuit of relay 1902 and closes a locking circuit for itself extending through the winding of relay 1819, the inner right-hand armature and contact of relay 1816, to ground on conductor 1804. Relay 1819, however, does not energize in this circuit since its winding is shunted by ground over a circuit extending through the intermediate armature and front contact of relay 1807. Upon the energization of relay 1802 a circuit is established which may be traced from ground at the armature contact of this relay, conductor 1808, the outer left-hand armatures and front contacts of relays 1809 and 1814, the outer left-hand armature and back contact of relay 1819, conductor 1820, and thence to battery through the right-hand winding of relay 1904. Relay 1904 upon energizing closes a locking circuit for itself extending through both of its windings and left-hand armature contact to ground on conductor 1811.
- Upon the cessation of the impulse of current through the windings of relays 1801 and 1802, these relays deenergize whereupon relay 1806 energizes as previously described. In response to the last weak negative impulse, relay 1801 again energizes and establishes a circuit from ground on conductor 1804 through its armature and contact for shunting down relay 1807. Upon the cessation of this impulse and the deenergization of relay 1801, relay 1806 deenergizes. Relays 1806 and 1807 both being now deen-

ergized the shunt around the winding of relay 1819 is removed and this relay energizes in the locking circuit of relay 1816 preparatory to controlling the registration of the stations digit.

70

Registration of stations designation on the register relays of the local sender.

It has been assumed that the numerical designation of the desired line is 3916-R 75 and that this designation has been registered upon the numerical and stations groups of register relays of the suburban sender. As switch 920 rotates from position 20½ to position 4½, a code of impulses representing the stations designation R is transmitted over the fundamental circuit under the control of stations relays 632, 633 and 641, all of these relays being at this time energized. This code of impulses comprises three impulses, a weak negative followed by a positive and a second weak negative impulse. As switch 920 rotates from position 20¾ to position 1¼, the ring conductor 911 of the fundamental circuit is connected to the positive terminal of the battery over the lower contact of cam 914, and the tip conductor 913 being open, no impulse is transmitted.

85

As switch 920 rotates from position 1¾ to position 2¼, the ring conductor 911 is connected to the negative pole of battery through the lower contact of cam 918, resistance elements 923 and 925, and the tip conductor 913 is connected to the positive pole of battery through the upper contact 90 of cam 914. The resulting impulse transmitted over the fundamental circuit is therefore weak and of negative polarity. As switch 920 rotates from position 2¾ to position 3¼, the ring conductor 911 is connected to the positive pole of battery over the lower contact of cam 914 and the tip conductor 913, over the upper contact of cam 915 (2¾ to 3¼), the lower contact of cam 915 (2½ to 3½), conductor 929, the upper contact 100 of cam 1149 (6 to 7), the No. 4 lead 1150, lead 659 Fig. 6, the outer right-hand armature and front contact of relay 632, the inner left-hand armature and front contact of relay 641, the outer right-hand armature and front contact of relay 633, conductor 660, contact of cam 934, conductor 935, the lower contacts of cam 1153 (6 to 7), conductor 1154, the right-hand contact of cam 936, and thence to the negative pole of battery 115 through resistance element 922. A weak positive impulse is thus transmitted over the fundamental circuit. During the rotation of switch 920 from position 3¾ to position

105

4¼, conductor 911 is connected to the negative pole of battery through the lower contact of cam 918 and resistance elements 923 and 925 and tip conductor 913 is connected to the positive pole of battery over the upper contact of cam 914 and the resultant im- 120

110

115

125

130

pulse which is transmitted over the fundamental circuit is negative in polarity and of weakened strength.

- At the office sender in response to the first 5 negative impulse, negatively polarized relay 1801 energizes, establishing the previously traced circuit for relay 1807, which latter relay upon energizing establishes a circuit for switching relay 1821 which may be 10 traced from battery through the winding of relay 1821, the right-hand armature and back contact of relay 1822, thence over the right-hand armatures and front contacts of relays 1819, 1814 and 1809 and the intermediate right-hand armature and contact of 15 relay 1807 to ground on conductor 1804.

- In response to the cessation of the first negative impulse, relay 1806 energizes in the manner previously described. In response to the second impulse of positive polarity, the positively polarized relay 1800 energizes and establishes a circuit for stations register relay 1905 which may be 20 traced from ground on conductor 1804 through the armature and contact of relay 1800, conductor 1815, the outer armature and front contact of relay 1807, the inner left-hand armatures and front contacts of relays 1813, 1816 and 1821, the inner left-hand 25 armature and back contact of relay 1825, conductor 1823 and through the winding of stations relay 1905 to battery. Relay 1905, upon energizing, locks through both of its 30 windings and its right-hand armature contact to ground on conductor 1906. In response to the last negative impulse of the code, relay 1801 again energizes and establishes a circuit for shunting down relay 1807 as previously described. Upon the cessation 35 of this impulse, relay 1801 deenergizes, opening the circuit of relay 1806. Relays 1806 and 1807 both being deenergized at this time, the shunt around the winding of relay 1822 is opened and relay 1822 energizes 40 in the locking circuit of relay 1821 to prepare the registration circuits for registering the thousands code of impulses.

Registration of thousands numerical code on the register relays of the local sender.

- During the rotation of impulser switch 920 from position $4\frac{1}{2}$ to position $8\frac{1}{2}$, a code of impulses is transmitted in accordance with the registration registered by the incoming brush register relays 605, 613, 614 and incoming group relay 625 of the suburban sender. It having been assumed that the thousands digit is 3 and that accordingly incoming brush register relays 605 and 614 and incoming group relay 625 are energized, a code comprising a positive, a negative and a strong negative impulse is, therefore, transmitted for setting incoming brush and group register relays of the local sender. As switch 920 rotates from position

4 $\frac{3}{4}$ to position $5\frac{1}{4}$, the ring conductor 911 of the fundamental circuit is connected to the positive pole of battery through the lower contact of cam 914, and the tip conductor 913 is connected to the negative pole of battery over the upper contact of cam 915 ($4\frac{3}{4}$ to $5\frac{1}{4}$), the upper contact of cam 933 ($4\frac{1}{2}$ to $5\frac{1}{2}$), conductor 931, the upper contact of cam 1133 (6 to 7), the No. 1 lead 1134, lead 661, Fig. 6, the inner right-hand armature and back contact of relay 613, the left-hand armature and front contact of relay 605, the right-hand armature and front contact of relay 614, conductor 662, the lower contact of cam 939 ($4\frac{1}{2}$ to $7\frac{1}{2}$), conductor 935, the lower contacts of cam 1153 (6 to 7), conductor 1154, the right-hand contact of cam 936, and thence to the negative pole of battery through resistance element 922. Thus, a weak impulse of positive current is transmitted over the fundamental circuit. As switch 920 rotates from position 5 $\frac{3}{4}$ to position $6\frac{1}{4}$, the ring conductor 911 is connected to the negative pole of battery through the lower contact of cam 918 and resistance elements 925 and 923, and the tip conductor of the fundamental circuit is connected to the positive pole of battery over the upper contact of cam 914. The resulting impulse of negative current transmitted over the fundamental circuit is, therefore, of weakened strength due to the inclusion of high resistance element 925. During the rotation of switch 920 from position 6 $\frac{3}{4}$ to position 7 $\frac{1}{4}$, the ring conductor 911 is connected to the positive pole of battery over the lower contact of cam 914, but since the tip conductor 913 is open at this time no impulse is transmitted. As switch 920 rotates from position 7 $\frac{3}{4}$ to position 8 $\frac{1}{4}$, the ring conductor 911 is connected over the lower contact of cam 918 through resistance elements 925 and 923 to the negative pole of battery, and the tip conductor 913 is connected to the positive pole of battery over the upper contact of cam 914. Since incoming group register relay 625 is energized at this time high resistance element 925 is shunted from the fundamental circuit by a shunt circuit which may be traced from one terminal of element 925 over conductor 927, the outer right-hand armature and contact of relay 625, conductor 663, the upper contact of cam 940 (7 to 9), the upper left-hand contact of cam 941 (7 $\frac{3}{4}$ to 8 $\frac{1}{4}$), and to the other terminal of resistance element 925. The negative impulse thus transmitted over the fundamental circuit is of strong character in view of the shunting of resistance element 925 from the fundamental circuit.

At the local sender in response to the first positive, impulse relay 1800 energizes and establishes a circuit which may be traced from ground on conductor 1804, the arma-

ture and contact of relay 1800, conductor 1815, the outermost armature and back contact of relay 1807, the left-hand armature and front contact of relay 1812, the outer left-hand armatures and front contacts of relays 1813, 1816 and 1821, the outer left-hand armature and back contact of relay 1825, conductor 1830, and thence to battery through the left-hand winding of register relay 1913. Relay 1913 upon energizing locks through both of its windings and its inner right-hand contact to ground on conductor 1906. In response to the second impulse of negative current relay 1801 energizes and establishes a circuit which may be traced from ground on conductor 1804 through its armature contact over conductor 1805, and through the winding of relay 1807 causing the energization of relay 1807. Relay 1807 upon energizing establishes a circuit for relay 1825 which may be traced from battery through the winding of relay 1825, the right-hand armature and back contact of relay 1826, the right-hand armatures and front contacts of relays 1822, 1819, 1814 and 1809, the intermediate armature and contact of relay 1807 to ground on conductor 1804. Upon the cessation of this impulse relay 1806 energizes in the manner previously described. In response to the last or strong negative impulse both the negatively polarized relay 1801 and marginal relay 1802 energize. Relay 1801 at this time causes the shunting down of relay 1807 in the manner previously described, and relay 1802 establishes a circuit which may be traced from ground at its armature contact over conductor 1808, the outer right-hand armature and front contact of relay 1806, the inner left-hand armatures and front contacts of relays 1809, 1814, 1819 and 1822, the inner left-hand armature and back contact of relay 1826, conductor 1829, and thence to battery through the left-hand winding of register relay 1915. Relay 1915 upon energizing locks in a circuit extending from battery through both of its windings and inner right-hand armature and contact to ground on conductor 1906. Upon the cessation of the last negative impulse relay 1806 deenergizes and since at this time relay 1807 is also deenergized, the shunt around the winding of relay 1826 is removed and this relay energizes in the locking circuit of relay 1825. With both relays 1825 and 1826 now energized circuits are prepared for controlling the registration of the hundreds digit of the desired number.

• *Registration of hundreds digit on register relays of local sender.*

During the rotation of switch 920 from position $8\frac{1}{2}$ to position $12\frac{1}{2}$, a code of impulses is transmitted in accordance with the setting of the final brush register relays 628,

629 and 630 and of the incoming group register relay 631 of the suburban sender. It having been assumed that the hundreds digit of the desired number is 9 and that, therefore, the final brush register relays 628 and 629 are energized and the incoming group register relay 631 is also energized, a code comprising a negative, a positive and a strong negative impulse is transmitted for setting the incoming group and final brush register relays of the local sender. As switch 920 rotates from position $8\frac{3}{4}$ to position $9\frac{1}{4}$, the ring conductor 911 of the fundamental circuit is connected to the positive pole of battery over the lower contact of cam 914, but since the tip conductor 913 is open at this time no impulse is transmitted. As switch 920 rotates from position $9\frac{3}{4}$ to position $10\frac{1}{4}$, the ring conductor 911 is connected to the negative pole of battery over the lower contact of cam 918 and through resistance elements 925 and 923, and the tip conductor 913 is connected to the positive pole of battery over the upper contact of cam 914. Since high resistance element 925 is included in the fundamental circuit at this time the resulting impulse transmitted over the fundamental circuit is weak and negative in polarity. During the rotation of switch 920 from position $10\frac{3}{4}$ to position $11\frac{1}{4}$, the ring conductor 911 of the fundamental circuit is connected to the positive pole of battery over the lower contact of cam 914, and the tip conductor 913 is connected over the upper contact of cam 915, the lower contact of cam 915 ($10\frac{1}{2}$ to $11\frac{1}{2}$), conductor 929, the upper contact of cam 1149 (6 to 7), the No. 4 lead 1150, lead 665, Fig. 6, the outer right-hand armature and front contact of relay 628, the left-hand armature and back contact of relay 630, the right-hand armature and front contact of relay 629, conductor 664, the upper contact of cam 939 ($8\frac{1}{2}$ to $11\frac{1}{2}$), and thence as previously traced through the upper right hand contact of cam 936 and resistance element 922 to the negative pole of battery. The resulting impulse of current transmitted over the fundamental circuit is, therefore, weak and positive in polarity. As switch 920 rotates from position $11\frac{3}{4}$ to position $12\frac{1}{4}$, the ring conductor 911 is connected to the negative pole of battery over the lower contact of cam 918 and through resistance elements 925 and 923, and the tip conductor 913 is connected to the positive pole of battery over the upper contact of cam 914. Since at this time the incoming group register relay 631 is energized, a shunt circuit is established around the high resistance element 925 which may be traced over conductor 927, conductor 653, the inner right-hand armature and front contact of relay 631, conductor 666, the lower right-hand contact of cam 940 (11 to 13), the

lower left-hand contact of cam 941 ($11\frac{3}{4}$ to $12\frac{1}{4}$), the outer right-hand armature and back contact of relay 903, and thence to a point between resistance elements 923 and 925. Since resistance element 925 is thus shunted from the fundamental circuit the negative impulse of current transmitted over the fundamental circuit is strong.

At the local sender in response to the first impulse of negative current the negatively polarized relay 1801 energizes and establishes the previously traced circuit for energizing relay 1807, and relay 1807 upon energizing establishes a circuit for relay 1827 which may be traced from battery through the winding of relay 1827, the right-hand armature and back contact of relay 1828, the right-hand armatures and front contacts of relays 1826, 1822, 1819, 1814 and 1809, and thence to ground on conductor 1804 through the intermediate armature and contact of relay 1807. Relay 1827 upon energizing locks through the winding of relay 1828 and its own right-hand armature and contact to ground on conductor 1804. Relay 1828, however, is shunted at this time and does not energize. Upon the cessation of the first negative impulse relay 1806 energizes in the manner previously described. In response to the second positive impulse of current the positively polarized relay 1800 responds and establishes a circuit which may be traced from ground on conductor 1804 over conductor 1815, the outer right-hand armature and front contact of relay 1807, the inner left-hand armatures and front contacts of relays 1813, 1816, 1821 and 1825, and the inner left-hand armature and front contact of relay 1827 over conductor 1831, the outer left-hand armature and back contact of relays 1912, conductor 1921 through the left-hand winding of relay 1916 to battery. Relay 1916 upon energizing locks in a circuit from battery through both its windings and right-hand armature and contact to ground on conductor 1906.

In response to the last impulse of strong negative current the negatively polarized relay 1801 and the marginal relay 1802 energize, relay 1801 shunting down relay 1807 as previously described and relay 1802 establishing a circuit which may be traced from ground through the armature contact of relay 1802, conductor 1808, the outer right-hand armature and front contact of relay 1806, the inner left-hand armatures and front contacts of relays 1809, 1814, 1819, 1822 and 1826, the inner left-hand armature and back contact of relay 1828, conductor 1832, and thence to battery through the left-hand winding of relay 1914. Relay 1914 upon energizing closes a locking circuit extending through both its windings and its inner right-hand armature contact to ground on conductor 1906. Upon the cessation of

the last negative impulse and the deenergization of relay 1801, relay 1806 deenergizes removing the shunt from around the winding of relay 1828 which now energizes in the holding circuit of relay 1827. Relays 1827 and 1828 being both energized prepare circuits for controlling the registration of the tens digit of the desired line.

Registration of the tens digit on register 75 relays of local sender.

During the rotation of switch 920 from position $12\frac{1}{2}$ to position $16\frac{1}{2}$, a code of impulses is transmitted in accordance with the setting of the tens register relays 638, 639, 640 and 642 of the suburban sender. It having been assumed that the tens digit of the desired number is 1 and that register relays 639 and 640 are energized at this time, a code comprising a positive and two negative impulses is transmitted over the fundamental circuit to register the tens digit 1 on the tens register relays of the local sender. As switch 920 rotates from position $12\frac{3}{4}$ through position $13\frac{1}{4}$, the ring conductor 911 of the fundamental circuit is connected to the positive pole of battery through the lower contact of cam 914, and the tip conductor 913 is connected to the negative pole of battery through the upper contact of cam 915, the upper contact of cam 933 ($12\frac{1}{2}$ to $13\frac{1}{2}$), conductor 931, and the upper contact of cam 1133 (6 to 7), No. 1 lead 1134, the No. 1 lead 667, Fig. 6, the inner right-hand armature and back contact of relay 638, the left-hand armature and front contact of relay 640, the right-hand armature and front contact of relay 639, conductor 668, the lower contact of cam 938 ($12\frac{1}{2}$ to $15\frac{1}{2}$), thence as previously traced through resistance element 922 to battery. A weak impulse of positive polarity is thus transmitted over the fundamental circuit. As switch 920 rotates from position $13\frac{3}{4}$ to position $14\frac{1}{4}$, the ring conductor 911 is connected to the negative pole of battery over the lower contact of cam 918 and through resistance elements 925 and 923, and the tip conductor 913 is connected to the positive pole of battery over the upper contact of cam 914. Since both resistance elements 923 and 925 are included in the fundamental circuit a weak impulse of negative polarity is transmitted over the fundamental circuit. As switch 920 rotates from position $14\frac{3}{4}$ to position $15\frac{1}{4}$, the ring conductor 911 is connected to the positive pole of battery over the lower contact of cam 914, but the tip conductor 913 being open at this time no impulse is transmitted. During the rotation of switch 920 from position $15\frac{3}{4}$ through position $16\frac{1}{4}$, the ring conductor 911 is connected to the negative pole of battery over the lower contact of cam 918 and through

resistance elements 925 and 923, and the tip conductor 913 is connected to the positive pole of battery over the upper contact of cam 914, and the resultant impulse transmitted over the fundamental circuit is weak and of negative polarity.

At the local sender in response to the first impulse of positive polarity, the positively polarized relay 1800 responds and establishes a circuit from ground on conductor 1804 through the armature and contact of relay 1800, conductor 1815, the outer armature and back contact of relay 1807, the outer left-hand armatures and front contacts of relays 1812, 1813, 1816, 1821, 1825 and 1827, conductor 1833, the right-hand armature and back contact of relay 1912, and thence to battery through the left-hand winding of relay 1917. Relay 1917 energizes in this circuit and establishes a locking circuit extending from battery through both its windings and its inner right-hand armature and contact to ground on conductor 1907. In response to the second impulse of negative polarity, the negatively polarized relay 1801 energizes and in the manner previously described establishes a circuit for relay 1807. Relay 1807 upon energizing establishes a circuit for relay 1912 which may be traced from battery through the winding of relay 1912, the left-hand armature and back contact of relay 1910, conductor 1834, and thence through the right-hand armatures and front contacts of relays 1828, 1826, 1822, 1819, 1814 and 1809 through the intermediate armature and contact of relay 1807 to ground on conductor 1804. Relay 1912 upon energizing locks up through the winding of relay 1910 and its own inner left-hand armature and contact to ground on conductor 1804. Relay 1910 being shunted at this time by a circuit extending through the armature contact of relay 1807 does not energize. Upon the cessation of the first negative impulse, relay 1806 energizes in the manner previously described. In response to the last negative impulse the negatively polarized relay 1801 energizes and in the manner previously described and shunts down relay 1807, and upon the termination of this impulse and the deenergization of relay 1801 relay 1806 deenergizes. The shunt around the winding of relay 1910 is now removed and relay 1910 energizes. Relays 1910 and 1912 being both energized circuits are prepared for controlling the registration of the units digit.

Registration of units digit on register relays of local sender.

During the rotation of switch 920 from position 16½ to position 20½, a code of impulses is transmitted in accordance with the setting of the units register relays 646 to 649 inclusive of the suburban sender. It having

been assumed that the units digit is 6 and that register relays 647, 648 and 649 are at the time energized, a code comprising a positive, a negative and a strong negative impulse is transmitted over the fundamental circuit to control the registration of the units digit upon the units register relays of the local sender. As switch 920 rotates from position 16¾ through position 17¼, the ring conductor 911 of the fundamental circuit is connected to the positive pole of battery over the lower contact of cam 914, and the tip conductor of the fundamental circuit is connected to the negative pole of battery over the upper contact of cam 915, the upper contact of cam 933 (16½ to 17½), conductor 931, the upper contact of cam 1133 (6 to 7), the No. 1 lead 1134, the No. 1 lead 671, Fig 6, the inner right-hand armature and back contact of relay 646, the left-hand armature and front contact of relay 648, the right-hand armature and front contact of relay 647, conductor 672, the upper contact of cam 938 (16½ to 19½), and thence as previously traced to battery through resistance element 922. An impulse of positive polarity is thus transmitted over the fundamental circuit. As switch 920 rotates from position 17¾ to position 18¼, the ring conductor 911 of the fundamental circuit is connected to the negative pole of battery over the lower contact of cam 918 and through resistance elements 925 and 923, and the tip conductor of the fundamental circuit is connected to the positive pole of battery through the upper contact of cam 914. During the rotation of switch 920 from position 18¾ to position 19¼, the ring conductor 911 is connected to the positive pole of battery over the lower contact of cam 914, but the tip conductor being open no impulse is transmitted at this time. During the rotation of switch 920 from position 19¾ to position 20¼, the ring conductor 911 is connected to the negative pole of battery over the lower contact of cam 918 through resistance elements 925 and 923, and the tip conductor is connected to the positive pole of battery over the upper contact of cam 914. Since at this time units register relay 649 is energized the high resistance element 925 is shunted from the fundamental circuit by a shunt extending over conductor 927, conductor 653, the inner right-hand armature and front contact of relay 649, conductor 669, the lower right-hand contact of cam 941 (19 to 1), the lower left-hand contact of cam 941 (19¾ to 20¼), the outer right-hand armature and back contact of relay 903, and thence to resistance element 925. A strong negative impulse is thus transmitted over the fundamental circuit. When switch 920 reaches position 1, as no driving circuits exist for its clutch magnet, it comes to rest in its normal position 1.

At the local sender in response to the first impulse of positive polarity, the positively polarized relay 1800 responds and establishes a circuit extending from ground on conductor 1804 over conductor 1815, the outer armature and back contact of relay 1807, the outer left-hand armatures and front contacts of relays 1812, 1813, 1816, 1821, 1825 and 1827, conductor 1833, the right-hand armature and front contact of relay 1912, conductor 1922, and thence to battery through the left-hand winding of relay 1918. Relay 1918 upon energizing locks over both of its windings and inner right-hand armature and contact to ground on conductor 1907. In response to the second impulse of negative polarity the negatively polarized relay 1801 responds and in the manner previously described establishes a circuit for relay 1807, which in turn establishes a circuit for relay 1911 which may be traced from battery through the winding of relay 1911, the inner left-hand armature and back contact of relay 1909, the left-hand armature and front contact of relay 1910, conductor 1834, and thence through the right-hand armatures and front contacts of relays 1828, 1826, 1822, 1819, 1814, 1809, and the intermediate armature contact of relay 1807 to ground on conductor 1804. Relay 1911 locks through the winding of relay 1909 and its own left-hand armature contact to ground on conductor 1804. Relay 1909 does not energize in this locking circuit since its winding is shunted at this time by the circuit extending through the intermediate armature and contact of relay 1807. Upon the cessation of the negative impulse of current and the deenergization of relay 1801, relay 1806 becomes energized in the manner previously described. In response to the last strong negative impulse of current relay 1801 and marginal relay 1802 energize, the energization of relay 1801 causing the shunting down of relay 1807 as previously described, and the energization of relay 1802 establishing a circuit which may be traced from ground at the armature contact of relay 1802 over conductor 1808, the outer right-hand armature and front contact of relay 1806, the inner left-hand armatures and front contacts of relay 1809, 1814, 1819, 1822, 1826, 1828, the outer right-hand armature and front contact of relay 1910, conductor 1923, and thence to battery through the left-hand winding of relay 1920. Relay 1920 upon energizing locks through both of its windings and its inner right-hand armature and contact to ground on conductor 1907. Upon the cessation of this impulse of negative current relay 1806 deenergizes whereupon relay 1909 becomes energized in the locking circuit of relay 1911. The complete office and numerical designation of the desired line C H E 3916-R has now been registered upon the register relays 65 of the local sender.

During the rotation of impulsing switch 920 from position 9 into normal position 1, relay 908 is deenergized since its locking circuit is opened at the upper contact of 70 cam 905, and, therefore, the ring conductor 911 of the fundamental circuit is completed over the lower contact of cam 917 (2 to 20 1/4) to conductor 1146, and the tip conductor 913 is completed over the lower right-hand and upper left-hand contacts of cam 916 (2 to 20 1/4) to conductor 1022. When switch 920 reaches position 1 with sender control switch 1220 in position 13, a circuit is established for advancing switch 1220 80 into position 14 awaiting the functioning of the district selector 1350, over a circuit which may be traced from battery through the magnet winding of switch 1220, the upper left-hand contact of cam 1211 (13), 85 conductor 1155, the lower contacts of cam 1136, conductor 1027, the upper contacts of cam 1036, conductor 941, the upper right-hand and lower left-hand contacts of cam 916 (1), the outer right-hand armature and 90 back contact of relay 908, conductor 912, the lower right-hand and upper left-hand contacts of cam 1025, conductor 1026, the right-hand contacts of cam 1147, conductor 1148, the outer left-hand armature and back 95 contact of relay 1011, conductor 1149, and thence to ground through the lower right-hand contact of cam 1141 (7 to 5).

Setting the A and B code registers of the local sender. 100

At the local sender at the time relay 1813 energized following the registration of the first digit of the office code, ground potential is applied to a terminal in the bank A¹ 105 of the code register A and a starting circuit is established through the stepping magnet 2002 of the code register A. The first circuit may be traced from ground through the lower contact of cam 1716 (1 to 7), conductor 1834, the outer right-hand armature and front contact of relay 1813, conductor 1835, the left-hand armature and back contact of relay 1923, the inner right-hand armature and back contact of relay 1924, the inner right-hand armature and 110 front contact of relay 1900, the inner right-hand armature and back contact of relay 1955, and thence to terminal 2001 of the bank A¹ of register A. The second circuit may be traced over conductor 1835, conductor 1930, the armature contact and winding of stepping magnet 2002, and thence to battery through the right-hand armature and 115 back contact of relay 2003. Magnet 2002 upon energizing interrupts its own circuit 120 and steps the wipers of code register A over the terminals of their respective banks until 125 this impulse of negative current relay 1806 deenergizes whereupon relay 1909 becomes energized in the locking circuit of relay 1911. The complete office and numerical designation of the desired line C H E 3916-R has now been registered upon the register relays 65 of the local sender.

the wiper 2004 encounters the bank terminal 2001 when a circuit is completed from ground connected to terminal 2001 over wiper 2004, the low resistance left-hand winding of relay 2003, and thence to battery through the right-hand armature and back contact of relay 2003. Relay 2003 energizes in this circuit opening the circuit through the stepping magnet 2002 and opening the shunt around its right-hand high resistance winding. Relay 2003 is now maintained energized over the circuit previously traced and through both of its windings.

Following the completion of the registration of the second code digit, relay 1816 energized and closed a circuit for applying ground potential to a terminal in the bank B¹ of the code register B and a circuit through the stepping magnet 2007 of this code register. The first circuit may be traced from ground on conductor 1834 through the outer right-hand armature and front contact of relay 1816, conductor 1836, the left-hand armature and back contact of relay 1925, the inner right-hand armature and front contact of relay 1901, conductor 1926, and thence to terminal 2006 of bank B¹. The second circuit may be traced from conductor 1836 over conductor 1977 through the armature contact and winding of stepping magnet 2007 to battery at the right-hand armature and back contact of relay 2008. Stepping magnet 2007 energizes in this circuit and advances the wipers of the B code register until the wiper 2009 engages the terminal 2006, when a circuit is established for relay 2008 which may be traced from ground connected to terminal 2006, wiper 2009, the low resistance left-hand winding of relay 2008, and thence to battery at the right-hand armature and back contact of relay 2008. Relay 2008 upon energizing opens the previously traced circuit of stepping magnet 2007 and removes the shunt from around its own right-hand high resistance winding whereupon relay 2008 is maintained energized over the previously traced circuit through both of its windings.

50 *Setting the translator switch.*

With relays 2003 and 2008 both energized a circuit is established for the differential relay 1707, which extends from grounded battery through the right-hand winding of this relay, the upper contacts of cam 1708, conductor 1709, and to ground through the left-hand armature contacts of relays 2003 and 2008. Relay 1707 upon energizing establishes a circuit for advancing sequence switch 1720 out of its normal position into position 2, which circuit extends from battery through the magnet winding of switch 1720, the lower right-hand contact of cam 1711 (1), conductor 1710, and thence to

ground at the armature and front contact of relay 1707. With sequence switch 1720 in position 2 and relay 1707 energized, a circuit is established for the updrive magnet 2010 of the translator switch 2000 which 70 may be traced from battery through the winding of this magnet, conductor 2011, the left-hand contacts of cam 1712 (2), and thence to ground at the armature and front contact of relay 1707. Magnet 2010 upon 75 energizing presses the depending portion of switch shaft 2012 against the constantly rotating updrive drum 2013, whereupon the switch shaft is driven upwardly in its brush selection movement until the test brush 2014 80 engages a terminal in the test bank 2015 which has been grounded through the combined settings of the A and B code registers. It has been assumed that terminal 2016 of the bank has been grounded by the 85 A and B code registers, therefore when brush 2014 engages this terminal a circuit is established through the left-hand winding of differential relay 1707, the right-hand contacts of cam 1713, conductor 1714, brush 90 2014, bank terminal 2016, conductor 2017, terminal 2018 of bank A³, wiper 2019, terminal 2021 of bank B², wiper 2022, conductor 2023, and thence to ground at the lower left-hand contact of cam 1715 (1 to 3). Current flowing through the left-hand winding of relay 1707 differentially balances the relay, which thereupon deenergizes opening at its armature and front contact the circuit 95 previously traced through the updrive magnet 2010 of the translator switch, thereby arresting the upward movement of the switch. The brush shaft of this switch is now positioned with a certain pair of its brush sets in cooperative relation with a 100 tripping finger on the tripping spindle 2034. Relay 1707 upon deenergizing also closes a circuit for driving sequence switch 1720 out of position 2 and into position 3, this circuit 105 extending from battery through the magnet 110 winding of switch 1720, the lower left-hand contact of cam 1711 (2), and thence to ground at the armature and back contact of relay 1707.

Upon leaving position 2 the initial energizing circuit extending through the right-hand winding of relay 1707 was opened at the contact of sequence switch 1708, but this circuit is again established as soon as the switch reaches position 3 and relay 1707, 115 therefore, again energizes. Upon reaching position 3 a circuit is established for the tripping magnet 2033 which may be traced through the winding of this magnet, conductor 2035, and thence to ground at the upper left-hand contact of cam 1715 (3 to 5). The tripping magnet upon energizing in this circuit rotates the tripping spindle 2034 to position tripping fingers to trip the 120 pair of brush sets of the translator switch 125 130

which have been positioned in operative relation to a pair of tripping fingers on the tripping spindle, so that the pair of brush sets may be tripped upon a subsequent movement of the switch shaft. It will be assumed that the brush sets shown in Fig. 20 of the drawing are, therefore, sets which are to be tripped at this time.

- Relay 1707 upon energizing in position 3 of switch 1720 again closes the circuit for advancing sequence switch 1720 out of position 3 and into position 4. With switch 1720 in position 4 and relay 1707 energized, the circuit of the updrive magnet 2010 of the translator switch is again established and the switch shaft is driven upwardly in its group selection movement. During the initial portion of this movement the selected pair of brush sets is tripped, and during the subsequent upward movement of the switch shaft the brushes of these sets are caused to wipe over the terminals of the banks to which they have access until the test brush 2014 engages a terminal in the test bank 2015 corresponding to the group setting of the code registers, this terminal having ground potential connected thereto through wipers of the A and B code registers. A circuit is now established extending from battery through the left-hand winding of relay 1707, the right-hand contacts of cam 1713, conductor 1714, test brush 2014, bank terminal 2022, conductor 2023, terminal 2024 of bank B⁴, wiper 2025, terminal 2026 of bank A⁶, wiper 2027, conductor 2028, conductor 1837, and thence to ground over the upper contact of cam 1716 (2 to 5). Upon the closure of this circuit through the left-hand winding of relay 1707, the relay is differentially balanced and de-energizes opening at its armature and front contact the circuit of updrive magnet 2010 to arrest the upward movement of the switch shaft, and to position the selected sets of brushes upon the first terminal of a group of bank terminals corresponding to the setting of code registers A and B, and closing at its armature and back contact the previously traced circuit for advancing switch 1720 out of position 4 and into position 5. Upon leaving position 4 the initial energizing circuit extending through the right-hand winding of relay 1707 is opened at the contact of cam 1708 (3 to 4), but relay 1707 is again energized as soon as sequence switch 1720 reaches position 5 if the last code registration has been completed, over a circuit which may be traced from battery through the right-hand winding of relay 1707, the upper left-hand and lower right-hand contacts of cam 1708, conductor 1717, the outer right-hand armature and front contact of relay 1821, conductor 1709, and thence to ground through the left-hand armature contacts of relays 2003 and 2008.

Relay 1707 upon energizing advances switch 1720 into position 6 over the circuit previously traced, and again establishes the circuit for updrive magnet 2010 for causing the movement of the selected sets of brushes of the translator switch over the selected group of terminals in the bank to which these sets of brushes have access, and until test brush 2014 engages a contact in the bank 2015 upon which ground potential has been placed by the energization of tandem units register relays, which register relays serve as a C code register. Upon the engagement of test brush 2014 with terminal 2029, a circuit is established through the left-hand winding of relay 1707, which may be traced from battery through the left-hand winding of this relay, the right-hand contacts of cam 1713, conductor 1714, brush 2014, bank terminal 2029, conductor 2030, the inner right-hand armature and front contact of register relay 1903, the inner right-hand armature and front contact of relay 1904, the inner right-hand armature and back contact of relay 1927, the left-hand armature and back contact of relay 1928, conductor 1929, and thence to ground through the upper right-hand contact of cam 1718 (5 to 7). The current flowing through the left-hand winding of relay 1707 now differentially balances this relay causing its deenergization, whereupon the circuit of updrive magnet 2010 of the translator switch is opened to arrest the upward movement of the switch shaft and a circuit is established over the armature and back contact of relay 1707 for advancing switch 1720 out of position 6 and into position 8. In passing out of position 6 the initial energizing circuit of relay 1707 is opened at the lower contact of cam 1708, and in passing into position 7 a circuit is established for relay 2031 which may be traced from battery through the winding of this relay, conductor 2032, thence to ground through the lower right-hand contact of cam 1715 (7 to 8). Relay 2031 upon energizing connects the brushes of the translator switch to the windings of translator register control relays 2100, 2101, 2102, 2103 and 2104.

Setting the translator register relays.

Upon the connection of relays 2100 to 2104 inclusive with the brushes of the translator switch, impulses are transmitted thereto from the pulse machine drum P M. In the case assumed 5 impulses are transmitted from battery through brush 2036, slip ring 2037, segments 2038, brush 2039, bank terminal 2040 and brush 2041 of the translator switch, conductor 2042, and thence to ground through the winding of class control relay 2100. Similarly, a circuit is established from battery through brush 2036, ring 2037, segments 2080, brush 2079, bank terminal 139

- 2045 and brush 2046 of the translator switch, conductor 2047, and thence to ground through the winding of district brush relay 2101. A circuit is closed for office brush 5 control relay 2102 which may be traced from battery through brush 2036, ring 2037, segments 2078, brush 2077, bank terminal 2048 and brush 2049 of the translator switch, conductor 2050, and thence to ground through 10 the winding of control relay 2102. The circuit of the district group register control relay 2103 may be traced from battery through brush 2036, ring 2037, segments 2051, brush 2052, bank terminal 2053 and 15 brush 2054 of the translator switch, conductor 2055, and thence to ground through the winding of relay 2103, and the circuit of office group register control relay 2104 may be traced from battery through brush 20 2036, ring 2037, segment 2043, brush 2044, bank terminal 2056 and brush 2076 of the translator switch, conductor 2057, and thence to ground through the winding of relay 2104.
- 25 Relay 2100 upon energizing closes an obvious circuit for relays 2105 and 2106 and the impulses received from the drum of the pulse machine by relay 2100 will thus be transmitted to the relays of 2105 and 2106.
- 30 Similarly, upon the energization of relays 2101, 2102, 2103 and 2104, relays 2124, 2126, 2131, 2132 and 2133 become energized upon each energization of the corresponding control relays. As soon as the pulse machine 35 has rotated the drum to a point where brush 2039 engages the first segment 2038 and relays 2100, 2105 and 2106 are thus energized, a circuit will be closed for the class register relay 2107 which may be traced from battery through brush 2036, slip ring 2037, segment 2058, brush 2066, conductor 2068, conductor 2108, and to ground through the right-hand winding of relay 2107. Relay 40 2107 upon energizing locks over a circuit 45 extending from ground through its left-hand winding and left-hand armature contact, conductor 2109, and to battery over the lower contact of cam 1719 (2 to 16 1/4). When the pulse machine drum rotates to a 50 position in which the second segment 2038 is engaged with brush 2039, a circuit is established for the second class register relay 2111 which may be traced from battery over brush 2036, ring 2037, segment 2059, brush 2067, conductor 2069, conductor 2110, and thence to ground through the right-hand winding of relay 2111. When the pulse machine drum rotates to a point in which the third segment 2038 is in engagement with brush 2039, a circuit is established for relay 2114 which may be traced from battery over brush 2036, ring 2037, segment 2064, brush 2062, conductor 2070, conductor 2113, and thence to ground 55 through the right-hand winding of relay 60 65 70 75 80 85 90 95 100 105 110 115 120 125 130
2114. Upon the engagement of brush 2039 with the fourth segment 2038 of the pulse machine drum, a circuit is established for class register relay 2115 which may be traced from battery to brush 2036, ring 2037, segment 2065, brush 2063, conductor 2071, conductor 2112, and thence to ground through the right-hand winding of relay 2115. When brush 2039 engages the fifth segment 2038, a circuit is established for the skip office register relay 2117 which may be traced from battery over segment 2036, ring 2037, segment 2072, brush 2073, conductor 2074, conductor 2116, and thence to ground through the right-hand winding of relay 2117. Relays 2111, 2114, 2115 and 2117 upon energizing lock through their left-hand windings and left-hand armature contacts to ground on conductor 2109.
- In a manner similar to that above described the district brush register relay 2119 and the compensating resistance register relay 2136 are energized through the operation of control relays 2101, 2124 and 2126 when the pulse machine drum rotates 90 through the positions in which the segments 2080 engage the brush 2079. Relays 2119 and 2136 lock to ground over conductor 2109 through their left-hand windings and inner left-hand armature contacts. When the pulse machine drum rotates through the positions in which the brush 2077 engages segments 2078, the office brush register relay 2123 and the compensating resistance relay 2135 energize through the operation control 100 relays 2102 and 2131, and upon energizing lock to ground on conductor 2134 through their left-hand windings and inner left-hand armature contacts and the upper contact of cam 1719 (2 to 16). As the pulse machine 105 drum rotates through positions in which brush 2052 engages segments 2051, district group register relays 2129 and 2128 are energized through the operation of control relays 2103 and 2132 and lock up through their 110 left-hand windings and inner left-hand armature contacts to ground on conductor 2134. As the pulse machine drum rotates through the position in which segment 2043 engages brush 2044, a circuit is established 115 through the operation of relays 2104 and 2133 for energizing the office group register relay 2122, which upon energizing locks through its left-hand winding and inner left-hand armature contact to ground on 120 conductor 2134.
- At the beginning of the transmission of impulses from the pulse machine P M to the translator register control relays, with control sequence switch 1720 in position 8, a circuit is established from battery through brush 2036, ring 2037, timing segments 2060 and brush 2061, conductor 2081, the left-hand contacts of cam 1722 (8), resistance element 1723, conductor 1724, the winding 130

of overflow relay 2202, the winding of sender stepping relay 2203, the upper contact of cam 1725 (8), and thence to ground through resistance element 2204. At this time a circuit is also closed for the No. 6 counting relay 2205 which may be traced from battery through the winding of relay 2205, the armature and back contact of the No. 6' counting relay 2206, the No. 6 lead 2207, lead 2207, Fig. 17, the lower right-hand contact of cam 1726 (8), conductor 1727, conductor 2208, the normally closed contacts associated with the outer left-hand armature of relay 2209, conductor 2210, the upper left-hand contact of cam 1728 (7 to 8), conductor 1729, the armature and contact of sender stepping relay 2203, and thence to ground at the upper right-hand contact of cam 1733 (7 to 8). In response to the first timing impulse through the stepping relay 2203, the circuit just traced through counting relay 2205 is closed and this relay energizes closing a locking circuit for itself extending from battery through its winding, the winding of the No. 6' counting relay 2206, the armature and front contact of relay 2205, conductor 2211, conductor 2212, and thence to ground through the left-hand contact of cam 1730 (8). Counting relay 2206 does not energize in this circuit in view of the fact that its winding is shunted by ground connected to one terminal of its winding over lead 2207 and through the contact of stepping relay 2203. As soon, however, as relay 2203 energizes following the transmission of the first timing impulse, this shunt circuit is opened and relay 2206 energizes extending the circuit from lead 2207 through the armature and front contact of relay 2206, the armature and back contact of the No. 5' counting relay 2214 to battery through the winding of the lower No. 5 counting relay 2213. Relay 2213 upon energizing closes a locking circuit for itself through the winding of the No. 5' counting relay 2214, the armature and contact of relay 2213, conductor 2215, conductor 2216, and thence to ground through the lower right-hand contact of cam 1730 (8). Upon the next deenergization of relay 2203 the No. 5' counting relay 2214 energizes in the locking circuit of relay 2213 and extends the connection from lead 2207 through its armature and front contact, the lower contacts of cam 2218, the armature and back contact of the No. 4' counting relay 2219, and thence to battery through the winding of the No. 4 counting relay 2217. In this manner in response to successive timing impulses from the pulse machine drum, counting relays 2217, 2221, 2222 and 2223 energize in succession and lock up through the corresponding upper counting relays. Upon the energization of the No. 1' counting relay 2234, the No. 6 lead 2207 is connected through its armature and front contact over conductor 2226, the inner left-hand armature and back contact of relay 2227, conductor 2228 through the winding of the No. 0 counting relay 2224 to battery. Relay 2224 upon energizing locks up through the winding of the No. 0' counting relay 2225 and the winding of relay 2229 in parallel. Upon the next deenergization of relay 2203, relays 2225 and 2229 become energized. At this time seven impulses have been counted out thus insuring a complete revolution of the pulse machine drum for transmitting the necessary impulses to set the translator register relays before relay 2229, by its energization, initiates the movement of the control sequence switch 1720 out of position 8 into position 9, preparatory to advancing the sender sequence switch 2220 into position 2 for controlling the first selective movement of the district selector 1350.

Upon the energization of relay 2225 a circuit is established for advancing sequence switch 1720 out of position 8 into position 9. This circuit may be traced from battery through the magnet winding of switch 1720, the lower left-hand contact of cam 1731 (8), conductor 2231, the lower contacts of cam 2230 to ground at the armature contact of relay 2225. With switch 1720 in position 9, if at this time the registration of the desired number has been completed, relay 1909 will be energized and with registration completed on the translator control register relays Fig. 21, a circuit is established for advancing the sequence switch 2220 of the sender out of normal position into position 2. This circuit may be traced from battery through the magnet winding of switch 2220, conductor 2234, the lower left-hand contact of cam 2235 (1), conductor 2236, the outer right-hand armatures and front contacts of register relays 2119 and 2123, the outer left-hand armature and front contact of relay 2129, the outer right-hand armature and front contact of register relay 2122, conductor 2156, conductor 2137, the outer left-hand armature and front contact of relay 1909, conductor 1931, and thence to ground at the lower right-hand contact of cam 1718 (9).

Setting the class and compensating resistance switches.

It will be assumed that the class switch 2320 is standing at this time in position 2 in which position it served the sender upon the last connection established by the sender, and since the desired connection is to be made to a manual tandem office in the local area, it is necessary to set the class switch into position 9. Therefore, when control switch 1720 passes into position 8½, a circuit is established for advancing class switch 2320 out of position 2 into position 3, which may be traced from ground over the upper left-hand contact of

- cam 1718, conductor 2138, the armature and front contact of class register relay 2107, conductor 2139, the upper left-hand contact of cam 2300 (1 to 2), and thence to battery 6 in parallel through the winding of class switch 2320 and class switch relay 2305. When the class switch reaches position 3 a circuit is closed for further advancing it into position 5 which may be traced from 10 ground on conductor 2138 through the right-hand armature and front contact of class register relay 2115, conductor 2142, the lower right-hand contact of cam 2301 (3 to 4), and thence through the windings of 15 class switch magnet 2320 and relay 2305. Upon reaching position 4 the driving circuit of switch 2320 is further extended over the upper left-hand contact of cam 2301 (4 to 6), conductor 2141, the right-hand armature and front contact of class switch relay 2114, and thence to ground on conductor 2138. When switch 2320 reaches position 7 20 a circuit is established for advancing it into position 9 which may be traced from battery through the winding of relay 2305 and the winding of switch 2320 over the lower right-hand contact of cam 2301 (7 to 8), conductor 2142, the right-hand armature and front contact of relay 2115 to ground on 25 conductor 2138. When switch 2320 reaches position 9 all driving circuits for advancing it out of position 9 are opened at the armature contacts of class register relays and switch 2320 is arrested in position 9. 30 Relay 2305 which was maintained energized during the advance of switch 2320 now de-energizes.

At this time circuits are established for advancing the compensating resistance switch 2350 out of the position in which it is standing, which in this case will be assumed to be position 5, into a position determined by the energized and deenergized condition of compensating resistance relays 40 2143, 2135, 2136 and 2144. It will be assumed that the nature of the connection being established demands the setting of the compensating resistance switch into position 45 4. With switch 1720 in position 9 a circuit is now established as previously traced over conductor 2138, conductor 2145, the right-hand armature and front contact of compensating resistance register relay 2136, conductor 2146, the upper right-hand contact of cam 2303 (5 to 8), and thence in parallel through the winding of relay 2304 and the winding of the driving magnet of switch 2350 to battery. Switch 2350 is advanced by this circuit into position 9, in which position a circuit is established for advancing it into position 1, which latter circuit may be traced from battery through the windings of relay 2304 and driving magnet of switch 2350, the upper right-hand contact of cam 2302 (9 to 18), conductor 2147, the 50 right-hand armature and front contact of register relay 2135, and thence to ground on conductor 2138. Upon reaching position 1 switch 2350 is advanced into position 3 over a circuit which may be traced over the 55 lower right-hand contact of cam 2302 (1 to 2), conductor 2145, the right-hand armature and back contact of register relay 2143, and thence to ground on conductor 2138. From position 3 switch 2350 is further advanced into position 4 over a circuit which may be traced through the lower right-hand contact of cam 2303 (3), conductor 2148, the right-hand armature and back contact of relay 2144, and thence to ground on conductor 2145. When switch 2350 reaches position 4 no driving circuits are available for advancing it out of position 4, and, therefore, the switch comes to rest. Relay 2304 which was maintained energized during the 60 advancement of the compensating resistance switch now deenergizes.

Advance of the operator's district selector for talking selection.

With sender control sequence switch 1720 in position 9 a circuit is now established for relay 1308 of the local sender district which may be traced from battery through the left-hand winding of relay 1308, the lower 65 left-hand contact of cam 1335, conductor 1336, wiper 1337 of sender finder SF, conductor 1338, the upper contacts of cam 1734 (9 to 17), the armature and back contact of relay 2229, the winding of polarized overflow relay 2202, the winding of sender stepping relay 2203, the upper contact of cam 2236 (2), and thence to ground through the resistance element 2204. Relays 1308 and 2203 energize in this circuit. Relay 1308 upon energizing closes a circuit for driving district sequence switch 1320 out of position 70 3 into position 4 which may be traced from battery through the magnet winding of this sequence switch, the lower contact of cam 1310 (3), conductor 1309, and thence to ground through the right-hand armature and front contact of relay 1308. When the sequence switch reaches position 4 battery is connected to the ring conductor 1303 of the 75 district link circuit through the winding of relay 1300 and the left-hand contacts of cam 1322, and ground is connected to the tip conductor 1302 through the lower left-hand and upper right-hand contacts of cam 1301. The 80 current now flowing back over the trunk conductors 1302 and 1303, through the windings of sender stepping relay 1108 and polarized overflow relay 1107 of the suburban sender, is in such a direction as to cause 85 the energization of polarized overflow relay 1107.

Upon the energization of relay 1107 a circuit is established for the No. 0 counting relay 1127 which may be traced from bat- 90

tery through the winding of relay 1127, the left-hand armature and back contact of relay 1132, the lower contact of cam 1028 (12 to 13) of the class switch, conductor 5 1029, the upper contact of cam 1217 (14), conductor 1218, and thence to ground at the armature contact of polarized relay 1107. Relay 1127 upon energizing closes a locking circuit for itself through the windings of 10 relays 1105 and 1128 in parallel through its own armature and contact, conductor 1159 and to ground at the upper right-hand contact of cam 1209 (14).

At the local sender district link, relay 1300 15 energizes in the fundamental circuit and closes a circuit for relay 1306, which latter relay became deenergized when sequence switch 1320 left position 3. The circuit of relay 1306 may now be traced from battery 20 through the armature contact and winding of stepping magnet 1313, conductor 1314, the winding of relay 1306, the upper contacts of cam 1329, and thence to ground at the armature contact of relay 1300. Relay 25 1306 upon energizing establishes a circuit for advancing sequence switch 1320 out of position 4 into position 5, which may be traced from battery through the magnet winding of switch 1320, conductor 1340, the upper left-hand contact of cam 1339 (4), and to ground at the inner left-hand armature contact of relay 1306. As soon as sequence switch 1320 reaches position 5 since 30 relay 1308 has been maintained energized in series with the sender stepping relay 2203 of the local sender through positions 3 to 5, switch 1320 immediately advances into position 6 over the circuit previously traced to ground through the right-hand armature and front contact of relay 1308. Relay 1308 35 is maintained energized after switch 1320 leaves position 5 by a circuit which may be traced from battery through its left-hand winding and inner left-hand armature and contact, conductor 1319, the lower contacts of cam 1341, and thence as previously traced over the fundamental circuit.

As soon as sequence switch 1320 leaves 40 position 4 the fundamental circuit previously traced extending back through the windings of sender stepping relay 1108 and polarized overflow relay 1107 of the suburban sender is opened at the left-hand contacts of cam 1322 (4), and the shunt previously existing around the windings of 45 relays 1105 and 1128 is removed at the armature contact of relay 1107. Relay 1128 upon energizing establishes a circuit for advancing control switch 1220 out of position 5 14 into position 15. This circuit may be traced from battery through the magnet winding of switch 1220, the lower left-hand contact of cam 1210 (13 to 14), conductor 1222, the right-hand contact of class switch 1029 (8 to 3), conductor 1030, the right-hand

contact of sender sequence switch cam 1129 (7 to 8), and to ground at the armature contact of relay 1128.

With switch 1220 in position 15 a circuit is now established for advancing the sequence switch 220 of the operator's district selector out of position 10 into position 11. This circuit may be traced from battery through the magnet winding of switch 220, conductor 227, the lower right-hand contact of cam 219 (10), conductor 334, wiper 335 of the district selector DS, the inner left-hand armature and contact of relay 302, the upper right-hand and lower left-hand contacts of cam 364, conductor 362, wiper 361 of sender selector SS, conductor 715, the upper contact of cam 739 (9), conductor 743, and thence to ground at the lower left-hand contact of cam 1223 (15). Upon the advance of sequence switch 220 into position 11 a circuit is closed for sender stepping relay 1108 which may be traced from ground at the upper right-hand contact of cam 258, the lower contact of cam 258 (9 to 11), conductor 259, wiper 366, the right-hand armature and contact of relay 302, the upper contacts of cam 328 (8), wiper 343 of sender selector SS, conductor 344, conductor 702, the lower left-hand contact of cam 703 (9), conductor 741, resistance element 1111, the upper contact of cam 1224, conductor 1109, the winding of relay 1108, the winding of relay 1107, conductor 1203, the lower contact of cam 1202 (15), conductor 1228, and thence to battery through the winding of transfer relay 1132. Relay 1108 upon energizing in this circuit establishes a circuit for advancing control switch 1220 from position 15 into the talking selection position 16, which circuit may be traced from battery through the winding of switch 1220, the lower right-hand contact of cam 1210 (15), conductor 1032, the contact of class switch cam 1031 (8 to 17), conductor 1118, the lower right-hand contact of cam 1227 (15 to 16), conductor 1122, the armature and contact of sender stepping relay 1108, conductor 1226, and thence to ground at the upper contact of cam 1225.

With the district sequence switch 220 in position 11 and the sender control switch 1220 in position 16, a fundamental circuit is established which may be traced from battery through the right-hand winding of relay 222, the lower left-hand contact of cam 228 (11), the left-hand contact of cam 225 (10 to 15), the outer left-hand armature and contact of relay 274, conductor 333, wiper 332, the outer left-hand armature and contact of relay 302, the left-hand contacts of cam 321 (7 to 8), conductor 358, wiper 357, conductor 706, the lower contact of cam 705 (3 to 9), conductor 723, the armature and back contact of relay 1105, conductor 1106, the upper contact of cam 1202 (16 to 14), 130

conductor 1203, windings of overflow relay 1107 and sender stepping relay 1108, conductor 1109, the upper contact of cam 1224 (15 to 16), resistance element 1111, conductor 1156, and thence to ground at the upper right-hand contact of cam 1223 (16). Since the class switch 1020 was set in position 12 for a non-loaded connection into the local area, a circuit is now established for the 5 No. 0 counting relay 1127 which may be traced from ground at the upper contact of cam 1225 (15 to 16), conductor 1226, the armature contact of stepping relay 1108, conductor 1122, the lower right-hand contact of cam 1227 (15 to 16), conductor 1118, the upper contact of cam 1213 (2 to 18), the lower right-hand contact of cam 1207 (16), conductor 1229, the inner left-hand armature and back contact of relay 1157, 10 conductor 1158, the left-hand contact of cam 1033 (12), conductor 1034, the left-hand armature and back contact of relay 1132, and thence to battery through the winding of the No. 0 counting relay 1127. 15 Upon the energization of district control relay 222 in the fundamental circuit, a circuit is established for advancing sequence switch 220 out of position 11 which may be traced from battery through the magnet winding of switch 220, the left-hand contacts of cam 229, and thence to ground at the inner left-hand armature and front contact of relay 222, and switch 220 will continue to advance toward position 15 so 20 long as relay 222 is maintained energized over the fundamental circuit. As sequence switch 220 passes through position 11½ a shunt circuit is established around the winding of sender stepping relay 1108 which 25 may be traced from ground through the lower right-hand contact of cam 225 (11½), the lower right-hand contact of cam 228 (11 to 15), and thence to battery through the right-hand armature, front contact and right-hand winding of relay 222. Relay 222 is maintained energized over this shunt circuit and sender stepping relay 1108 deenergizes. Upon the deenergization of relay 1108 the No. 0' counting 30 relay 1105 becomes energized in the locking circuit of relay 1127, which locking circuit may be traced from battery through the winding of relay 1127, the winding of relay 1105, the armature contact of relay 1127, conductor 1159, and thence to ground at the upper right-hand contact of cam 1209 (16). Upon the energization of counting relay 1105 the previously traced fundamental circuit is opened and control relay 222 of the 35 district selector becomes deenergized opening the driving circuit of sequence switch 220 to arrest the sequence switch in position 12, which position is the proper position for controlling the windings of repeating coil 40 214 for non-loaded talking over the selected

trunk circuit 1302, 1303 to an office in the local area.

Restoration of the semi-mechanical suburban sender.

As soon as sequence switch 220 leaves position 10½ the circuit of lamp 210 is opened at the right-hand contact of cam 211, and since at this time lamp 208 is illuminated over the left-hand contact of cam 209, the operator is apprised of the fact that selection has been completed by the suburban sender. When switch 220 leaves position 11, the circuit previously traced for holding relays 301 and 302 of the sender selector circuit energized, is opened at the upper right-hand contact of cam 267, but relays 301 and 302 are maintained energized over a branch of this holding circuit extending through the right-hand contacts of cam 262 (11 to 16), the outer left-hand armature and front contact of relay 222 and the upper contact of cam 243 (10 to 16) until talking selection has been completed and relay 222 becomes deenergized. Upon the opening of this holding circuit and the release of relays 301 and 302, a circuit is established for advancing the sequence switch 320 into position 9 which may be traced from battery through the magnet winding of switch 320, the upper right-hand contact of cam 310 (2 to 8), and thence to ground at the inner left-hand armature and back contact of relay 301. Position 9 of switch 320 is a sub-normal position in which the switch stands until the 45 sender selector circuit is allotted for use by the allotter 339.

Following the advance of sequence switch 320 out of position 8 the holding circuit of relay 700, which was previously traced from battery through the left-hand winding and left-hand armature contact of relay 700 over conductor 325, wiper 324, conductor 326, and to ground at the lower right-hand contact of cam 308 (2¾ to 8½), is opened at cam 308. The shunt around the right-hand winding of relay 700 is now removed and both windings of relay 700, which are differentially wound, become energized over a circuit which may be traced from battery through the left-hand winding and left-hand armature contact of relay 700, the right-hand winding of relay 700, and thence to ground at the lower left-hand contact of cam 701, and relay 700 immediately releases due to the differential action of its two windings. Until the sender has been completely restored to normal position, busy ground potential is maintained on conductor 325 through the right-hand winding of relay 700 and the lower left-hand contact of cam 701 (2 to 18).

During the registration of the line designation upon the registers of the sender, lamp 744 was maintained dimly lighted over a

- circuit extending from battery through the lamp, the outer right-hand armature and front contact of relay 700, resistance element 745, and to ground at the right-hand 5 contact of cam 701 (5 to 8). Upon the completion of the registration and during the functioning of the sender to control the establishment of the desired connection or the transmission of the line designation to the 10 local sender, lamp 744 was flashed over a circuit extending through the lamp, the outer right-hand armature and front contact of relay 700, the upper contacts of cam 719 and to ground through interrupter 746. 15 During the release of the sender following the deenergization of relay 700, lamp 744 is brightly lighted over a circuit extending through the lamp, the outer right-hand armature and back contact of relay 700, and 20 to ground at the upper right-hand contact of cam 709 (2 to 18).
- Relay 700 upon deenergizing closes a circuit for advancing sequence switch 720 out of position 9 into position 18 which may 25 be traced from battery through the magnet winding of switch 720, the left-hand contact of cam 704 (2 to 17), and thence to ground at the inner right-hand armature and back contact of relay 700. When switch 720 30 leaves position 9 the locking circuits previously traced for the energized register relays of Fig. 6 are opened at the right-hand contacts of cam 733 (13/4 to 9), and the upper left-hand contact of cam 725 (13/4 to 9), 35 and ground is removed from the locking conductor 804 extending through the locking circuits of the route register relays of Fig. 8 at the upper left-hand contact of cam 709 (13/4 to 9), but the route register relays 40 do not unlock at this time since ground potential is also maintained on the locking conductor 804 through the upper contact of cam 812 (2 to 9) until the route switch 820 is restored to normal position. 45 Upon reaching position 10 circuits are established by sequence switch 720 for advancing the route switch 820, the class switch 1020, the sender switch 1120, and the sender control switch 1220 from positions in which 50 they are standing into normal position. A circuit for advancing route switch 820 may be traced from battery through the magnet winding of switch 820, the upper right-hand contact of cam 815 (2 to 9), conductor 849, 55 and thence to ground through the upper left-hand contact of cam 733 (10 to 2). Switch 820 upon reaching normal position (10 or 1) disconnects ground from locking conductor 804, whereupon the route register relays 60 disconnect ground from the upper right-hand contact of cam 733 (10 to 2). Switch 820 upon reaching normal position (10 or 1) disconnects ground from locking conductor 804, whereupon the route register relays 65 energize. The circuit for restoring class switch 1020 may be traced from battery through the magnet winding of switch 1020, the lower left-hand contact of cam 1034 (2 to 18), conductor 1035, and thence to ground at 70 the lower left-hand contact of cam 733 (10 to 2).
- A circuit for restoring the sender sequence switch 1120 may be traced from battery through the magnet winding of switch 1120, the lower left-hand contact of cam 1103 (2 to 18), conductor 1160, and thence to ground through the lower right-hand contact of cam 725 (10 to 2). Control switch 1220 is restored over a circuit which may be traced from battery through the magnet winding of switch 1220, the lower right-hand contact of cam 1211 (8 to 18), conductor 1230, and thence to ground at the upper right-hand contact of cam 725 (10 to 2). 75
- With these sequence switches in their normal positions a circuit is now established for advancing the register control sequence switch 720 from position 18 into normal position, which circuit may be traced from battery through the magnet winding of switch 720, the lower contact of cam 704 (18), conductor 721, the lower contacts of cam 1200, conductor 1201, the lower contacts of cam 1100, conductor 1101, the upper contacts of cam 1000, conductor 1001, and thence to ground at the lower left-hand contact of cam 812 (10). Upon the advance of switch 720 into position 1 ground potential is removed from conductor 325 at the lower contact of cam 701, and since now all operated apparatus of the sender has been restored to normal position, the sender is available for use in controlling the establishment of other connections. 80
- Upon the movement of district sequence switch 220 into position 12 with local sender district sequence switch 1320 in position 6, a circuit is closed extending through the windings of relays 1300 and polarized relay 263 which may be traced from battery through the winding of relay 1300, the lower contacts of cam 1301, conductor 1302, bank terminal 249 and brush 252 of district selector 250, the contact of cam 266 (12 to 15), the normally closed contacts associated with the upper armature of relay 226, the upper portion of the right-hand winding of repeating coil 214, the upper contact of cam 264, the winding of relay 263, the lower contact of cam 265, the lower portion of the right-hand winding of coil 214, the normally closed contacts associated with the lower armature of relay 226, the upper contact of cam 260 (12 to 15), brush 253 and bank terminal 251 of switch 250, trunk conductor 1303, conductor 1304 90 the upper contacts of cam 1305, and thence to ground at the upper right-hand contact of cam 1312 (2 to 15 1/2). The current flowing in this circuit energizes relay 1300 but is not in the proper direction to effectively energize the polarized relay 263. Relay 1300 upon energizing closes the previously traced circuit for again energizing relay 1306, which latter relay upon energizing 95 100

- 130

locks over the left-hand contact of cam 1329 (4 to 18), the outer right-hand armature of relay 1306, the left-hand contacts of cam 1305 to ground at the upper right-hand contact of cam 1312 (2 to 15½).

District brush selection at the local sender district.

- 19 Upon the movement of sequence switch 1320 into position 6 with relay 1308 of the district link and sender stepping relay 2203 of the local sender energized over the fundamental circuit previously traced, a circuit 20 is established for the updrive magnet 1342 of the district selector which may be traced from battery through the winding of magnet 1342, the upper right-hand contact of cam 1345 (6), conductor 1309, and thence to ground at the right-hand armature and front contact of relay 1308. Magnet 1342 upon energizing presses the depending portion of switch shaft 1343 against the constantly rotating updrive roller 1344, thereby causing the movement of the switch shaft 25 upwardly in its brush selection movement. As the switch shaft approaches its first brush selection position, the shaft wiper 1346 engages a conducting portion of the 30 brush selection commutator segment 1349, whereupon a circuit is established in shunt of the winding of the sender stepping relay 2203 which may be traced from battery through the left-hand winding of relay 1308, the inner left-hand armature and front contact of this relay, conductor 1319, the lower contacts of cam 1341, the upper left-hand contact of cam 1335 (5½ to 6), conductor 1355, the segment 1349, wiper 1346, 35 and thence to ground at the right-hand contact of cam 1384 (11 to 9). Relay 1308 is maintained energized in this circuit and sender stepping relay 2203 being shunted, deenergizes. As the switch shaft continues 40 in its upward movement, the shaft wiper 1346 engages an insulating portion of segment 1349 and the previously traced shunt circuit is opened, whereupon sender stepping relay 2203 again energizes. In this 45 manner as the switch shaft continues in its upward movement, the sender stepping relay 2203 is intermittently energized and deenergized.
- At the local sender upon the initial energization of sender stepping relay 2203 in the fundamental circuit previously traced, it having been assumed that the district brush translator register relay 2119 was energized and locked, a circuit is established for the No. 2 50 counting relay 2222 which may be traced from battery through the winding of relay 2222, the armature and back contact of the No. 2 counting relay 2239, the lower contact of cam 2288 (2 to 5), the No. 2 lead 2237, the No. 2 lead 2118, Fig. 21, the inner right-hand ar-
- mature and front contact of register relay 2119, the right-hand armature and back contact of register relay 2120, conductor 2121, the upper left-hand contact of cam 2240 (2), conductor 2241, conductor 2208, 70 the right-hand contact of cam 2243 (1¾ to 2), the armature and front contact of sender stepping relay 2203, and thence to ground through the upper left-hand contact of cam 2242 (2). Upon the energization of the No. 2 counting relay 2222, it closes a locking circuit for itself extending through its own winding, the winding of the No. 2' counting relay 2239, the armature and front contact of relay 2222, and thence to ground at the lower left-hand contact of cam 2244 (2). Relay 2239 does not energize in this locking circuit until sender stepping relay 2203 deenergizes upon the engagement of shaft wiper 1346 with the first conducting portion 85 of segment 1349 associated with district selector 1350. When relay 2239 does energize it extends the No. 2 counting relay lead 2237 through its armature and front contact, the armature and back contact of the No. 1' counting relay 2234, through the winding of the No. 1' counting relay 2223 to battery. In response to the next energization of stepping relay 2203, the No. 1' counting relay energizes and closes a locking circuit for itself 90 extending through the No. 1' counting relay 2234, its own armature contact, and to ground at the upper left-hand contact of cam 2244 (2). In response to the next deenergization of relay 2203, the No. 1' counting relay 2234 energizes in the locking circuit of relay 2223 and extends the No. 2 lead 2237 through its armature and front contact, conductor 2226, the inner left-hand armature and back contact of relay 2227, conductor 105 2228, and thence to battery through the winding of the No. 0 counting relay 2224. In the manner previously described upon the next energization and deenergization of relay 2203 the No. 0 and No. 0' counting relays 110 2224 and 2225 energize.
- Upon the energization of the No. 0' counting relay 2225, relay 2239 energizes in parallel therewith and opens the fundamental circuit. The No. 0' counting relay 2225 upon 115 energizing at its armature and front contact closes a circuit extending over the lower right-hand and upper left-hand contacts of cam 2230 for advancing sequence switch 2220 out of position 2 into position 4. Upon 120 leaving position 2 the previously traced locking circuits for the counting relays are opened at the left-hand contacts of cam 2244 (2) and the counting relays thereupon deenergize.
- As soon following the opening of the fundamental circuit as the shaft wiper 1346 engages the next insulating portion of segment 1349, relay 1308 deenergizes opening 125 the circuit of the updrive magnet 1342 for 130

arresting the upward movement of the switch shaft, and at its right-hand armature and back contact closing a circuit extending over conductor 1321 and the left-hand contact of cam 1310 (6) for advancing sequence switch 1320 into position 7. The third set of brushes, which will be assumed to be the set of brushes 1357, 1358 and 1359 disclosed in Fig. 13, has now been selected for use.

With sequence switch 1320 in position 7 a circuit is now established for the trip magnet 1360 which extends from battery through the winding of magnet 1360, conductor 1362, the lower right-hand and upper left-hand contacts of cam 1305, and thence to ground at the upper right-hand contact of cam 1312 (2 to 15½). Magnet 1360 upon energizing in this circuit rotates the tripping spindle 1361 to position a tripping finger thereon in association with the selected set of brushes for tripping this set of brushes upon the next upward movement of the switch shaft 1343, all in the well-known manner.

With sequence switch 1320 in position 7 and the sender sequence switch 2220 in position 4, the previously traced fundamental circuit is established for controlling the group selection movement of the district selector 1350. Relays 1308 and 2203 energize in this circuit, relay 1308 closing a circuit at its right-hand armature and front contact for advancing sequence switch 1320 out of position 7 into position 8, and at its inner left-hand armature and front contact closing a locking circuit for maintaining itself locked to the fundamental circuit following the movement of sequence switch 1320 into position 8, this locking circuit extending through its left-hand winding and inner left-hand armature contact to the tip conductor 1336 of the fundamental circuit over the lower contacts of cam 1341.

45 District group selection.

With sequence switch 1320 in position 8 the circuit of the updrive magnet 1342 is again established through the right-hand armature and front contact of relay 1308 and the switch shaft 1343 is again driven upwardly. During the initial portion of this upward movement the selected set of brushes is tripped by the tripping finger on spindle 1361, and during the remainder of this movement the tripped set of brushes wipe over the terminals of its associated bank. As the switch shaft approaches its first group selection position, the shaft wiper 1348 engages a conducting portion of segment 1368, and a circuit is thereupon established in shunt of the winding of the sender stepping relay 2203 which may be traced from battery through the left-hand winding of relay 1308, the inner left-hand armature and front con-

tact of this relay, conductor 1319, the lower contacts of cam 1341, the lower right-hand contact of cam 1335 (7¾ to 8), conductor 1356, commutator segment 1368, wiper 1348, and thence to ground at the upper left-hand contact of cam 1334 (11 to 9). Relay 1308 is maintained energized over this shunt circuit but relay 2203 deenergizes. As the switch shaft continues in its upward movement the shaft wiper 1348 engages an insulating portion of segment 1368 and the previously traced shunt circuit is opened, whereupon relay 2203 again energizes. In this manner during the upward movement of the switch shaft the sender stepping relay 2203 is intermittently energized and deenergized.

At the local sender upon the initial energization of relay 2203 with the sequence switch 2220 in position 4 and district group register relays 2128 and 2129 energized as assumed, a circuit is established for the No. 4 counting relay 2217 which may be traced from battery through the winding of relay 2217, the armature and back contact of the No. 4' counting relay 2219, the left-hand contacts of cam 2218, the No. 4 lead 2245, the No. 4 lead 2125, Fig. 21, the outer left-hand armature and front contact of register relay 2128, the outer left-hand armature and back contact of relay 2127, the right-hand armature and front contact of register relay 2129, conductor 2130, the upper right-hand contact of cam 2240 (4), conductor 2241, conductor 2208, the left-hand contact of cam 2243 (3 to 4), the armature and front contact of sender stepping relay 2203, and thence to ground through the upper right-hand contact of cam 2242 (4). In the manner previously described counting relay 2217 energizes and locks in series with the No. 4' counting relay 2219, which latter relay energizes upon the first deenergization of sender stepping relay 2203. In response to successive energizations and deenergizations of sender stepping relay 2203, the counting relays energize and lock up in succession until the No. 0' counting relay 2225 energizes in parallel with relay 2229. Upon the energization of the No. 0' counting relay 2225, a circuit is established for advancing sender sequence switch 2220 out of position 4 into position 5 which may be traced from battery through the magnet winding of switch 2220, the upper contacts of cam 2230 (4), conductor 2306, the armature and back contact of compensating resistance relay 2304, if at this time the compensating resistance switch 2350 has assumed its designated setting, conductor 2246, and thence to ground at the armature contact of relay 2225. Upon the movement of sequence switch 2220 out of position 4, the locking circuits of the energized counting relays are opened at the left-hand contacts of cam 2244 (4).

Upon the energization of relay 2229 the 130

previously traced fundamental circuit is opened, and as soon as the shaft wiper 1348 engages the next insulating portion of group selection segment 1368, relay 1308 deenergizes. Upon deenergizing relay 1308 opens the previously traced circuit for the updrive magnet 1342 to arrest the upward movement of the switch shaft, and at the back contact of its right-hand armature establishes the previously traced circuit for advancing sequence switch 1320 out of position 8 into position 9. The selected set of brushes have now been positioned upon the first set of bank terminals in the selected fifth group. Upon the advance of switch 1320 into position 9 a local circuit is established for relay 1308 which may be traced from battery through its right-hand winding and to ground through the right-hand contacts of cam 1312, whereupon the previously traced circuit is established at its right-hand armature and front contact for advancing sequence switch 1320 into position 10.

25 *District selector trunk hunting.*

If upon the movement of sequence switch 1320 into position 10 the first set of bank terminals of the selected group upon which the brushes 1357, 1358 and 1359 are resting are connected to an idle trunk circuit, relay 1308 immediately deenergizes advancing sequence switch 1320 out of position 10 into position 12. If, however, the first trunk in the group is busy relay 1308 is maintained locked after sequence switch 1320 leaves position 9 over a circuit extending from battery through its left-hand winding, its inner left-hand armature and front contact, its outer left-hand armature and front contact, the upper right-hand and lower left-hand contacts of cam 1332 (9 to 10), test brush 1359, and to ground on the test terminal of the bank upon which the brush 1359 is then resting. With relay 1308 energized when sequence switch 1320 reaches position 10, the previously traced circuit for the updrive magnet 1342 is again established and the switch shaft is driven upwardly in a trunk hunting movement until the brush 1359 engages the test terminal of an idle trunk, when the locking circuit of relay 1308 is no longer established and relay 1308 deenergizes opening the circuit of the updrive magnet 1342 and closing the previously traced circuit for advancing sequence switch 1320 into position 12. Until the brushes are properly centered upon the bank terminals of the idle trunk, relay 1308 is maintained locked through its right-hand winding, the upper right-hand contact of cam 1307 (10), conductor 1376, centering segment 1354, shaft wiper 1351, the left-hand contact of cam 1316 (10), conductor 1309, and thence to ground at the right-

hand armature and front contact of relay 1308.

Upon the deenergization of relay 1308, busy ground potential is connected to the test terminal 1365 of the selected trunk 1403, 1404 over test brush 1359, shaft wiper 1352, 70 commutator segment 1353, conductor 1367, the upper right-hand and lower left-hand contacts of cam 1341, the inner left-hand armature and back contact of relay 1308, and thence to ground through the upper 75 left-hand contact of cam 1334 (9½ to 11), to insure that the selected trunk shall be maintained busy to other district selectors having access thereto until sequence switch 1320 reaches position 12. When the sequence switch 1320 reaches position 12, busy ground potential is applied to terminal 1365 over conductor 1367 and the upper contacts of cam 1341, this busy potential being maintained until sequence switch 1320 leaves position 16½. 85

Skip office.

At the local sender when sender sequence switch 2220 reaches position 5, a circuit is 90 established for advancing sender control sequence switch 1720 out of position 9 into position 10, which circuit may be traced from battery through the magnet winding of switch 1720, the upper right-hand contact of cam 1711 (9), conductor 2248, and thence to ground through the lower contacts of cam 2247 (5). Since it has been assumed that the tandem manual office trunk 1403, 1404 is accessible directly from the terminal 95 bank of district switch 1350, and skip office register relay 2117 was energized, a circuit is now established for locking the No. 0' counting relay in its energized condition 100 until sequence switch 2220 passes through position 5. This circuit may be traced from battery through the winding of the No. 0 counting relay 2224, the No. 0' counting relay 2225, the armature and front contact of the No. 0 counting relay 2224, conductor 110 2211, conductor 2212, the right-hand contacts of cam 1712 (9 to 13), conductor 2250, the lower contacts of cam 2249, conductor 2149, and thence to ground at the right-hand armature and contact of skip office 115 translator register relay 2117.

When switch 2220 reaches position 5 with relay 2225 energized, a circuit is established for advancing control switch 1720 into position 14, which circuit may be traced through the magnet winding of switch 1720, the lower left-hand contact of cam 1731 (10 to 11, 13), conductor 2231, the lower contacts of cam 2230 to ground at the armature contact of relay 2225. A circuit is also closed 120 for advancing sender sequence switch 2220 into position 6 during the movement of control switch 1720 from position 13¾ to position 125

tion 14 which may be traced from ground at the upper contact of cam 1737 (13 $\frac{3}{4}$ to 14), conductor 2267, the right-hand contact of class switch cam 2328 (7 to 9), the inner 5 right-hand armature and back contact of relay 2305, conductor 2329, the lower right-hand contact of cam 2235 (5), conductor 2233, through the magnet winding of sequence switch 2220 to battery.

10 *Interoffice trunk test.*

With sender sequence switch 2220 in position 6 and sender control switch 1720 in position 14, the circuits of the sender are 15 conditional for testing the operative condition of the interoffice trunk 1403, 1404. A circuit may now be traced extending from the office sender to the selected trunk circuit at the manual tandem office, extending 20 from battery through the right-hand winding of relay 1400, the normally closed contacts associated with the right-hand armature of relay 1401, trunk conductor 1402, trunk conductor 1403, bank terminal 1363 and 25 brush 1357 of selector switch 1350, the lower contact of cam 1366 (12), conductor 1336, wiper 1337, conductor 1338, the upper contacts of cam 1734 (9 to 17), the armature and back contact of relay 2229, the winding 30 of polarized overflow relay 2202, conductor 2251, the winding of trunk test relay 2307, the upper contact of class switch cam 2308 (3 to 9), conductor 2309, the lower contact of cam 2252 (6), conductor 2312, compensating resistance 2310, the lower right-hand contact of cam 2311 (4), conductor 1703, wiper 1330, conductor 1331, the lower contact of cam 1367, brush 1358 and bank terminal 1364 of switch 1350, trunk conductors 35 40 45 1404 and 1405, the normally closed contacts associated with the left-hand armature of relay 1401, and thence to ground through the left-hand winding of relay 1400. If the trunk is in normal condition, that is, has no open conductors, the test relay 2307 energizes in this circuit and at its armature contact establishes a circuit for relay 2313.

As sender sequence switch 2220 passes through positions 3 to 6, a circuit is established 50 for advancing the relay call indicator impulser 2420 into position 8 preparatory to transmitting tandem code impulses. This circuit may be traced from battery through the magnet winding of switch 2420, 55 the upper right-hand contact of cam 2402 (1 to 2), conductor 2403, the upper contact of class switch cam 2316 (9), conductor 2317, the outer right-hand armature and back contact of relay 2305, conductor 2318, 60 and thence to ground at the upper right-hand contact of cam 2353 (3 to 6).

Relay 2313 upon energizing also establishes 65 a circuit for the tandem relay 2400 which may be traced from battery through the winding of relay 2400, conductor 2401, the

lower contact of class switch cam 2315, conductor 2316, and thence to ground at the left-hand contact of cam 2253 (5 $\frac{3}{4}$ to 6). Relay 2400 upon energizing closes 70 a locking circuit for itself extending through its inner left-hand armature and contact, the lower contact of cam 2404 (8 to 2), conductor 2405, conductor 1907, and thence to ground at the lower left-hand contact of cam 1737 (2 to 75 17). This locking circuit over cam 2404 is maintained until after switch 2420 has completed the last half of its first revolution or until the tandem code impulses have all been transmitted. Relay 2400 also closes a circuit 80 for relay 2406 which may be traced from battery through the winding of relay 2406, the inner right-hand armature and contact of relay 2400, and thence to ground on conductor 2405. Relay 2406 upon energizing 85 closes a locking circuit for itself over the upper contact of cam 2404 to ground on conductor 2405. Thus, through the energization of relay 2400 and the closure of the upper contact of cam 2404 through position 90 9, relay 2406 is maintained energized until switch 2420 has completed the first half of its second revolution, as hereinafter described.

Relay 2313 upon energizing also establishes 95 a circuit for advancing the sender sequence switch 2220 into position 7, which circuit may be traced from battery through the magnet winding of switch 220, the lower contacts of cam 2254 (6), conductor 2255, 100 the outer left-hand armature and front contact of relay 2313, conductor 2322, the lower contact of cam 2323 (9), the lower left-hand and upper right-hand contacts of cam 2407 (8 to 9), conductor 2403, the upper contact 105 of class switch cam 2316 (9), conductor 2317, the outer right-hand armature and back contact of relay 2305, conductor 2318, and thence to ground through the upper right-hand contact of cam 2253 (3 to 6). 110

Trunk assignment by the tandem manual operator.

At the tandem office upon the energization 115 of relay 1400 in the circuit previously traced, a circuit is established for relay 1408 which may be traced from battery through the inner left-hand armature and back contact of relay 1409, the winding of relay 1408, the inner left-hand armature and back 120 contact of relay 1426, conductor 1406, and thence to ground at the armature contact of relay 1400. Relay 1408 upon energizing closes a locking circuit for itself extending from battery through its inner right-hand armature and contact for maintaining itself 125 energized independently of battery current supplied through the armature contact of relay 1409, and at its right-hand armature and front contact establishes a circuit for 130

the assignment lamp 1410, which lamp is brilliantly lighted. The operator at the tandem office noting the illumination of lamp 1410 depresses the assignment key 1411 associated with the trunk circuit corresponding to the illuminated lamp 1410, whereupon a circuit is established for the assignment relay 1412 which may be traced from battery through the winding of relay 1500, conductor 1501, the right-hand winding of relay 1412, conductor 1413, the left-hand armature and front contact of relay 1408, the right-hand contact of key 1411, conductor 1414, the armature and back contact of relay 1502, and thence to ground through the outer left-hand armature and back contact of relay 1503.

Relay 1412 upon energizing in this circuit closes a locking circuit for itself extending from battery on conductor 1501 through both of its windings, its inner left-hand armature and contact, conductor 1415, and thence to ground at the inner right-hand armature and back contact of sleeve relay 1416. Relay 1412 also closes a circuit for relay 1409 which may be traced from battery through the outer left-hand armature and back contact of sleeve relay 1416, conductor 1418, the winding of relay 1409, and thence to ground at the outer left-hand armature and contact of relay 1412. Relay 1409 upon energizing opens the initial energizing circuit of relay 1408 and establishes a circuit for relay 1419 which may be traced from battery through the inner right-hand armature and contact of relay 1408, the outer left-hand armature and front contact of relay 1409, and thence to ground through the winding of relay 1419, and at the front contact of its right-hand armature prepares a flashing circuit for assignment lamp 1410. With relays 1412 and 1419 now energized, a circuit is established for the lamp indicator connecting relay 1421 which may be traced from battery through the left-hand armature and front contact of relay 1419, conductor 1420, the winding of relay 1421, conductor 1422, the right-hand armature and contact of relay 1412, conductor 1423, the winding of relay 1502, and thence to ground at the inner armature and back contact of relay 1503. Relays 1502 and 1421 energize in this circuit, relay 1421 disconnecting the windings of trunk relay 1400 from trunk conductors 1403 and 1404 and extending these conductors over conductors 1423 and 1424 to the windings of control relays 1504, 1505 and 1506 of the call indicator.

Upon the deenergization of relay 1400 following the energization of relay 1421, the locking circuit of relay 1408 is opened and relay 1408 thereupon deenergizes opening the previously traced circuit for lamp 1410 and connecting the lamp 1410 in a circuit extending through the right-hand armature

and front contact of relay 1409 to ground through interrupter 1425 for flashing the lamp 1410 until the line designation has been transferred from the local sender to the lamps of the call indicator. Upon the deenergization of relay 1408, the initial energizing circuit of relay 1419 is opened at the inner right-hand armature and front contact of relay 1408, and relay 1419 is now maintained energized in a locking circuit extending through its winding, its right-hand armature and front contact, and to battery through the winding of relay 1426. Relay 1426 upon energizing in this locking circuit opens the initial energizing circuit of relay 1408 and prepares a locking circuit for itself which is effective upon the reenergization of relay 1400, as will hereinafter be described.

At the local sender upon the opening of the fundamental circuit by the operation of the indicator connecting relay 1421, relays 2307 and 2313 deenergize. A circuit is now effective for advancing the relay call indicator impulser 2420 out of position 8 and through a revolution and a half for transmitting code impulses corresponding to the complete designation of the desired line. This circuit may be traced from battery through the magnet winding of switch 2420, the lower contact of cam 2402 (8 to 9), the outer right-hand armature and front contact of relay 2406, conductor 2412, the right-hand contact of class switch cam 2321 (9), conductor 2324, the lower contacts of cam 2258 (7), conductor 2259, the outer left-hand armature and back contact of relay 2313, conductor 2322, and thence to ground at the lower contact of cam 2253. During the rotation of impulser switch 2420 codes of impulses are transmitted over a circuit which may be traced from ring conductor 2408 at the relay call impulser circuit through the outer left-hand armature and front contact of relay 2406, conductor 2409, the upper contacts of cam 2256, the outer right-hand armature and back contact of relay 2313, conductor 2257, the upper right-hand contact of cam 2252 (6 to 17), conductor 2312, compensating resistance element 2310, the lower right-hand contact of cam 2311 (4), conductor 1703, thence as previously traced to conductor 1404, conductor 1424, the windings of control relays 1506, 1505 and 1504, conductor 1423, trunk conductor 1403, thence as previously traced to conductor 1338, the upper contacts of cam 1734 (9 to 17), the armature and back contact of relay 2229, the upper contacts of cam 2249, conductor 2319, the inner left-hand armature and back contact of relay 2313, conductor 2411, the inner left-hand armature and front contact of relay 2406, and thence to the tip conductor 2410 of the relay call indicator impulser circuit, Fig. 24. 130

Relay 1504 included in the above traced circuit is marginal and responds only to strong impulses of current. Relays 1505 and 1506 are both sensitive, relay 1505 responding only to negative impulses and 1506 only to positive impulses.

Transmission of tandem hundreds digit to relay call indicator.

10 As has been assumed, the office or tandem designation of the desired line C H E has been transferred to the A and B code registers and the tandem units register relays of the local sender. With the previously traced fundamental circuit established between the relay call indicator impulser 2420, Fig. 24, and the relay call indicator, Figs. 15 and 16, tandem code impulses are transmitted during the rotation of the impulser switch 2420 from position 8 into position 1 during the second half of its first revolution.

As switch 2420 rotates from position 8½ into position 12½, a code of impulses comprising a strong negative and a weak negative impulse is transmitted to represent the letter C, or its numerical equivalent numeral 2. For the purpose of this description the code impulses will be described by reference to the pole of battery which is connected to the tip and ring conductors 2410 and 2408 of the fundamental circuit at the impulser shown in Fig. 24. The tandem hundreds code is transmitted under the control of the A code register, Fig. 20, this register being in position 2, as previously described.

As switch 2420 rotates from position 8¾ to position 9½, positive battery potential is connected to the ring conductor 2408 over the right-hand contact of cam 2413, but as the tip conductor 2410 is open at this time no impulse over the fundamental circuit results. As switch 2420 rotates from position 9¾ to position 10½, the ring conductor 2408 is connected to the negative pole of battery over the lower contact of cam 2414 through the high resistance element 2419 and the low resistance element 2418, and the tip conductor 2410 is connected to the positive pole of battery through the left-hand contact of cam 2413. The high resistance element 2419 is shunted at this time, however, by a circuit which may be traced from one terminal of element 2419 over conductor 2427, the upper contact of cam 2238 (6 to 7), the No. 2 lead 2237, the No. 2 lead 2076, Fig. 20, terminal 2097 of bank A⁵ of register A, wiper 2085, conductor 2086, the upper contact of cam 2421 (8½ to 11½), the lower contact of cam 2429 (9¾ to 10½), the outer right-hand armature and front contact of relay 2400, and thence to the other terminal of resistance element 2419. The resulting impulse of negative current transmitted

over the fundamental circuit is, therefore, a strong impulse. During the rotation of switch 2420 from position 10¾ to position 11½, the ring conductor 2408 is connected to the positive pole of battery through the right-hand contact of cam 2413, but as the tip conductor 2410 is open at this time no impulse is transmitted. As switch 2420 rotates from position 11¾ to position 12½, the ring conductor 2408 is connected over the lower contact of cam 2414 and through resistance elements 2419 and 2418 to the negative pole of battery, and the tip conductor 2410 is connected to the positive pole of battery through the left-hand contact of cam 2413. As no shunt exists at this time around the high resistance element 2419, this high resistance is included in the fundamental circuit and the resulting impulse of negative current is, therefore, weak.

At the relay call indicator, Figs. 15 and 16, in response to the first impulse of current over the fundamental circuit, which as previously described is a strong negative impulse, the negatively polarized relay 1505 and the marginal relay 1504 respond. Relay 1505 upon energizing closes a circuit extending from ground through the outer right-hand armature and back contact of relay 1542, the outer right-hand armature and front contact of relay 1500, conductor 1527, conductor 1543, conductor 1544, the armature and contact of relay 1505, the left-hand armature and back contact of relay 1507, the winding of relay 1508, and thence to battery through the low resistance left-hand winding of relay 1507. Relay 1508 energizes in this circuit but owing to the high resistance winding of relay 1508, relay 1507 does not receive sufficient current to become energized. Upon the energization of relay 1508 a circuit is established for relay 1509 which may be traced from battery through the winding of relay 1509, the right-hand armature and back contact of relay 1517, the intermediate armature and front contact of relay 1508, and thence to ground on conductor 1544. Relay 1509 energizes in this circuit and establishes a locking circuit for itself extending through its own winding, the winding of relay 1517, and to ground on conductor 1544 through the right-hand armature and contact of relay 1509, but relay 1517 does not energize in this locking circuit since at this time its winding is shunted by ground connected through the armature contact of relay 1508.

Marginal relay 1504 upon energizing closes a circuit for lamp relay 1526 which may be traced from ground through the armature and contact of relay 1504, the outer left-hand armature and back contact of relay 1507, the outer left-hand armature and back contact of relay 1517, conductor 1525, and thence to battery on conductor 130

- 1532 through the left-hand winding of relay 1526. Relay 1526 upon energizing locks in a circuit from battery through both of its windings, its inner right-hand armature contact, and to ground on conductor 1527.
- 5 Relay 1508 upon energizing also establishes a circuit which may be traced from ground on conductor 1544 through the innermost armature and contact of relay 1508, the right-hand high resistance winding of relay 1507, the winding of relay 1508, thence to battery through the left-hand winding of relay 1507, but this circuit is ineffective to energize relay 1507 since the right-hand winding of relay 1507 is shunted by a connection to ground through the armature contact of relay 1505. Upon the deenergization of relay 1505 following the completion of the first negative impulse, the shunt 10 around the winding of relay 1507 is removed at the contact of relay 1505 and relay 1507 thereupon energizes. Upon the energization of relay 1507 a new shunt is established around the winding of relay 1517 extending 15 through its inner right-hand armature and front contact.

- The next impulse which is transmitted being a weak negative impulse, only the negatively polarized relay 1505 responds, closing a circuit from ground on conductor 1544, the armature and contact of relay 1505, the left-hand armature and front contact of relay 1507 to one terminal of the winding of relay 1508, and since the other terminal of 20 this winding is at the time connected to ground at the right-hand winding of relay 1507 and the innermost armature and contact of relay 1508, relay 1508 is shunted down and deenergizes. Relay 1507 is now maintained energized through its low resistance 25 left-hand winding and its left-hand armature and front contact through the armature and contact of relay 1505, and deenergizes upon the cessation of the second negative impulse and the consequent deenergization of relay 1505. The tandem hundreds code has now been transmitted and in response thereto the lamp relay 1526 has been energized and locked.
- 30 50 *Transmission of tandem tens digit to relay call indicator.*

During the rotation of impulser switch 2420 from position $12\frac{1}{2}$ to position $16\frac{1}{2}$, a code of impulses is transmitted in accordance with the setting of the B code register, Fig. 20. It having been assumed that the second office code letter is H having a numerical equivalent of 4, and that the code 35 register B has been set into position 4, a code comprising a weak negative, a positive and a second weak negative impulse is now transmitted. As the impulser switch rotates from position $12\frac{3}{4}$ to position $13\frac{1}{4}$, ring conductor 2408 of the fundamental cir-

cuit is connected to the positive pole of battery over the right-hand contact of cam 2413, but since the tip conductor 2410 is open at this time no impulse results. In rotating from position $13\frac{3}{4}$ to position $14\frac{1}{4}$, the ring conductor 2408 is connected through the lower contact of cam 2414 and resistance elements 2419 and 2418 to the negative pole of battery, and the tip conductor 2410 is connected to the positive pole of battery through the left-hand contact of cam 2413. Since both resistance elements 2418 and 2419 are included in the fundamental circuit, a weak negative impulse results. During the rotation of switch 2420 from position $14\frac{3}{4}$ to position $15\frac{1}{4}$, the ring conductor 2408 is connected to the positive pole of battery over the right-hand contact of cam 2413, and the tip conductor 2410 is connected over the contacts of cam 2416, conductor 2425, the upper contacts of cam 2218, the No. 4 lead 2245, the No. 4 lead 2087, Fig. 20, terminal 2088 of bank B^a of code register B, wiper 2089, conductor 2090, the lower contact of cam 2421 ($12\frac{1}{2}$ to $15\frac{1}{2}$), the upper contact of cam 2429 ($14\frac{3}{4}$ to $15\frac{1}{4}$), the outer left-hand armature and front contact of relay 2400, and thence to the negative pole of battery through the high resistance element 2417. A weak positive impulse is thus transmitted over the fundamental circuit. As switch 2420 rotates from position $15\frac{3}{4}$ to position $16\frac{1}{4}$, the ring conductor 2408 is connected to the negative pole of battery through the lower contact of cam 2414 and resistance elements 2419 and 2418, and the tip conductor 2410 is connected to the positive pole of battery through the left-hand contact of cam 2413, and a second weak negative impulse is consequently transmitted.

At the relay call indicator, Figs. 15 and 16, in response to the first weak negative impulse of current, the negatively polarized relay 1505 responds establishing a circuit for relay 1508 as previously traced, which in turn closes a circuit for relay 1510 which may be traced from battery through the winding of relay 1510, the right-hand armature and back contact of relay 1518, the right-hand armature and front contact of relay 1517, the intermediate armature and front contact of relay 1508, and thence to ground on conductor 1544. Relay 1510 upon energizing closes a locking circuit for itself extending through its winding, the winding of relay 1518, the inner right-hand armature and front contact of relay 1510, and thence to ground on conductor 1544. Relay 1518 does not energize in this circuit since its winding is shunted by ground connected through the armature and contact of relay 1508. Upon the cessation of the first negative impulse and the deenergization of relay 1505, relay 1507 becomes energized in the manner previously described. In response 100

to the next impulse which is of positive polarity, the positively polarized relay 1506 energizes establishing a circuit for lamp relay 1600 which may be traced from ground 5 on conductor 1544 through the armature and contact of relay 1506, the outer right-hand armature and front contact of relay 1508, the inner left-hand armature and front contact of relay 1510, the inner left-hand armature 10 and back contact of relay 1511, conductor 1528, the left-hand winding of relay 1600, and thence to battery on conductor 1601. Relay 1600 upon energizing locks to ground on conductor 1527 through both of its windings and its inner right-hand contact. In response to the last negative impulse, relay 1505 again energizes and through its left-hand armature contact closes a shunt around the winding of relay 1508 as previously traced. Relay 1508 thereupon de-energizes. Upon the cessation of the last negative impulse, relay 1507 deenergizes, and since at this time both relays 1507 and 1508 are deenergized, the shunt around the 25 winding of relay 1518 is open and relay 1518 energizes in the locking circuit of relay 1510. The tandem tens code impulses have now resulted in the energization of the tandem tens lamp relay 1600.

30 *Transmission of tandem units digit to relay call indicator.*

During the rotation of impulser 2420 from position $16\frac{1}{2}$ to position $20\frac{1}{2}$, a code of impulses is transmitted in accordance with the setting of the tandem units register relays 1902, 1903, 1904, 1927 and 1928. It having been assumed that the third office code letter was E having a numerical equivalent of 3, 35 and that register relays 1902, 1903 and 1904 are energized, a code comprising a positive, a strong negative and a weak negative impulse is transmitted for registering this code designation upon the lamp relays of the relay call indicator. As switch 2420 rotates from position $16\frac{3}{4}$ to position $17\frac{1}{4}$, the ring conductor 2408 of the fundamental circuit is connected to the positive pole of battery over the right-hand contact of cam 2413, and the tip conductor 2410 is connected over the upper contact of cam 2416, the lower contact of cam 2415 ($16\frac{3}{4}$ to 50 $17\frac{1}{4}$), conductor 2426, the upper contact of cam 2262, No. 3 lead 2263, No. 3 lead 1947, Fig. 19, the inner right-hand armature and front contact of relay 1903, the inner right-hand armature and front contact of relay 1904, the inner right-hand armature and back contact of relay 1927, conductor 1932, 55 the contact of cam 2422 ($16\frac{1}{2}$ to $19\frac{1}{2}$), the upper contact of cam 2429 ($16\frac{3}{4}$ to $17\frac{1}{4}$), the outer left-hand armature and front contact of relay 2400, and thence to the negative pole of battery through the high resistance element 2417. The resulting im-

pulse transmitted over the fundamental circuit is, therefore, weak and of a positive polarity.

As switch 2420 rotates from position $17\frac{3}{4}$ to position $18\frac{1}{4}$, the ring conductor 2408 is connected to the negative pole of battery over the lower contact of cam 2414 and through resistance elements 2419 and 2418, and the tip conductor 2410 is connected to the positive pole of battery through the left-hand contact of cam 2413. Since at this time register relays 1902, 1903 and 1904 are energized, a shunt exists around the high resistance element 2419 which may be traced from one terminal of this element through the upper contact of cam 2414 ($17\frac{3}{4}$ to $18\frac{1}{4}$), lead 2426, thence as previously traced through the contact of cam 2422, the lower contact of cam 2429 ($17\frac{3}{4}$ to $18\frac{1}{4}$), the outer right-hand armature and front contact of relay 2400, and to the other terminal of resistance element 2419. The resulting negative impulse transmitted over the fundamental circuit is, therefore, strong. During the rotation of switch 2420 from position $18\frac{3}{4}$ to position $19\frac{1}{4}$, the ring conductor 2408 is connected to the positive pole of battery through the right-hand contact of cam 2413, and the tip conductor 2410 being open at this time no impulse results. During the rotation of switch 2420 from position $19\frac{3}{4}$ to position $20\frac{1}{4}$, the ring conductor 2408 of the fundamental circuit is connected to the negative pole of battery over the lower contact of cam 2414 and through resistance elements 2419 and 2418, and the tip conductor 2410 is connected to the positive pole of battery through the left-hand contact of cam 2413. Since no shunt exists at this time around the high resistance element 2419, a weak negative impulse is transmitted over the fundamental circuit.

At the relay call indicator in response to the first positive impulse, the positively polarized relay 1506 energizes and establishes a circuit from ground on conductor 1544 through its armature and front contact, the outer right-hand armature and back contact of relay 1508, the left-hand armature and front contact of relay 1509, the outer left-hand armature and front contact of relay 1510, the outer left-hand armature and back contact of relay 1511, conductor 1529, and thence to battery on conductor 1601 through the left-hand winding of lamp relay 1602. Relay 1602 upon energizing locks to ground on conductor 1527 through both of its windings and inner right-hand armature contact. In response to the second impulse of strong negative current, the negatively polarized relay 1505 and marginal relay 1504 energize. Relay 1505 upon energizing closes the previously traced circuit for relay 1508, which upon energizing establishes a circuit for relay 1511 which may be traced from 130

- battery through the winding of relay 1511, the right-hand armature and back contact of relay 1519, the right-hand armatures and front contacts of relays 1518 and 1517, the intermediate armature and contact of relay 1508 to ground on conductor 1544. Relay 1511 upon energizing locks in a circuit extending through the winding of relay 1519, but relay 1519 being shunted at this time by a circuit extending through the armature and contact of relay 1508 does not energize in this locking circuit. Relay 1504 upon energizing establishes a circuit which may be traced from ground at the armature contact of this relay over the outer right-hand armature and back contact of relay 1507, the outer left-hand armature and front contacts of relays 1517 and 1518 and outer left-hand armature and back contact of relay 1519, conductor 1530, and thence to battery through the left-hand winding of lamp relay 1603. Relay 1603 upon energizing locks to ground on conductor 1527 through both of its windings and its inner right-hand armature and contact.

Upon the cessation of this impulse of current through the windings of relays 1504 and 1505, these relays deenergize whereupon relay 1507 energizes in the manner previously described. In response to the last weak negative impulse, relay 1505 again energizes and establishes a circuit from ground on conductor 1544 for shunting down relay 1508. Upon the cessation of this impulse and the deenergization of relay 1505, relay 1507 deenergizes. Relays 1507 and 1508 being both deenergized the shunt circuits around the winding of relay 1519 are opened and this relay energizes in the locking circuit of relay 1511 preparatory to controlling the registration of the stations digit.

Transmission of the stations designation to the relay call indicator.

- It has been assumed that the numerical designation of the desired line is 3916-R and that this designation has been registered upon the numerical and stations groups of register relays of the local sender. Therefore, as switch 2420 rotates from position 20½ to position 4½, a code of impulses representing the stations designation R is transmitted over the fundamental circuit under the control of the stations relays, stations relay 1905 being energized at this time. This code of impulses comprises a weak negative followed by a positive and a second weak negative impulse. As switch 2420 rotates from position 20¾ to position 1¼, the ring conductor 2408 of the fundamental circuit is connected to the positive pole of battery through the right-hand contact of cam 2413, and the tip conductor 2410 being at this time open no impulse results. As switch 2420 rotates from position 1¾ to position 2¼, the

ring conductor 2408 is connected to the negative pole of battery over the lower contact of cam 2414 and through resistance elements 2419 and 2418, and the tip conductor 2410 is connected to the positive pole of battery 70 through the left-hand contact of cam 2413. Since no shunt exists around the high resistance element 2419, the impulse of negative current transmitted over the fundamental circuit is of weak strength. During the 75 rotation of switch 2420 from position 2¾ to position 3¼, the ring conductor 2408 is connected to the positive pole of battery through the right-hand contact of cam 2413, and the tip conductor 2410 is connected to the negative pole of battery over the contacts of cam 2416, conductor 2425, upper contacts of cam 2218, the No. 4 lead 2245, the No. 4 lead 1933, Fig. 19, the left-hand armature and front contact of register relay 1905, conductor 2430, the contact of cam 2431 (20½ to 3½), conductor 2437, the contacts of cam 2260 (6 to 7), conductor 2261, the right-hand contact of cam 2423 (2¾ to 3¼) and thence to the negative pole of battery through resistance element 2417. The resulting impulse is, therefore, of weak positive polarity. As switch 2420 rotates from position 3¾ to position 4¼, the ring conductor 2408 is connected to the negative pole of battery 95 through the lower contact of cam 2414 and resistance elements 2419 and 2418, and the tip conductor 2410 is connected to the positive pole of battery through the left-hand contact of cam 2413. A weak negative impulse is, therefore, transmitted over the fundamental circuit.

At the relay call indicator, Figs. 15 and 16, in response to the first negative impulse, the negatively polarized relay 1505 responds 105 and in the manner previously described establishes a circuit for relay 1508, which in turn establishes a circuit for relay 1512 which may be traced from battery through the winding of relay 1512, the right-hand armature and back contact of relay 1520, the right-hand armatures and front contacts of relays 1519, 1518 and 1517 to ground on conductor 1544 through the intermediate armature and contact of relay 1508. Relay 1512 110 upon energizing locks up through the winding of relay 1520, but since the winding of relay 1520 is shunted at the armature and contact of relay 1508, relay 1520 does not energize at this time. Upon the cessation of 115 the first negative impulse, relay 1507 becomes energized in the manner previously described.

In response to the second impulse of positive polarity, the positively polarized relay 125 1506 energizes and establishes a circuit for the stations lamp relay 1534 which may be traced from ground upon conductor 1544, the armature contact of relay 1506, the outer armature and front contact of relay 1508, 130

the inner left-hand armatures and front contacts of relays 1510, 1511 and 1512, the inner left-hand armature and back contact of relay 1513, conductor 1531, and thence through 5 the left-hand winding of lamp relay 1534 to battery on conductor 1532. Relay 1534 upon energizing locks up over a circuit extending from battery through both of its windings, its right-hand armature and contact, conductor 1533, the inner armature and front contact of relay 1500, and to ground at the inner right-hand armature and back contact of relay 1542. In response to the last impulse of negative current, the negatively polarized relay 1505 again energizes 10 causing the deenergization of relay 1508 in the manner previously described. Upon the cessation of this impulse, relay 1507 deenergizes and since at this time both relays 1507 15 and 1508 are deenergized, the shunt around the winding of relay 1520 is opened and relay 1520 energizes in the locking circuit of relay 1512 preparatory to controlling the operation of the thousands lamp relays.

20 *Transmission of the thousands digit to the relay call indicator.*

During the rotation of switch 2420 from position 4½ to position 8½, a code of impulses is transmitted in accordance with the registration recorded upon the incoming brush register relays and the incoming group of register relays, Fig. 19. It having 30 been assumed that the thousands digit is 3 and that accordingly incoming brush register relay 1913 and incoming group register relay 1914 are energized, a code comprising a positive, a negative and a strong negative impulse is, therefore, transmitted for controlling the registration of the thousands digit upon the lamp relays of the relay call indicator. As switch 2420 rotates from position 4¾ to position 5¼, the ring conductor 2408 is connected to the positive pole of 35 battery through the right-hand contact of cam 2413, and the tip conductor 2410 is connected to the negative pole of battery over the upper contact of cam 2416, the upper contact of cam 2415 (4½ to 5½), conductor 40 2428, the upper contact of cam 2265, No. 1 lead 2266, No. 1 lead 1934, Fig. 19, the outer right-hand armature and front contact of relay 1913, the left-hand armature and back contact of relay 1948, the left-hand and 45 back contact of relay 1949, conductor 1935, the lower contact of cam 2432 (4½ to 7½), conductor 2437, the lower contacts of cam 2260, conductor 2261, the right-hand contact of cam 2423 (4¾ to 5¼), and thence to 50 battery through the high resistance winding 2417. Thus, a weak impulse of positive current is transmitted over the fundamental circuit. As switch 2420 rotates from position 5¾ to position 6¼, the ring conductor 2408 is connected to the negative pole of

battery through the lower contact of cam 2414 and resistance elements 2419 and 2418, and the tip conductor 2410 is connected to the positive pole of battery over the left-hand contact of cam 2413. Since the high resistance element 2419 is included in the fundamental circuit, the resulting impulse is, therefore, of weakened strength.

During the rotation of switch 2420 from position 6¾ to position 7¼, ring conductor 2408 is connected to the positive pole of battery through the right-hand contact of cam 2413, and since the tip conductor 2410 is open at this time no impulse is transmitted.

As switch 2420 rotates from position 7¾ to position 8½, the ring conductor 2408 is connected over the lower contact of cam 2414 to the negative pole of battery through resistance elements 2419 and 2418, and the tip conductor 2410 is connected to the positive pole of battery through the left-hand contact of cam 2413. Since incoming group relay 1914 is energized at this time high resistance element 2419 is shunted from the fundamental circuit by a shunt circuit which may be traced from one terminal of element 2419 over conductor 2436, conductors 1936 and 1937, the intermediate right-hand armature and contact of relay 1914, conductor 2435, the left-hand contact of cam 2434 (7 to 9), the upper right-hand contact of cam 2433 (7¾ to 11¾), the outer right-hand armature and back contact of relay 2400 to the other terminal of resistance element 2419. It is to be noted in this connection that relay 2400 deenergized following the completion of the transmission of the tandem units code, or as soon as impulser 2420 rotated beyond position 2. The negative impulse transmitted over the fundamental circuit at this time is of strong character in view of the fact that high resistance element 2419 is shunted from the fundamental circuit.

At the relay call indicator, in response to the first positive impulse, the positively polarized relay 1506 energizes and establishes a circuit for lamp relay 1604 which may be traced from ground on conductor 1544 through the armature contact of relay 1506, the outer armature and back contact of relay 1508, the outer left-hand armatures and contacts of relays 1509, 1510, 1511 and 1512, the outer left-hand armature and back contact of relay 1513, conductor 1535, the left-hand winding of lamp relay 1604, and thence to battery on conductor 1611. Relay 1604 upon energizing locks over both of its windings and its inner right-hand armature and contact to ground on conductor 1527. In response to the second impulse of negative current, the negatively polarized relay 1505 responds and in the manner previously described establishes a circuit for relay 1508, and relay 1508 in turn estab-

lishes a circuit for relay 1513 which may be traced from battery through the winding of relay 1513, the right-hand armature and back contact of relay 1521, the right-hand armatures and front contacts of relays 1520, 1519, 1518 and 1517, the intermediate armature and contact of relay 1508 to ground on conductor 1544. Relay 1513 thereupon establishes a locking circuit through its own winding, the winding of relay 1521, the right-hand armature and contact of relay 1513, and to ground on conductor 1544. Relay 1521 being shunted at this time through the armature and contact of relay 1508 does not energize in this locking circuit. Upon the cessation of this negative impulse, relay 1507 energizes in the manner previously described.

In response to the last impulse of strong negative current, the negatively polarized relay 1505 and marginal relay 1504 both energize, relay 1505 causing the deenergization of relay 1508 in the manner previously described, and marginal relay 1504 establishing a circuit for lamp relay 1605 which may be traced from ground at the armature contact of relay 1504, the outer right-hand armature and front contact of relay 1507, the inner left-hand armatures and front contacts of relays 1517, 1518, 1519 and 1520, the inner left-hand armature and back contact of relay 1521, conductor 1536, and thence to battery on conductor 1611 through the left-hand winding of relay 1605. Relay 1605 upon energizing locks through both of its windings and its inner right-hand armature contact to ground on conductor 1527. Upon the cessation of this last negative impulse relay 1507 deenergizes, and since at this time both relays 1507 and 1508 are deenergized, the shunt around the winding of relay 1521 is removed and this relay energizes in the locking circuit of relay 1513 preparatory to controlling the registration of the hundreds digit upon the lamp relays of the indicator.

Transmission of hundreds digit to the relay call indicator.

During the rotation of switch 2420 from position $8\frac{1}{2}$ to position $12\frac{1}{2}$, a code of impulses is transmitted in accordance with the setting of the final brush register relays and of the incoming group register relays, Fig. 19. It having been assumed that the hundreds digit of the desired number is 9, and that, therefore, the final brush register relay 1916 and the incoming group register relay 1915 are locked energized, a code comprising a negative, a positive and a strong negative impulse is transmitted for setting the hundreds lamp relays of the relay call indicator. As switch 2420 rotates from position $8\frac{3}{4}$ to position $9\frac{1}{4}$, the ring conductor 2408 is connected to the positive pole of

battery through the right-hand contact of cam 2413, but since at this time the tip conductor 2410 is open no impulse is transmitted. As switch 2420 rotates from position $9\frac{3}{4}$ to position $10\frac{1}{4}$, the ring conductor 2408 is connected to the negative pole of battery over the lower contact of cam 2414 and through resistance elements 2419 and 2418, and the tip conductor 2410 is connected to the positive pole of battery over the left-hand contact of cam 2413. Since high resistance element 2419 is included in the fundamental circuit at this time, the resulting impulse is weak and negative in polarity. During the rotation of switch 2420 from position $10\frac{3}{4}$ to position $11\frac{1}{4}$, the ring conductor 2408 is connected to the positive pole of battery through the right-hand contact of cam 2413, and the tip conductor 2410 is connected over the contacts of cam 2416, conductor 2425, the upper contacts of cam 2218, the No. 4 lead 2245, No. 4 lead 1939, Fig. 19, the left-hand armature and front contact of register relay 1916, conductor 1940, the upper contact of cam 2432 ($8\frac{1}{2}$ to $11\frac{1}{2}$), conductor 2437, the contacts of cam 2260, conductor 2261, the left-hand contact of cam 2423 ($10\frac{3}{4}$ to $11\frac{1}{4}$), the outer left-hand armature and back contact of relay 2400, and thence to the negative pole of battery through high resistance element 2417. The resulting impulse of current transmitted over the fundamental circuit is, therefore, weak and positive in polarity.

As switch 2420 rotates from position $11\frac{3}{4}$ to position $12\frac{1}{4}$, the ring conductor 2408 is connected to the negative pole of battery over the lower contact of cam 2414 and through resistance elements 2419 and 2418, and the tip conductor is connected to the positive pole of battery through the left-hand contact of cam 2413. Since at this time the incoming group register relay 1915 is energized, a shunt circuit is established around the high resistance element 2419 which may be traced over conductor 2436, conductors 1936 and 1937, the outer right-hand armature and contact of relay 1915, conductor 1941, the lower right-hand contact of cam 2434 (11 to 13), the upper left-hand contact of cam 2433 ($11\frac{3}{4}$ to $12\frac{1}{4}$), the outer right-hand armature and back contact of relay 2400, and thence to a point between resistance elements 2418 and 2419. Since resistance element 2419 is shunted from the fundamental circuit the negative impulse of current transmitted is strong.

At the relay call indicator in response to the first impulse of negative current, the negatively polarized relay 1505 energizes and establishes the previously traced circuit for energizing relay 1508, and relay 1508 upon energizing establishes a circuit for relay 1514 which may be traced from battery through the winding of relay 1514, the right-

hand armature and back contact of relay 1522, and thence through the right-hand armatures and front contacts of relays 1521, 1520, 1519, 1518 and 1517, and the intermediate armature and contact of relay 1508 to ground on conductor 1544. Relay 1514 upon energizing locks through the winding of relay 1522 and its own right-hand armature and contact to ground on conductor 1544, but relay 1522 does not energize at this time since its winding is shunted at the armature and contact of relay 1508. Upon the cessation of the first negative impulse, relay 1507 energizes in the manner previously described.

In response to the second positive impulse of current, the positively polarized relay 1506 responds and establishes a circuit for the hundreds lamp relay 1606 which may be traced from ground on conductor 1544 through the armature contact of relay 1506, the outer right-hand armature and front contact of relay 1508, the inner left-hand armatures and front contacts of relays 1510, 1511, 1512, 1513 and 1514, the inner left-hand armature and back contact of relay 1515, conductor 1537, the left-hand winding of relay 1606, and thence to battery on conductor 1611. Relay 1606 upon energizing in this circuit locks through both of its windings at its inner right-hand armature contact to ground on conductor 1527. In response to the last impulse of strong negative current, the negatively polarized relay 1505 and the marginal relay 1504 energize, relay 1505 shunting down relay 1508 as previously described, and relay 1504 establishing a circuit for lamp relay 1607 which may be traced from ground through the armature contact of relay 1504, the outer right-hand armature and front contact of relay 1507, the inner left-hand armatures and front contacts of relays 1517, 1518, 1519, 1520 and 1521, the inner left-hand armature and back contact of relay 1522, conductor 1538, and thence to battery through the left-hand winding of relay 1607. Relay 1607 upon energizing locks through both of its windings and its inner right-hand armature and front contact to ground on conductor 1527. Upon the cessation of this last negative impulse relay 1507 deenergizes, and since at this time both relays 1507 and 1508 are deenergized, the shunting circuits around the winding of relay 1522 open and this relay energizes in the locking circuit of relay 1514.

Transmission of tens digit to the relay call indicator.

During the rotation of switch 2420 from position $12\frac{1}{2}$ to position $16\frac{1}{2}$, a code of impulses is transmitted in accordance with the setting of the tens register relays of

Fig. 19. It having been assumed that the tens digit of the desired number is one and that register relay 1917 is energized at this time, a code comprising a positive and two negative impulses is transmitted over the fundamental circuit to register the tens digit one on the tens lamp relays of the indicator. As switch 2420 rotates from position $12\frac{3}{4}$ through position $13\frac{1}{4}$, the ring conductor 2408 is connected to the positive pole of battery through the right-hand contact of cam 2413, and the tip conductor 2410 is connected to the negative pole of battery over the upper contact of cam 2416, the upper contact of cam 2415 ($12\frac{1}{2}$ to $13\frac{1}{2}$), conductor 2428, the upper contact of cam 2265 (6 to 7), the No. 1 lead 2266, the No. 1 lead 1942, Fig. 19, the outer right-hand armature and front contact of relay 1917, the left-hand armature and back contact of relay 1950, the left-hand armature and back contact of relay 1951, conductor 1943, the lower contact of cam 2438 ($12\frac{1}{2}$ to $15\frac{1}{2}$), conductor 2437, contacts of cam 2260, conductor 2261, the left-hand contact of cam 2423 ($12\frac{3}{4}$ to $13\frac{1}{4}$), the outer left-hand armature and back contact of relay 2400, and to battery through high resistance element 2417. A weak impulse of positive polarity is thus transmitted over the fundamental circuit. As switch 2420 rotates from position $13\frac{3}{4}$ to position $14\frac{1}{4}$, the ring conductor 2408 is connected to the negative pole of battery over the lower contact of cam 2414 and through resistance elements 2419 and 2418, and the tip conductor 2410 is connected to the positive pole of battery through the left-hand contact of cam 2413. Since both resistance elements 2419 and 2418 are included in the fundamental circuit, a weak impulse of negative polarity is transmitted over the fundamental circuit. As switch 2420 rotates from position $14\frac{3}{4}$ to position $15\frac{1}{4}$, the ring conductor 2408 is connected to the positive pole of battery over the right-hand contact of cam 2413, but the tip conductor 2410 being open at this time no impulse is transmitted. During the rotation of switch 2420 from position $15\frac{3}{4}$ to position $16\frac{1}{4}$, the ring conductor 2408 is connected to the negative pole of battery over the lower contact of cam 2414 and through resistance elements 2419 and 2418, and the tip conductor 2410 is connected to the positive pole of battery over the left-hand contact of cam 2413, and the resulting impulse transmitted over the fundamental circuit is weak and of negative polarity.

At the relay call indicator in response to the first impulse of positive polarity, the positively polarized relay 1506 responds and establishes a circuit for the tens lamp relay 1608 which may be traced from ground on conductor 1544 through the armature con-

tact of relay 1506, the outer right-hand battery through the upper contact of cam 2416, the upper contact of cam 2415 (16½ to 17½), conductor 2428, the upper contact of cam 2265 (6 to 7), the No. 1 lead 2266, No. 1 lead 1944, Fig. 19, the outer right-hand armature and front contact of relay 1918, 70 the left-hand armature and back contact of relay 1952, the left-hand armature and back contact of relay 1953, conductor 1945, the upper contact of cam 2438 (16½ to 19½), conductor 2437, contacts of cam 2260, 75 conductor 2261, the left-hand contact of cam 2423 (16¾ to 17¼), the outer left-hand armature and back contact of relay 2400, and to the negative pole of battery through the high resistance element 2417. An impulse of positive polarity is thus transmitted over the fundamental circuit. 80

As switch 2420 rotates from position 17¾ to position 18¼, the ring conductor 2408 is connected to the negative pole of battery 85 over the lower contact of cam 2414 and through resistance elements 2419 and 2418, and the tip conductor 2410 is connected to the positive pole of battery through the left-hand contact of cam 2413. A weak 90 negative impulse is thus transmitted over the fundamental circuit. As switch 2420 rotates from position 18¾ to position 19¼, the ring conductor 2408 is connected to the positive pole of battery over the right-hand 95 contact of cam 2413, but the tip conductor 2410 being open at this time no impulse is transmitted. During the rotation of switch 2420 from position 19¾ to position 20¼, the ring conductor 2408 is connected to 100 the negative pole of battery through the lower contact of cam 2414 and resistance elements 2419 and 2418, and the tip conductor 2410 is connected to the positive pole of battery through the left-hand contact of cam 2413. 105 Since at this time units register relay 1920 is energized, the high resistance element 2419 is shunted from the fundamental circuit by a shunt extending over conductor 2436, the outer right-hand armature and contact 110 of relay 1920, conductor 1946, the lower left-hand contact of cam 2433 (19 to 1), the upper right-hand contact of cam 2433 (19¾ to 20¼), the right-hand armature and back contact of relay 2400, and thence to resistance element 2419. A strong impulse of negative current is thus transmitted over the fundamental circuit. When switch 2420 reaches position 1, as no driving circuits exist for its clutch magnet, it comes to rest 115 120 in its normal position 1.

At the relay call indicator, Figs. 15 and 16, in response to the first impulse of positive polarity, the positively polarized relay 1506 responds and establishes a circuit extending from ground on conductor 1544 over the armature contact of relay 1506, the outer armature and back contact of relay 1508,

5 10 15 20 25 30 35 40 45 50 55 60 65 70 75 80 85 90 95 100 105 110 115 120 125

Transmission of the units digit to the relay call indicator.

During the rotation of switch 2420 from position 16½ to position 20½, a code of impulses is transmitted in accordance with the setting of the units register relays, Fig. 19. It having been assumed that the units digit is 6 and that register relays 1918 and 1920 are at the time energized, a code comprising a positive, a negative and a strong negative impulse is transmitted over the fundamental circuit to control the registration of the units digit upon the units lamp relays of the indicator. As switch 2420 rotates from position 16¾ to position 17¼, the ring conductor 2408 is connected to the positive pole of battery through the right-hand contact of cam 2413, and the tip conductor 2410 is connected to the negative pole of

the outer left-hand armatures and front contacts of relays 1509 to 1515 inclusive, conductor 1540, and thence to battery through the left-hand winding of relay 1609. Relay 5 upon energizing in this circuit closes a locking circuit for itself extending through both of its windings and its inner right-hand armature contact. In response to the second impulse of negative polarity, the negatively 10 polarized relay 1505 responds and in the manner previously described establishes a circuit for relay 1508, which in turn establishes a circuit for relay 1516, which may be traced from battery through the winding of 15 relay 1516, the inner right-hand armature and back contact of relay 1524, and thence through the right-hand armatures and front contacts of relays 1517 to 1523 inclusive, through the intermediate armature and contact 20 of relay 1508 to ground on conductor 1544. Relay 1516 upon energizing establishes a locking circuit for itself extending through the winding of relay 1524 and to ground on conductor 1544 through its inner right-hand armature and front contact. Relay 1524, however, does not energize in this locking circuit since its winding is shunted at the armature contact of relay 1508.

Upon the cessation of the negative impulse of current, relay 1507 becomes energized in the manner previously described. In response to the last strong negative impulse of current, the negatively polarized relay 1505 and marginal relay 1504 both energize, the energization of relay 1505 causing the deenergization of relay 1508, and the energization of marginal relay 1504 establishing a circuit for lamp relay 1610 which may be traced from ground through the armature contact of relay 1504, the outer armature and front contact of relay 1507, the inner left-hand armatures and front contacts of relays 1517 to 1523 inclusive, conductor 1541, the left-hand winding of relay 1610 to battery. Relay 1610 upon energizing locks through both of its windings and its inner right-hand armature and contact to ground on conductor 1527. Upon the cessation of the last negative impulse relay 1507 deenergizes, and since at this time both relays 1507 and 1508 are deenergized, the shunt around the winding of relay 1524 is removed and this relay energizes in the locking circuit of relay 1516. The complete office and numerical designation of the desired line has now been transferred to the lamp relays of the relay call indicator.

Following the rotation of impulser switch 2420 out of position 9 during its second revolution, the locking circuit of relay 2406 is opened at the upper contact of cam 2404, and during the remaining portion of the second revolution of switch 2420 the ring conductor 2408 of the fundamental circuit is con-

nected to conductor 2409 over the right-hand contact of cam 2439 (2 to 20 $\frac{1}{4}$), and the tip conductor 2410 is connected to conductor 2411 over the right-hand contacts of cam 2440 (2 to 20 $\frac{1}{4}$). When switch 2420 reaches position 1 a circuit is established for advancing the sender control switch 1720 out of position 14 into position 16 which may be traced from ground through the lower contact of cam 2253 (7 to 5), the outer left-hand armature and back contact of relay 2313, conductor 2259, the contacts of cam 2258 (7), the right-hand contact of class switch cam 2321 (9), conductor 2412, the outer right-hand armature and back contact of relay 2406, the left-hand contacts of cam 2440 (1), conductor 2441, the lower contacts of class switch cam 2326 (5 to 9) conductor 2327, the lower right-hand and upper left-hand contacts of cam 2266 (7), the upper left-hand contact of cam 1739 (14), and thence to battery through the magnet winding of switch 1720.

With switch 1720 in position 16 a circuit is established for the No. 0' counting relay 2225 which may be traced from ground at the lower contact of cam 2253 (7 to 5) over the circuit previously traced to the upper right-hand contact of cam 1739 (16 to 17 $\frac{1}{4}$), conductor 1740, the winding of the No. 0' counting relay 2225, thence to battery through the winding of the No. 0 counting relay 2224. Relay 2225 upon energizing establishes a circuit from ground at its armature contact over the lower contacts of cam 2230, conductor 2231, the lower left-hand contact of cam 1731 (16), and through the winding of sequence switch magnet 1720 for advancing the control switch into position 17. With switch 1720 in position 17 a circuit is established for advancing the district sequence switch 1320 out of selection beyond position 12 into position 13. This circuit may be traced from battery through magnet winding of switch 1320 conductor 1340, the lower left-hand contact of cam 1339 (12), conductor 1324, wiper 1325, conductors 1326 and 1741, the inner right-hand armature and back contact of relay 2209, conductor 2268, the lower right-hand contact of cam 1742 (17), the lower right-hand contact of cam 1722 (17), conductor 2231, the lower contacts of cam 2230 and thence to ground at the armature and contact of relay 2225, which latter relay is still maintained energized over the contact of relay 1739 until switch 1720 leaves position 17 $\frac{1}{4}$. When district sequence switch 1320 reaches position 13, since at this time the trunk keeping relay 1306 is energized, the sequence switch is advanced directly into position 16 over a circuit which may be traced from battery through the magnet winding of switch 1320, conductor 1340, the upper left-hand contact

of cam 1339 (13) to ground at the inner left-hand armature and front contact of relay 1306.

Restoration of the local sender.

As soon as the district sequence switch 1320 advances out of position $12\frac{1}{2}$ the previously traced holding circuit of relay 1700 is opened at the lower left-hand contact of 10 cam 1318 ($2\frac{1}{2}$ to $12\frac{1}{2}$), and relay 1700 upon deenergizing establishes a circuit extending from ground at its outer right-hand armature and back contact over the upper left-hand contact of cam 1731 (17) for advancing 15 switch 1720 out of position 17 into position 18. Upon the advance of switch 1720 into position 18, the No. 0' counting relay 2225 becomes deenergized. With switch 1720 in position 18 a polarizing circuit is 20 established for the sender stepping relay 2203 for the purpose of polarizing this relay in such a direction as to function properly upon the next seizure of the sender. This circuit may be traced from battery through 25 the upper contacts of cam 1722 (18), resistance element 1723, conductor 1724, the windings of polarized relay 2202 and sender stepping relay 2203, the upper contact of cam 1725 (18), and thence to ground 30 through resistance element 2204. Relay 2203 upon energizing now establishes a circuit for advancing sender sequence switch 2220 into normal position 1, which circuit may be traced from battery through the 35 magnet winding of switch 2220, conductor 2233, the upper left-hand contact of cam 2235 (2 to 18), conductor 2269, the lower contacts of cam 1734, the armature and contact of relay 2203, and thence to ground 40 through the upper right-hand contact of cam 1733 (18).

As soon as sequence switch 2220 reaches normal position a circuit is established for advancing control switch 1720 into normal 45 position which may be traced from battery through the magnet winding of switch 1720, the lower right-hand contact of cam 1731 (18), conductor 1743, the right-hand armature and back contact of relay 1732, if at 50 this time the translator switch has returned to normal position, conductor 1744, thence to ground at the lower left-hand contact of cam 2242 (1). During the restoration of switches 1720 and 2220 into normal position, the sender is maintained busy from 55 ground over the upper right-hand contact of cam 1747 (2 to 18) and through the left-hand winding of relay 1700, this busy ground potential being removed as soon as 60 switch 1720 leaves position 18.

Upon the advance of switch 1720 into position 14 just prior to the transmission of relay call indicator code impulses, ground potential was removed from conductor 1804 65 at the lower contact of cam 1705 (1 to 9),

and all of the relays of Fig. 18 and relays 909 to 912 inclusive of Fig. 19 were unlocked and released. When control switch 1720 leaves position 17 ground potential is removed from conductor 1907 at the lower left-hand contact of cam 1737 (2 to 17), and the tandem hundreds, tens and units relays which were energized and locked during the establishment of the connection are released. When the sender sequence switch 2220 leaves 70 position 17 ground potential is removed from conductor 1811 at the lower right-hand contact of cam 2242 (2 to 17), and the numerical and stations register relays of Fig. 19 are thereupon released. The entire 80 sender has now been restored to its normal condition and may be taken for use in the establishment of other connections.

At the district link circuit, Fig. 13, upon the advance of sequence switch 1320 into 85 position 16, the holding circuit of relay 1306, which up to this time extends from battery through the winding of magnet 1313, conductor 1314, the winding of relay 1306, the left-hand contact of cam 1329 (4 to 18), the 90 outer right-hand armature and front contact of relay 1306, the left-hand contacts of cam 1305, and to ground at the upper right-hand contact of cam 1312 (2 to $15\frac{1}{2}$), is opened at the upper right-hand contact of cam 1312, 95 and relay 1306 is maintained energized by ground potential supplied over the sleeve conductor 1311 of the trunk 1302, 1303.

Indication of the line number upon the lamps of the relay call indicator. 100

Upon the completion of the tandem tens registration on the lamp relays of Fig. 16 and the energization of relay 1511, a circuit is completed for the No. 2 tandem hundreds 105 lamp 1553 which may be traced from battery through the outer right-hand armature and contact of relay 1511, conductor 1545, the outer left-hand armature and back contact of relay 1546, the left-hand armature and front contact of relay 1526, the inner left-hand armature and back contact of relay 1547, lamp 1553 the outer right-hand armature and front contact of relay 1526, the outer left-hand armature and back contact 110 of relay 1547, the outer right-hand armature and back contact of relay 1548, conductor 1549, and thence to ground at the outer right-hand armature and contact of relay 1510. Upon the completion of the tandem units registration and the energization 115 of relay 1512, a circuit is established for relay 1550 which may be traced from battery through the winding of relay 1550 to ground at the outer right-hand armature 120 and contact of relay 1512. Relay 1550 upon energizing establishes circuits for the No. 4 tandem tens lamp 1617 and the No. 3 tandem units lamp 1618. The circuit for lamp 1617 may be traced from battery through 125 130

the inner right-hand armature and contact of relay 1550, conductor 1551, the outer left-hand armature and back contact of relay 1612, the left-hand armature and back contact of relay 1613, the outer right-hand armature and back contact of relay 1614, the left-hand armature and front contact of relay 1600, lamp 1617, the outer right-hand armature and front contact of relay 1600, conductor 1615, the outer left-hand armature and contact of relay 1550 to ground on conductor 1544. The circuit for lamp 1618 may be traced from battery through the outer right-hand armature and contact of relay 1550, conductor 1552, the outer left-hand armature and back contact of relay 1616, the left-hand armature and front contact of relay 1603, the inner left-hand armature and front contact of relay 1602, lamp 1618, the inner right-hand armature and back contact of relay 1616, and thence to ground on conductor 1527.

Tandem lamps 1553, 1617 and 1618 now being illuminated indicate the No. 243 corresponding to the office designation C H E. The operator noting these lamps may proceed at this time to order up the trunk over the order wire, not shown, extending to the indicated office which will be assumed to be the terminating office shown in Fig. 14 and receive from the terminating operator the assignment of a trunk.

Upon the completion of the hundreds registration and the energization of relay 1515, a circuit is established for relay 1554, which latter relay upon energizing establishes circuits for lighting the selected No. 3 thousands lamp 1620 and the No. 9 hundreds lamp 1621. The circuit for lamp 1620 may be traced from battery through the outer left-hand armature and contact of relay 1554, conductor 1555, the outer left-hand armature and front contact of relay 1605, lamp 1620, the outer right-hand armature and front contact of relay 1604, the left-hand armature and back contact of relay 1619, and thence to ground on conductor 1527 through the inner right-hand armature and front contact of relay 1605. The circuit for lamp 1621 may be traced from battery through the inner left-hand armature and contact of relay 1554, conductor 1556, lamp 1621, the left-hand armature and front contact of relay 1606, the outer right-hand armature and back contact of relay 1624, the left-hand armature and back contact of relay 1625, the inner right-hand armature and front contact of relay 1607 to ground on conductor 1527.

Upon completion of the units registration and the energization of relays 1516 and 1524, circuits are established for the No. 1 tens lamp 1622 and the No. 6 units lamp 1623.

The circuit of lamp 1622 may be traced from battery through the intermediate right-hand

armature and contact of relay 1516, conductor 1626, the outer left-hand armature and back contact of relay 1627, the left-hand armature and back contact of relay 1628, the outer right-hand armature and front contact of relay 1608, lamp 1622, the outer right-hand armature and back contact of relay 1627, and thence to ground on conductor 1527. The circuit of lamp 1623 may be traced from battery through the intermediate right-hand armature and front contact of relay 1524, conductor 1629, the outer left-hand armature and front contact of relay 1610, lamp 1623, the outer right-hand armature and front contact of relay 1609, the left-hand armature and back contact of relay 1630, and thence to ground on conductor 1527 through the inner right-hand armature and front contact of relay 1610.

Upon the energization of relay 1524, a circuit is also established extending from ground at the left-hand armature and contact of relay 1524 over conductor 1557, and to battery through the winding of relay 1558 and in parallel through the armature and back contact of relay 1560 to battery through the winding of relay 1503. Relay 1558 upon energizing establishes a circuit for the R stations lamp 1559 which may be traced from battery through the armature and contact of relay 1558, lamp 1559, the left-hand armature and front contact of relay 1534, the left-hand armature and back contact of relay 1560, conductor 1561, the outer right-hand armature and front contact of relay 1514, and thence to ground on conductor 1544. The line designation 3916-R of the desired line terminating in the Chelsea office is now indicated by the lamps of the relay call indicator.

Upon the energization of relay 1503, the holding circuit previously traced through the windings of relays 1502 and 1421 is opened and these relays deenergize. The deenergization of relay 1421 disconnects the control conductors 1423 and 1424 of the relay call indicator from trunk conductors 1403 and 1404 and reconnects the trunk conductors with the windings of relay 1400. Relay 1400 is now energized over the trunk conductors in series with polarized relay 263 of the zero operator's district link and at its armature and contact establishes a locking circuit for relay 1426, in shunt of the winding of relay 1419. Relay 1419 thereupon deenergizes opening at its right-hand armature and contact the initial energizing circuit of relay 1426 and at its left-hand armature and contact the energizing circuit of relay 1421.

Extension of the connection to the terminating office.

The tandem operator, noting the illumination of the lamps of the indicator, picks up

the plug 1430 and tests the sleeve of the trunk jack 1427 of the assigned trunk 1434, 1440 and then inserts the plug in the jack. Upon the insertion of the plug in the jack 5 sleeve relay 1416 is energized over sleeve conductor 1428 and the sleeve contacts of the plug and jack, and at its outer right-hand armature disconnects the tip of the plug 1430 from the test winding of 10 her head set and connects the tip of the plug over conductor 1435 to conductor 1436. Relay 1416 at its inner right-hand armature and back contact opens the holding circuit extending through the windings of relay 1412 and 1500, whereupon 15 these relays deenergize, relay 1500 disconnecting ground potential from the holding conductors 1533, 1527 and 1544 for releasing all energized relays of the relay call indicator. At its outer left-hand armature and back contact, relay 1416 opens the circuit of 20 relay 1409 for disconnecting the lamp 1410 from the circuit extending through the interrupter 1425, the signal on lamp 1410 25 thereupon being changed from a flashing signal, indicating registration upon the relay call indicator, to a dark signal indicating completion of such registration.

With the plug 1430 in the jack 1427 of 30 the assigned trunk 1434, 1440 and sleeve relay 1416 energized, a circuit is now established for relay 1431 which may be traced from battery through the right-hand winding of relay 1432, trunk conductor 1434, the 35 tip contacts of jack 1427 and plug 1420, conductors 1435, 1436, 1437 and 1438, winding of relay 1431, conductor 1439, the ring contacts of plug 1430 and jack 1427, conductor 1440, and to ground through the left-hand 40 winding of relay 1432. Relay 1431 upon energizing establishes a circuit for relay 1441 extending from battery through the winding of relay 1441, the armature and front contact of relay 1431, conductors 1442 45 and 1443 to ground at the outer right-hand armature and front contact of relay 1426, relay 1441 upon energizing locking through its right-hand armature and contact to ground on conductor 1443 independently of 50 the armature contact of relay 1431.

The operator at the terminating office responds to the seizure of the assigned trunk, and in response to the transmission of the line number, indicated on the relay call indicator over the order wire by the tandem operator, inserts plug 1444 in which the trunk 1434, 1440 terminates in the jack 1445 of the indicated line, and proceeds to call the party R on such line, all in the well-known manner. In response to the insertion of the plug in the jack, sleeve relay 1446 60 is energized over the sleeve conductor of the cord and establishes an obvious circuit for the calling lamp 1447. Upon the response 65 of the called subscriber 1450, supervisory

relay 1448 is energized in the well-known manner over the called subscriber's line loop opening at its right-hand armature and contact the circuit of sleeve relay 1446 to extinguish lamp 1447 and closing at its left-hand armature and contact the circuit of relay 1433. Relay 1433 upon energizing disconnects bridged battery from conductors 1434 and 1440 of the trunk circuit, whereupon relay 1431 at the tandem operator's trunk circuit deenergizes. With relay 1441 energized and relay 1431 deenergized, a circuit is now established for reversing relay 1401 which may be traced from battery through the winding of relay 1401, the left-hand armature and contact of relay 1441, the armature and back contact of relay 1431, and thence to ground on conductor 1443. The energization of reversing relay 1401 reverses the connection of the terminals of battery to the trunk conductors 1403, 1404, thereby causing the current flowing over the trunk circuit through the district selector 1350 over trunk circuits 1302 and 1303 through the windings of polarized relay 263 to cause the energization of polarized relay 263. 70 75 80 85 90 95 100

Relay 263, upon energizing in response to reversal of current over the trunk line leading to the tandem office, establishes a circuit for relay 236 which may be traced from battery through the winding of relay 236, right-hand armature and back contact of relay 268 and to ground at the armature and front contact of relay 263, and relay 236 locks up over its inner left-hand armature contact to ground at the left-hand contact of cam 204 (2 to 18). At its outer left-hand armature and back contact relay 236 opens the circuit of lamp 208 and since at this time lamp 210 is dark, the semi-mechanical or zero operator is apprised of the fact that the called subscriber has answered. 105 110 115

During the conversation the calling subscriber 150 receives talking current from battery through the left-hand winding of repeating coil 214 at the zero operator's link circuit and the called subscriber 1450 receives talking current from the battery associated with the terminating operator's cord circuit, Fig. 14, the talking path between the two subscribers extending over the conductors indicated by the heavy lines of Figs. 1, 2, 13 and 14. 120 125 130

Upon the termination of the conversation the subscribers restore their receivers to their switchhooks and at the terminating operator's position, relay 1448 deenergizes, reestablishing the circuit of sleeve relay 1446 to establish the circuit of lamp 1447 and to reconnect battery and ground through the windings of relay 1432 to the conductors 1434 and 1440 of the trunk circuit extending to the tandem office. The operator at the terminating office noting the 130

illumination of lamp 1447 withdraws the plug 1444 from the jack 1445, thereby restoring the apparatus at her position to normal condition. Upon the connection of battery and ground to the conductors of the trunk circuit 1434 and 1440, relay 1431 again energizes, opening the circuit of reversing relay 1401, which thereupon restores the initial connection of battery and ground to the conductors of trunk 1403 and 1404 for causing the release of polarized relay 263 at the zero operator's link circuit. Upon the release of relay 263, with relay 236 energized, a circuit is established for the supervisory lamp 210 which may be traced from battery through lamp 210, the upper contact of cam 211 (11 to 13), the right-hand armature and contact of relay 236 and to ground at the armature and back contact of relay 263.

Upon the restoration of the calling subscriber's receiver to its switchhook, relay 213 which has been maintained energized over the subscriber's line loop during the conversation deenergizes, establishing a circuit for lamp 212 which may be traced from battery through this lamp, the armature and back contact of relay 213 and thence to ground at the upper contact of cam 257 (2 to 18). The operator noting the illumination of lamps 210 and 212 withdraws the plug 112 from the jack 113, thereby opening the circuit previously traced through the windings of relays 116 and 200. Since at this time relay 207 is deenergized, its locking circuit having been opened upon the release of relay 213, a circuit is established for relay 274 which may be traced from battery through the winding of relay 274, left-hand contact of cam 269 (11 to 16), the upper armature and contact of relay 200 and to ground at the right-hand armature and back contact of relay 207. Relay 274, upon energizing, closes a locking circuit for itself over its inner left-hand armature and contact to ground at the left-hand contact of cam 204 (2 to 18), and at its right-hand armature and front contact establishes a circuit extending over the left-hand contact of cam 270 (11 to 16), for advancing sequence switch 220 into position 17. Upon reaching position 17 a circuit is established for advancing sequence switch 220 into position 18 over the right-hand contact of cam 269 (17), the upper armature and contact of relay 200 and to ground at the right-hand armature and contact of relay 207.

With switch 220 in position 18 a circuit is established for the downdrive magnet 271 which may be traced from battery through the winding of magnet 271 and to ground through the right-hand contacts of cam 270 (18). The energization of downdrive magnet 271 in the well-known manner through the operation of downdrive roller 272 drive,

the switch shaft 231 downwardly into normal position. When the switch shaft reaches its normal position a circuit is established for advancing the sequence switch 220 into its normal position, this circuit extending through the magnet winding of switch 220, the upper right-hand contact of cam 219 (5 to 18), normal commutator segment 273, shaft wiper 240 and thence to ground at the upper contact of cam 204 (9 to 7). The selector switch 250 and the sequence switch associated therewith are now in normal position.

At the trunk circuit 102, upon the de-energization of relay 116, the circuit of relay 109 is opened and since at this time there is no energizing circuit for line relay 103, the calling subscriber having restored his receiver to the switchhook, relay 109 disconnects ground potential from the test terminal 110 thereby causing the release of selector switch 101 and of line switch 100.

Upon the restoration of the district selector switch 250, the sleeve circuit over test brush 244 is opened at the upper left-hand contact of cam 241 and relay 1306 which has been held energized over this circuit during the establishment of the connection deenergizes, closing at its inner right-hand armature and back contact a circuit extending over the upper right-hand contact of cam 1339 (16 to 17), and conductor 1340 for driving sequence switch 1320 out of position 16 into position 18. With switch 1320 in position 18 a circuit is established for the downdrive magnet 1369 which may be traced from battery through the winding of magnet 1369 to ground through the upper right-hand and lower left-hand contacts of cam 1318. In the well-known manner upon the energization of magnet 1369 the depending portion of the switch shaft 1343 is pressed against the downdrive roller 1370 and the switch shaft is moved downwardly into normal position. Upon reaching normal position a circuit is established for advancing sequence switch 1320 into normal position which may be traced from battery through the magnet winding of switch 1320, the upper right-hand contact of cam 1310 (7 to 18), normal segment 1347, shaft wiper 1348, thence to ground at the right-hand contact of cam 1334. The local district selector 1350 and the sequence switch associated therewith are now in normal position.

Upon the movement of sequence switch 220 of district selector 250 beyond position 15 during the restoration of switch 250, the circuit of relay 1400 is opened, whereupon the locking circuit of relay 1426 is broken. Relay 1426, upon deenergizing, opens the locking circuit for relay 1441 and establishes a circuit for disconnect lamp 1417 which may be traced from battery through the outer left-hand armature and front con-

- tact of sleeve relay 1416, lamp 1417 and to ground at the outer right-hand armature and back contact of relay 1426. The operator noting the illumination of disconnect 5 lamp 1417 withdraws the plug 1430 from the jack 1427, whereupon sleeve relay 1416 becomes deenergized and all apparatus associated with her link circuit is restored to normal position. The entire apparatus 13 which has been employed in the establishment of the previously described connection is now in normal position and may be employed in the establishment of other connections.
- 15 *The establishment of a full mechanical connection in the local area by the zero operator.*

- Should the zero operator be called upon 20 to establish a connection with a subscriber in a full mechanical office, she would record the number of the desired line upon the keys of her keyboard in the same manner as was previously described and her suburban 25 sender would then function in the manner described to transfer the call by means of code impulses to a local sender associated with a district selector having access to the desired full mechanical office. The local 30 sender functions in the same manner as previously described for recording the office and numerical designation of the desired line upon its register relays and code registers up to the point where the sender sequence switch 2220 reaches position 6 following the setting of the district switch, for example, district switch 1350 and an office selector if one is employed. Since the call 35 is to be established to a full mechanical office, the class switch 2320 has been set by the class relays of the sender into position 2 instead of position 9 as previously described.

- When the sender sequence switch 2220 45 reaches position 6 following the setting of the district selector and office selector, or if the office selector is omitted following the skip office functioning of the sender, a circuit is established for advancing sender control switch 1720 into position 16. This circuit may be traced from battery through the magnet winding of switch 1720, the left-hand contacts of cam 1739 (14), conductor 1745, the left-hand armature and back 50 contact of relay 2305, and thence to ground through the right-hand contact of class switch cam 2331 (2). A trunk test fundamental circuit is now established through the winding of trunk test relay 2307 for 55 testing the condition of the trunk which has been seized extending into the desired full mechanical office. This fundamental circuit is the same as previously described for the trunk test except that high resistance 60 element 2330 is included in series with the

winding of relay 2307 through the lower contact of class switch cam 2308 (2). If the tested trunk is in condition for extending the desired connection, relay 2307 energizes, establishing the previously traced 70 circuit for relay 2313 which closes a circuit for advancing sender sequence switch 2220 into position 7. This circuit may be traced from battery through the magnet winding of switch 2220, the lower contacts of cam 75 2254, conductor 2255, the outer left-hand armature and front contact of relay 2313, conductor 2322, the upper contact of cam 2323 (2 to 3), the lower right-hand and upper left-hand contacts of cam 2407, the lower 80 contact of cam 2316 (2 to 3), the outer right-hand armature and back contact of relay 2305, conductor 2318, and thence to ground at the upper right-hand contact of cam 2353. Upon reaching position 7, switch 2220 is 85 advanced into position 8 over conductor 2233, the upper right-hand contact of cam 2235 (7), and the left-hand contact of class switch cam 2331 (2). In positions 8 and 10 of sender sequence switch 2220, the counting 90 relays of the sender are controlled over the lower contacts of cam 2240 in accordance with the setting of the incoming brush and incoming group translator register relays, Fig. 19, to control the setting of the incoming selector of the desired mechanical office. Since the functioning of the incoming and final selector switches of the full mechanical office is not relevant to this invention, no disclosure of these switches has been made. 95 For a full disclosure of the switches in the manner in which they are operated, reference may be had to the patent to F. A. Stearn, No. 1,505,171, issued Aug. 19, 1924.

In positions 12, 14 and 16 of switch 2220, 105 the counting relays are controlled over the contacts of cam 2270 in accordance with the setting of the final brush, tens and units register relays of Fig. 19 to control the setting of the final selector switch. Following 110 the completion of units selection and the energization of the No. 0' counting relay 2225, sender sequence switch 2220 is advanced into position 17 over a circuit extending from battery through its winding, 115 the upper left-hand contact of cam 2230 (16), the lower right-hand contact of this cam (5 to 3), and to ground at the armature contact of relay 2225.

With the sender sequence switch 2220 in 120 position 17 a fundamental circuit is established from the office sender and through the incoming selector and reverse current is received over this fundamental circuit for energizing both the sender stepping relay 125 2203 and the polarized overflow relay 2202. With both relays 2202 and 2203 energized, a circuit is established for the No. 0 counting relay 2224 which may be traced from battery through the winding of this relay, 130

conductor 2228, the inner left-hand armature and back contact of relay 2227, conductor 2226, the lower left-hand and upper right-hand contacts of cam 1728 (17), the 5 armature and contact of sender stepping relay 2203, conductor 2271, the upper contact of class switch cam 2332 (14 to 3), conductor 2333, the left-hand contact of cam 1746 (17), and to ground at the armature and contact of 10 polarized relay 2202. The No. 0 counting relay 2224, upon energizing, locks up through the windings of the No. 0' counting relay 2225 and relay 2229 in parallel. As soon as the fundamental circuit is opened at the incoming 15 selector, relay 2203 becomes deenergized and relays 2225 and 2229 energize in the locking circuit of No. 0 counting relay 2224. Upon the energization of relay 2225 a circuit is established for advancing district 20 sequence switch 1320 out of position 12 and into the talking position 16 as previously described. Following the advance of the district sequence switch 1320, the local sender is restored in exactly the same manner as 25 hereinbefore described.

The establishment of a connection through one or more mechanical tandem offices.

Should the zero operator be called upon to 30 establish a connection with a line in a distant office to be reached through intervening mechanical tandem offices, she would record the number of the desired line upon the keys of her keyboard in the same manner as was previously described and her 35 suburban sender would then function in the manner described to transfer the call by means of code impulses to a local sender associated with a district having access to 40 the first mechanical tandem office through which the connection is to be extended. The local sender functions in the same manner as before described to record the office and 45 numerical designations of the desired line, but since the call is for a mechanical tandem office the class switch 2320 is set into position 4. The local sender then proceeds to 50 set the district selector 1350 to select an idle trunk extending to the mechanical tandem office. Referring to the diagram of Fig. 29 it will be noted that the switch 1350 selects a district selector in the first mechanical tandem office which may be identical in structure to itself.

55 As soon as the district selector in the mechanical tandem office is seized an idle sender is associated therewith in the manner described in connection with the operator's local sender and the impulser switch 60 2420 of the local sender thereupon proceeds to transmit codes of impulses corresponding to the tandem office and numerical designations of the desired line. These impulses are recorded upon the registers of the selected 65 mechanical tandem sender in the manner

previously described. If as assumed, the desired line is to be reached through a second mechanical tandem office, the impulses recorded upon the registers of the sender in the first mechanical tandem office are 70 again retransmitted to a register sender in the second mechanical tandem office from whence they may be again retransmitted to a call indicator in a manual tandem office in the manner hereinbefore described. 75

Had the desired line terminated either in the first or second mechanical tandem office, the sender of such office would have controlled the full mechanical extension of the connection to the subscriber's line by setting 80 incoming and final selector switches in the manner hereinbefore described. The complete circuits for extending a connection through one or more mechanical tandem offices have not been fully disclosed herein, 85 but since the apparatus of each tandem office may be identical with the local sender apparatus of Figs. 17 to 24, inclusive, it has been thought unnecessary to repeat the detail circuits at each tandem office. 90

It will be obvious from a consideration of the circuit diagram of Fig. 28 that the calling subscriber may obtain his own connections through the mechanical tandem offices to the line of a desired subscriber by 95 dialing the complete designation of the desired line. In that case the sender of the office in which his line terminated controls the selection of a trunk circuit extending to the first mechanical tandem office through 100 which the desired connection is to be extended and then transmits code impulses to set the registers of a register sender in the mechanical tandem office to record the complete line designation. From that point the 105 connection is established in the manner outlined above.

What is claimed is:

1. In a telephone exchange system, a sending device, registers associated therewith, 110 means for registering upon said registers the designations of desired connections, selectively operable mechanism, means for controlling said mechanism comprising a plurality of registers, and means for transferring designations from the registers of said sending device to the registers of said controlling means by means of impulses of varying characteristics. 115

2. In a telephone exchange system, a sending device, registers associated therewith, means for registering upon said registers the designation of a desired connection, selectively operable mechanism, other registers, means for transferring designations from the 125 first named registers to said latter registers by means of impulses of varying characteristics, and means under the control of said latter registers for controlling said mechanism. 130

- second sending device operated in accordance with certain of its registers for controlling said switches and in accordance with the setting of all of said registers for controlling its mechanism.
11. In a telephone exchange system, a sending device, registers associated therewith, means for registering upon said registers the office and numerical designation of a desired line, a second sending device, tandem and numerical registers associated therewith, means under the control of said first sending device for extending a connection therefrom to said second sending device, means effective thereupon for transferring the designation registered upon the registers of said first device to the registers of said second device by means of impulses of varying characteristics, selectively operable mechanism, selector switches for extending a connection from said second sending device to said mechanism, and means under the control of said second sending device operated in accordance with the office designation registered by said tandem registers for controlling said switches and in accordance with the office and numerical designation registered upon both said tandem and numerical registers for controlling said mechanism.
12. In a telephone exchange system, a sending device, registers associated therewith, means for registering upon said registers the office and numerical designation of a desired line, a second sending device, registers associated therewith, each of said latter registers comprising a group of relays, means for transferring said designation from the first named registers to said latter registers, code registers adapted to be variously set in accordance with the setting of certain of said relay registers, a control switch and register control relays adapted to be set by said code registers, selectively operable mechanism, and means under the control of said second sending device in accordance with the setting of said relay registers and register control relays for controlling said mechanism.
13. In a telephone exchange system, a sending device, registers associated therewith, means for registering upon said registers the designation of a desired line, an impulser switch associated with said device, a second sending device, registers associated therewith, means under the control of said switch for transmitting impulses of varying characteristics in accordance with the setting of the registers of said first device to transfer the line designation to the registers of said second device, a selectively operable mechanism, and means under the control of said second device and in accordance with the setting of the registers thereof for controlling said mechanism.
14. In a telephone exchange system, a sending device, registers associated therewith, means for registering upon said registers the designation of a desired line, an impulser switch associated with said device, a second sending device, relay registers associated therewith, means under the control of said switch for transmitting impulses of varying characteristics in accordance with the registers of said first device to transfer the line designation to said relay registers, a selectively operable mechanism, and means under the control of said second device and in accordance with the setting of said relay registers for controlling said mechanism.
15. In a telephone exchange system, a sending device, registers associated therewith, an operator's keyboard, means under the control of said keyboard for registering upon said registers the designation of a desired line, a second sending device, registers associated therewith, means for transferring said line designation from the registers of said first device to the registers of said second device by means of impulses of varying characteristics, selectively operable mechanism, means under the control of said second device and in accordance with the setting of the registers thereof for controlling said mechanism.
16. In a telephone exchange system, selector switches for extending connections, a sending device, a multi-position route switch associated with said sending device for governing the selective movements of said selector switches, a group of register relays associated with said sending device for determining the positioning of said route switch, and means for variously energizing said relays in accordance with desired routings of connections.
17. In a telephone exchange system, selector switches for extending connections, a sending device, a route switch associated with said sending device for governing the selective movements of said selector switches, a group of register relays associated with said sending device for determining the positioning of said route switch, and means for transmitting codes of impulses of varying characteristics for variously energizing said relays in accordance with desired routings of connections.
18. In a telephone exchange system, an operator's position, selector switches for extending connections from said operator's position, a sending device, a route switch associated with said sending device for governing the selective movements of said selector switches, a group of register relays associated with said sending device for determining the position of said route switch, a keyboard, and means associated with said keyboard for transmitting codes of impulses for variously energizing said relays in ac-

- cordance with desired routings of connections.
19. In a telephone exchange system, an operator's position, selector switches for extending connections from said operator's position, a sending device, a route switch associated with said sending device for governing the selective movements of said selector switches, a keyboard, a plurality of routing keys thereon, a group of register relays associated with said sending device less in number than said routing keys, means under the control of said keys for transmitting codes of impulses to variously energize said relays, and means controlled by said relays for determining the positioning of said route switch in positions corresponding in number to the number of said keys.
20. In a telephone exchange system, an operator's position, selector switches for extending connections from said operator's position, a sending device, a route switch associated with said sending device for governing the selective movements of said selector switches, a keyboard, routing keys thereon equal in number to the number of routes accessible from said operator's position, a group of register relays associated with said sending device less in number than said routing keys, means under the control of said keys for transmitting codes of impulses to variously energize said relays, and means controlled by said relays for determining the positioning of said route switch into positions corresponding in number to the number of said keys.
21. In a telephone exchange system comprising a plurality of offices between certain of which direct trunk lines exist and between others of which no direct trunk lines exist, means at each office for registering the complete designation of a desired line, means at each office for extending connections to desired lines terminating therein, means for extending connections between offices, and means under the control of said registering means for alternatively governing the first named line extending means or for governing the second named line extending means and for repeating the complete line designation to another office.
22. In a telephone exchange system comprising a plurality of offices between certain of which direct trunk lines exist and between others of which no direct trunk lines exist, means at each office for registering the complete designation of a desired line, means at each office for extending connections to desired lines terminating therein, means for extending connections between offices, and means under the control of said registering means for alternatively governing the first named line extending means or for govern-
- ing the second named line extending means and for repeating the complete line designation to another office, said line designation being repeated successively through several offices.
23. In a telephone exchange system comprising a plurality of offices, the method of establishing connections which consists in registering the designation of a desired line upon registering apparatus in an originating office, selecting a trunk line to a second office, retransmitting said designation to said second office, registering said designation in said second office and continuing to extend said connection, retransmit and register said designation through successive offices and ultimately controlling the completion of the connection at the office in which the desired line terminates in accordance with the last registration of said line designation.
24. In a telephone exchange system comprising a plurality of offices, the method of establishing connections which consists in registering the designation of a desired line upon the registering apparatus in the originating office, selecting a trunk line to a second office, retransmitting said designation to said second office by means of impulses of varying characteristics, registering said designation in said second office and continuing to extend said connection, retransmit and register said designation through successive offices and ultimately controlling the completion of the connection at the office in which the desired line terminates in accordance with the last registration of said line designation.
25. In a telephone exchange system comprising a plurality of offices, the method of establishing connections which consists in registering the complete designation of a desired line upon the registering apparatus in an originating office, selecting a trunk line to a second office in accordance with the office designation of a desired line, retransmitting said complete designation to said second office, registering said designation in said second office and continuing to extend said connection, register and retransmit said line designation through successive offices and ultimately controlling the completion of said connection at the office in which the desired line terminates in accordance with the last registration of said line designation.
26. In a telephone exchange system comprising a plurality of offices in which desired lines terminate, the method of establishing connections which consist in registering the complete designation of desired lines upon the registering apparatus in an originating office, alternatively extending connections to the desired line accessible over direct trunks from the originating office or extending con-

nections to a second office, retransmitting said designations to said second office, registering said designations in said second office, alternatively repeating said connections over 5 direct trunks accessible from said second office or further extending said connections to another office and continuing to extend said connections, register and retransmit said line designations through successive 10 offices and ultimately controlling the completion of the connections at the office in which the desired lines terminate in accordance with the designations of such lines.

27. In a telephone exchange system, a calling line, a desired line, a sending device, registers associated therewith, means for registering upon said registers the office and numerical designations of said desired line, a second sending device, registers associated 15 therewith, means for transferring said designation from the registers of the first device to the registers of the second device, other sending devices, registers associated therewith; means for successively transferring 20 said designation from one sending device to another, and means controlled by each sending device in succession for extending a con- 25

nection from said calling line toward said called line.

28. In a telephone exchange system, a calling line, a desired line, a sending device, registers associated therewith, means for registering upon said registers the office and numerical designations of said desired line, a second sending device, registers associated 30 therewith, means for transferring said designation from the registers of the first device to the registers of the second device, other sending devices, registers associated therewith, means for successively transferring 35 said designation from one sending device to another, means controlled by each sending device in succession in accordance with the office portion of said designation for extending a connection from said calling line toward said called line, and means controlled by the sending device last employed in accordance with the numerical designation of the desired line for completing the desired 40 connection. 45

In witness whereof, I hereunto subscribe my name this 28th day of June A. D., 1921.

WILLIAM L. DODGE.
